UNITED STATES PATENT OFFICE

BOLF HOFGAARD, OF STABEKK, NEAR OSLO, NORWAY, ASSIGNOR TO HOFGAARD-REMINGTON CORPORATION, OF NEW YORK, N. Y., A CORPORATION OF DELAWARE

CALCULATING MACHINE

Application filed March 12, 1929, Serial No. 346,292, and in Great Britain March 13, 1928.

This application is a continuation in part of my copending application Ser. No. 292,388, filed July 13, 1928.

The present invention has for its object an electric calculating machine which is based on the general broad principle of operation described and claimed in my copending U. S. patent applications Serial Number 688,564, filed January 25, 1924 and Ser. No. 221,330 filed September 22, 1927; and this application is, as to certain features, a continuation in part of the said applications.

According to the principle of operation described and claimed in the afore-mentioned 15 patent applications, the electric calculating machine comprises two sets of 10 digit lines, said digit lines being adapted to be interconnected in 10 different group combinations through suitable contact units by the closing 20 of contacts corresponding to the various numbers entering into the calculation, and each group combination again comprises 10 possible single combinations as between individual digit lines. Therefore, there are, as between 25 individual digit lines 100 possible combinations between the two sets of each ten digit lines.

In the present embodiment I elect to employ as in said applications sets of relays, 30 the relays of a given set corresponding in number to the digits of the numerical monetary or other system for which the machine is adapted to be used, i. e. in the ten-digit system of numbers, I employ ten relays in 35 each set, each relay corresponding respectively to the digit values 1-0 inclusive; and respective relays each having contact means representing digit values 1-0 inclusive.

The machine also comprises registering elements, each of which is adapted to be operated by a current passing through a line in one of the afore-mentioned sets of digit lines. The said registering elements in turn control contact members for closing said lines in 45 the other set of digit lines.

In a calculating machine of this kind, the effect of depressing a certain key on the key board will depend on the key of the same denominational value previously depressed, 50 the result registered being equal to any func-

tion of the digits corresponding to the said keys for which the particular machine is constructed.

Thus, in an adding machine for single numbers, if key No. 3 has been depressed, the 55 depression of key No. 4, owing to the combination in which the two sets of 10 digit lines have been connected by the key No. 3, through one of the relays in the interconnecting sets of relays, will actuate the registering element 60 for No. 7, and so on.

In the calculating machine, according to this principle which was described in the afore-mentioned patent application Serial Number 688,564, the means for successively 65 registering the effects of depressions of the keys consist in a ribbon or strip which is caused to be perforated by means of electrically operated perforating members, said perforations acting to establish the contacts 70 for closing the digit line circuit upon the depression of the next key.

In my copending U. S. application Ser. No. 221,330, filed September 22, 1927, I have disclosed an improved manner of recording and 75 registering, such for example as by means of relays. The present invention embodies this improvement and in this respect is in part a continuation of said last-mentioned application.

One object of the present invention is to provide an electric calculating machine of the type specified by means of which it is possible to perform all the four principal kinds of calculation, that is, addition, subtraction, multiplication and division, by means of one single set of digit keys, corresponding in number to the digit system employed, i. e. in the present embodiment a series of 10 keys, with an appropriate number of control keys for setting the machine for the calculation to be performed.

Another object of the present invention is to provide an electric calculating machine of the type specified, comprising the least possible amount of mechanical elements commensurate with the preferred manner of performance. The machine, according to the present invention, comprising principally a combination of multiple contact relays 80 85 90 95 100

of substantially the same general type, thus providing a calculating machine easily adopted for mass production.

Another object of the present invention 5 is to provide an electric calculating machine of the type specified, comprising one or more register units each comprising a number of registering elements, each registering element comprising a set of contacts, and the 10 product of the number of registering elements and number of contacts in each element being equal to the product of the number of digits in the numerical system employed and the number of denominations for 15 which the machine is adapted; and each of said register units cooperating with a set of calculating contact relays, and being adapted to operate independently or in cooperation with each other, in order to automatically 20 perform various combinations of calculating operations with the numbers entered into the machine such as by means of the key board.

Another object of the present invention 25 is to provide an electric calculating machine, in which the contacts of each multiple contact relay of the registers cooperate with electrically operated means for locking the contacts closed, and again releasing the same 30 and locking them in open position when a new number of the same denominational value is entered into the same register.

Another object of the present invention is to provide an electric calculating machine 35 of the type specified, having means for automatically reversing the order of the digits entered into the machine, such as by means of the key board, in a machine for multi-digit numbers. The purpose of this improvement is to enable numbers to be entered into the machine, starting with the digit of the largest denominational value, causing, however, the digit of the smallest denominational value to operate first and so on, whereby 45 the process of tabulating is greatly simplified.

Another object of the present invention is to provide an electric calculating machine, having novel means for enabling the operator 50 to ascertain at any time during the entering of a number into the machine the number of digits which he has entered.

Another object of the present invention is to provide an electric calculating machine of 55 the type specified, having means for enabling the operator to clear the machine of the last number entered therein, so as to be able to correct possible mistakes in entering.

Another object of the present invention is 60 to provide an electric calculating machine of the type specified, having one or more register units, each of which may be utilized in connection with suitable calculating relays for the desired calculating; and means co- 65 operating with said register units by means

of which a number entered into the machine may be transferred to one or more of said register units for the purpose of being mathematically combined with the number previously set up in said register, or for the purpose of automatically clearing said register of any number previously set up therein, said number being then replaced by the new number transferred to said register.

Another object of the present invention is 75 to provide an electric calculating machine of the type specified, having means for entering a number into one or more registers either in the direct or reversed order: such provision being of advantage in connection with reversal of the second and following numbers (i.e. such as the second factor in multiplication or the divisor) in a multiplication or division process for the purpose of facilitating the tabulation of the recording mechanism, as 80 will be explained in detail in the following specification.

Another object of the present invention is to provide an electric calculating machine of the type specified, having means for indicating 90 optically or otherwise the moment at which the full capacity of the machine has been reached.

Another object of the present invention is to provide an electric calculating machine of 95 the type specified, having means to prevent a larger number from being subtracted from a smaller number as well as means for automatically indicating and recording the moment at which the result of a series of addition or subtraction calculations passes from positive to negative value or vice versa.

Another object of the present invention is to provide an electric calculating machine of 100 the type specified, having means for automatically wiping out one or more of the last digits of a number, and increasing the value of the last remaining digit by one, in case the numerical value of the following number would be equal to or more than a predetermined numerical value (in the present embodiment five or more).

Another object of the present invention is to provide an electric calculating machine of 115 the type specified, having means for enabling the operator at any time during the working of the machine to ascertain the number set up in any of the register units of the machine.

Another object of the present invention is to provide an electric calculating machine of 120 the type specified by means of which the division of one number in another is performed automatically, means being provided for setting the machine for any desired number of digits in the quotient, and for making the machine automatically stop the division process when the desired number of digits in the quotient has been reached and recording the result of the division performed.

Another object of the present invention is 125

to provide an electric calculating machine of the type specified, having means for maintaining the remainder of any division process set up in a register in order to enable the 5 operator to ascertain the amount of said remainder after the division operation has been performed.

Another object of the present invention is to provide an electric calculating machine of 10 the type specified, adapted to perform a number of consecutive multiplications or divisions either by multiplying or dividing the result of a multiplication or a division operation performed with the next number entered 15 in the machine, or by multiplying or dividing a series of consecutive numbers entered in the machine with a certain number previously entered in the machine.

Further and more specific objects, features 20 and advantages will more clearly appear from the detailed description given below taken in connection with the accompanying drawings which form a part of this specification.

25 In order that the principles of my invention may be better understood, I shall now proceed in the following specification to describe various details of a calculating machine constructed in accordance with a present 30 preferred embodiment of my invention, as well as some embodiments of calculating machines adapted for addition as well as for addition in combination with other calculating processes, such as subtraction, multiplication, 35 and division.

On the drawings, Fig. 1 represents diagrammatically a plan of a registering device for a calculating machine in accordance with the principles of my invention; serving principally as a simple illustration of this feature of the invention.

Fig. 2 is a diagrammatic cross section on the line 2—2 on Fig. 1 seen in the direction of the arrows. The circuit leads have been 45 omitted from Fig. 2 for the sake of clearness.

Fig. 3 is a detail section through one of the multiple contact relays illustrated on Fig. 2 during the reverse movement of the locking mechanism.

50 Fig. 4 is a detail section similar to Fig. 3, illustrating the locking armature of the relay locked in a different position from that illustrated on Fig. 2.

Figs. 1, 2, 3 and 4 above referred to serve to 55 illustrate the principles of a registering device by means of which electric impulses may be registered and stored in multiple contact relays, the armatures of which are adapted to be locked in different positions by means of a locking device.

The said multiple contact relays which constitute one of the principal features of the present machine serve as a substitute for the registering device specified in my above 60 mentioned U. S. patent application Ser. No.

688,564, and it will be understood that the contact armatures of these multiple contact relays will be retained by the locking mechanism in one or the other of two different positions irrespective of the energization of the multiple contact relays, being permitted to move from one position to another under the influence of the magnetic relays or of their own spring action only when released by the locking mechanism. Certain features of the locking relay registering device, herein disclosed but not claimed, form the subject matter of my copending application, Ser. No. 221,330, above referred to.

Although the locking mechanism here illustrated as the preferred form is a mechanical locking mechanism, it will easily be understood that the locking mechanism may also consist in a magnetic locking device, the magnets whereof are adapted to be energized or de-energized independent of the relay magnets.

It will be understood in accordance with the following specification that for performing calculating operations in a numerical system comprising n digits, the registering device of the present preferred embodiment will have to comprise n multiple contact relays. The registering device illustrated on Fig. 1 comprises three multiple contact relays and accordingly would serve for a numerical system comprising three digits. For the usual decimal system the registering device would comprise ten multiple contact relays of the same type; the three digit system having been assumed as an illustration for purposes of simplicity merely, and as an introduction to the decimal digit machine to be described hereinafter as illustrating a present preferred embodiment of the invention.

The number of locking armatures in each multiple contact relay in the present embodiment of the invention is determined in each case in accordance with the highest denominational value for which the calculating machine in question should be adapted. Thus, a machine adapted to perform calculating operations with numbers up to 99,999 will have to be provided in each multiple contact relay with five locking contact armatures.

Fig. 5 is a diagrammatic plan view of a register unit constructed according to the principles of my invention and adapted for the decimal numerical system, and hence being provided with 10 register elements in the form of multiple contact relays; and in connection therewith is shown two switching relays associated therewith, the purpose of which will be explained below. It will be noted that for the sake of clearness some mechanical details of the locking mechanism have been omitted on Fig. 5; it being understood that such details are similar to those shown in Fig. 1.

Fig. 6 is a diagram of a key board adapt-

ed to be used in connection with the registering device illustrated on Fig. 5 for registering representations of numbers in the several relays of the latter, responsive to current impulses corresponding to the several keys of the said key board.

Fig. 7 is a diagrammatic plan view serving to illustrate the general principles of an addition machine in accordance with my present invention; and also serving to illustrate the principles of reversing the order of impulses during transmission from one registering device to another, and of subtracting and of recording.

Fig. 8 is a diagrammatic plan of reversing relays and relays utilized in the recording of totals with or without the discarding of decimals; Fig. 8 being schematically shown on Fig. 7 as IV.

Fig. 8a is a diagrammatic plan view illustrating the devices of Fig. 8 and the auxiliary reversing relays utilized for division; and forms a part of Figs. 16, 17 and 18 respectively.

Fig. 9 is a diagrammatic plan view of a complete set of addition relays adapted for a numerical system comprising ten digits.

Fig. 9a is a diagrammatic plan view of a set of relays for transfer operations and auxiliary relays for performing subtraction by means of said addition relays such as are illustrated in Fig. 9.

Fig. 10 is a purely schematic diagram illustrating the general manner of connecting certain units, and comprising as a part thereof of a standard register assembly.

Fig. 10a is a diagrammatic plan view showing detail circuits of a standard register assembly; and forming a part of Figs. 16, 17 and 18 respectively.

Fig. 11 is a diagrammatic illustration showing various unitary parts and their interconnections for performing multiplication according to a present preferred embodiment of my invention.

Fig. 11a is a diagrammatic plan view forming a part of Figs. 17 and 18.

Fig. 12 is a diagrammatic plan view of a set of calculating relays for multiplication purposes adapted for a numerical system comprising ten digits.

Fig. 13 is a purely schematic diagram illustrating the general principle of a multiplication circuit.

Fig. 14 is a similar showing of these circuits as adapted for selection in division.

Fig. 14a is a diagrammatic plan view forming a part of Fig. 18.

Fig. 14b is a plan view of the division ratchet mechanism and associated electrical connections diagrammatically shown in Fig. 14a.

Fig. 15 is a more or less diagrammatic plan view illustrating a part of Figs. 16, 17 and

18, and comprising the recorder and key board.

Fig. 16 is a diagram of the arrangement of Figs. 15, 10a and 8a, which together illustrate a machine adapted to add, subtract and transmit; in accordance with the principles described in connection with Fig. 7.

Fig. 17 is a diagram of the arrangement of Figs. 15, 10a and 11a and 8a, which together illustrate a machine adapted to perform the functions of the machine illustrated in Fig. 16, and also multiplication; in accordance with the principles described in connection with Fig. 11 and

Fig. 18 is a diagram of the arrangement of Figs. 15, 10a, 14a, 11a and 8a, which together illustrate a machine adapted to perform the functions of the machine illustrated in Fig. 17, and also division.

Introduction to registering device principle of construction and operation

The registering device illustrated on Figs. 1-4 comprises a number of multiple contact relays co-operating with a magnetically operated ratchet device for actuating the locking mechanism for the locking armatures in the said relays.

Referring to Fig. 1, each of the relays Ab, Ad and Ae comprises a coil B (Fig. 2), one terminal of which is permanently connected to the minus line of the battery, the relay being cut in and out by means of contacts connected in the lead from the other terminal to the plus line of the battery. The coil B is enclosed in a soft iron jacket C and has a central core D.

The armatures, which also serve as contacts, comprise soft iron members E, mounted on plate springs F, which are fastened at their lower ends to insulator blocks G and are connected up to the lines which they are adapted to close and interrupt.

At their upper ends the armatures are provided with contacts H, cooperating with stationary contacts I, mounted in insulator blocks J on the top of the relays. When a relay is energized, the armatures of the said relay, if not locked, will be drawn away from their normal position, in which they rest against an insulated strip fastened to the central core D, and will close the contacts H. I. Certain details of this relay, disclosed but not claimed herein, form the subject matter of my copending application, Ser. No. 181,223, filed April 5, 1927.

The locking mechanism for the relay contacts comprises bell crank levers K pivoted on the top of the relays and provided at one end with noses L, cooperating with the upper ends of the plate springs F, so as to normally keep the armatures locked in the position illustrated on the drawing, in which the contact between H. I is interrupted. The bell crank levers K with their other arms are all

5 pivotally connected to locking bars M, so that a movement to the left, that is in the direction of the arrow (Fig. 3) of a locking bar M, will release all the contact armatures locked by means of the bell crank levers K connected to the said bar.

10 If one of the relays is cut in when the locking bar M is moved to the left, the contact armature of that relay which is controlled by the said locking bar will be moved towards its corresponding stationary contact, and when the locking bar is then returned to its original position (Fig. 4), the said contact will be locked by means of the nose L in its 15 closed position, so that it remains in that position even after the relay is de-energized.

15 The calculating machine here specified being adapted to work with numbers up to five figures, each multiple contact relay is provided with five locking contacts (H, I), corresponding respectively to units, tens, hundreds, thousands, and tenths thousands denominational digits. There is one locking bar M for each series of locking contacts corresponding to the same denominational value. Thus, in the present machine there are five locking bars M, each connected to cooperate with one locking contact in each of the multiple contact relays.

20 30 The device for actuating the locking bars M comprises a magnetically operated ratchet mechanism which is also illustrated on Figs. 1 and 2. The ratchet mechanism is actuated by means of two magnetic relays N and O

25 35 which may be of any convenient type, but which are preferably constructed on the same lines as the multiple contact relays such as Ab, Ad, etc., each having, however, only one pivoted armature respectively designated P and Q. The armature P of relay N is connected by means of bell crank lever R to a sliding ratchet bar S, cooperating with a pawl T, pivotally mounted on a sleeve U which is slidably, but not rotatably mounted 40 on a rocking shaft V. A coil spring W tends to press sleeve U towards the position illustrated in Fig. 1. The sleeve U carries an arm X, the free end of which is provided with a downwardly extending knob Y, adapted to cooperate with upwardly extending cam surfaces Z on the ends of each locking bar M. The arms X also carry a contact spring AA, cooperating with stationary contacts BB mounted on an insulated plate CC.

45 55 The relay O has its armature Q pivotally connected at the top by means of rod DD to an arm EE on rocking shaft V.

When the magnetic relay N is energized, the armature P of that relay is moved in the direction indicated by the arrow on Figs. 1 and 2, and this movement by means of bell crank lever R causes the ratchet bar S to perform a movement in the direction indicated by the arrow on Fig. 1, taking the sliding sleeve U with it in the same direc-

tion by means of pawl T. During this movement the knob Y will act on the cam surface Z so as to push the locking bar M towards the left, that is in the direction indicated by the arrow (see Fig. 3) against the action of compression springs FF (see Fig. 1). In case one of the multiple contact relays such as Ab, etc. is under current during this movement to the right of the locking bar, the corresponding contacts H, I will be closed, and as the locking bar M will slip back into its original position as soon as the knob Y has passed the cam surface Z, the said contacts H, I will be locked in closed position (see Fig. 4). At the same time the locking bar M, slipping back into its original position will lock the arm X so that it cannot return to its original position, even when ratchet bar S is moved back again. When relay N is de-energized, its armature P will be pulled back to its original position by means of spring GG acting on bell crank lever R so as to move ratchet bar S back to the position illustrated on the drawing. During this movement the pivoted pawl T will slip over the second tooth on the ratchet bar and will come to rest against the active surface of the same.

When relay N is again energized, the same series of operations will be repeated, the knob Y now acting on the cam surface Z on the second locking bar M, and so on until all locking bars have been acted upon in succession.

50 55 The magnetic relay O serves to return sleeve U to its original position, and this operation takes place in the following manner.

60 When the relay O is energized, its armature Q will be pulled towards the right as indicated by the arrow (Fig. 2, dotted position) and will thereby turn the rocking shaft V, so that the lever EE, the arm X, and the pawl T take up the position indicated in dotted lines on Fig. 2. In this position the knob Y goes clear of the cams Z and the pawl T goes clear of the ratchet bar S, so that the coil spring W is free to push sleeve U back to its original position, the contact spring AA being at the same time lifted off the stationary contacts BB. As soon as the magnetic relay O is again deenergized, a spring HH will pull the rocking shaft V back to the position shown in full lines.

65 70 In the following description it will be necessary to refer on numerous occasions to certain electrical impulses which are representative of certain digit values. In order to simplify an understanding of the invention as much as possible, we will assume that the current impulses, representative of certain digit values, are physical elements which are placed in certain units of the apparatus in accordance with the principles of operation thereof. In other words, instead of referring

to an electrical impulse activating a relay to cause a proper contact to be made therein which represents a certain digit value, reference will merely be made to the digit being placed in the relay; likewise, with respect to the calculating relays if an impulse representing a digit, say 2, passes into an addition calculating relay representing the digit 4, thus causing an impulse to pass out of the relay representing the digit 6, this will be referred to as entering the digit 2 into an addition relay 4 and thereby causing digit 6 to come out of the relay. With this assumed illustrative method in mind, it is believed that an understanding of the invention will be greatly facilitated.

The registering device above described may be utilized for the purpose of storing numbers, each digit being independently stored in a multiple contact relay by locking one of the armatures in said relay when the contact carried by said armature touches its corresponding contact. In the present embodiment respective relays represent digit values in the numerical system 1 to 0 and the individual multiple contacts in each relay are equal in number to the denominational capacity of the particular registering device.

The manner in which this spring operation may be performed will be understood by reference to the diagrammatic plan on Fig. 1 on which the registering device is illustrated as adapted to cooperate with a contact relay Aa' and a number of keys OI' , NJ , $Kb1'$, $Kb2'$, $Kb3'$; the key OI' serving to energize Aa' , the key NJ serving to energize relay O and the keys $Kb1'$, $Kb2'$ and $Kb3'$ serving to energize respectively the relays Ab , Ad and Ae .

The contact relay Aa' which is also illustrated in vertical section on Fig. 2 is identical with regard to construction with the multiple contact relays Ab , Ad and Ae shown on Fig. 2, but does not cooperate with the locking mechanism.

The contact board or key board which is also shown in section on Fig. 2 comprises an insulated bar OO' , to which the several keys are fastened, and a contact bar NN' which is directly connected to the plus lead of the source of current employed.

The energization of relay Aa' (Fig. 1) takes place by depressing key OI' , whereby current passes from the plus lead through contact bar NN' , line a' through the coil of relay Aa' to the minus lead of the battery (Fig. 1).

In the following description of current circuits it should be borne in mind that one terminal of each of the coils of all relays is connected to the minus lead of the battery or other source of current, and the energization of the relay will therefore always take place when the other terminal of said relay is con-

nected to the plus side of the battery, the source of current.

The energization of relay Aa' has the effect of closing the contact armatures of said relay with the stationary contacts thereof so as to connect leads $f1$, $b1$, $d1$, $e1$ respectively with the leads $f2$, $b2$, $d2$, $e2$.

If key $Kb3'$ is now depressed, the plus lead through contact bar NN' is connected with lead $e1$ and further through contact relay Aa' with lead $e2$ energizing multiple contact relay Ae , representing digit 3. It should be noted that the depression of key OI' must be maintained. The energization of relay Ae in the first instance has no effect on the locking armatures thereof owing to the fact that they are all locked in the position illustrated on Fig. 2 by means of the locking device.

The multiple contact relay Ae , however, (as well as the other relays Ab and Ad) comprises a free contact armature $He2'$ and a corresponding stationary contact $Ie2'$ connected respectively with the coil of relay N through lead $c3$, $c4$, and through lead $c2$ with the plus lead through contact bar NN' and the other relays Ab and Ad are similarly provided with corresponding contacts and circuit connections. It is of course obvious that since these pairs of stationary and armature contacts are in series (the said pairs of contacts being in parallel) in their respective circuits, it is immaterial whether the one or the other contact of a pair is connected to a given line.

The energization of relay Ae as explained, will consequently have the immediate effect of energizing relay N . The effect of energization of relay N has been explained above, and the movement of the ratchet device caused by said energization will cause a movement of the first locking bar $M1$ so as to release, as indicated on Fig. 3, the locking contact armatures controlled by said locking bar. As relay Ae is energized the released locking contact armature in that relay will be attracted towards the corresponding stationary contact I in that relay as indicated on Fig. 4, and will be immediately locked in closed position upon the return movement of the locking bar.

It will be understood that as the other multiple contact relays Ab and Ad have not been energized during the movement of locking bar $M1$ above referred to, the locking contact armatures controlled by said locking bar in these relays will remain in open position in case that is the position they have, but if before the movement of the locking bar they are locked in closed position, as indicated on Fig. 4, they will be released and snap back into their open position as indicated on Fig. 2 owing to the action of their springs F . Also it will be understood that if the locking contact armature controlled by the said locking bar in relay Ae is in closed position at the moment of actuating the locking bar, it will

remain in that position owing to the relay A_e being energized during the releasing period.

Key $Kb3'$ must be maintained depressed for a sufficient period (extremely short) to permit the ratchet device to perform one step and pass the first locking bar $M1$, as has been described above, and when the key $Kb3'$ is released after this stepping movement has been performed, relay N is again de-energized and the return of the ratchet bar S sleeve U is resting with its pawl T against the second tooth of the ratchet bar S .

It will be noted that the current impulse caused by the depression of key $Kb3'$ has now caused digit 3 to be registered in multiple contact relay A_e , by locking the locking contact armature under the first locking bar $M1$ of the registering device, designating a certain desired denominational value.

The depression of one of keys $Kb2'$ or $Kb1'$ instead of key $Kb3'$, as will be easily understood, would have had the same effect in one of multiple contact relays A_d , A_b respectively. Provided key OI' is maintained depressed so as to maintain the energization of relay Aa' , digits, either of the same or different digit values, may be stored in the registering device under the subsequent locking bars, representing different denominational values, in the same manner as has been described above, the ratchet device moving for each impulse one step away from its original position, each time actuating a locking bar.

When the desired number of impulses has been registered in this manner by locking armature contacts in the several multiple contact relays, the ratchet device may be returned to its original position by depressing key NJ , whereby the plus lead is connected through contact bar NN' , leads $f1$, $f2$ with the coil terminal of relay O , so as to release the ratchet mechanism and return the same to its original position in the manner which has been described above.

On Fig. 5 there is diagrammatically illustrated a register unit in accordance with the principle described in connection with Fig. 1 and adapted for use in a calculating machine in accordance with my invention, and the register unit is shown in connection with certain switching relays whose functions are to be described following. The register unit as illustrated on Fig. 5 comprises a set of ten multiple contact relays, and digits may be stored in said relays by means of a key board arrangement as illustrated on Fig. 6, and which is adapted to be connected with the register by means of electric cables, in a manner similar to that heretofore described in connection with Fig. 1.

Each of the multiple contact relays is provided as on Fig. 1 with five locking armatures being the five left hand armatures shown. As has been mentioned before, the locking mechanism of these armatures has

been omitted on Fig. 5 in order to not unnecessarily complicate the drawings. In order to register in the multiple contact relays on Fig. 5 impulses caused by the depression of keys $Kb1$, $Kb2$, $Kb3$, etc. of Fig. 6, switch OI is first closed as indicated by the arrow; corresponding to and performing the same function as key OI' on Fig. 1, that is, to energize coupling relay Aa by connecting one coil terminal of the same through lead a with the key bar NN , which is connected in the usual manner with the plus lead.

The keys $Kb1$ — $Kb9$ and $Kb0$ are adapted to connect plus respectively to lines 1 to 9 and 0 which are connected respectively to lines $j43$ to $j52$.

On Fig. 6 lead a is indicated as passing through a connecting box SS . In some cases it may be desirable to insert an automatically operating interrupter in line a so as to be able to de-energize relay Aa temporarily without changing the position of switch OI . Such automatic interrupter, as will be explained later, may then be connected in series in line a by means of connecting box SS .

After energization of coupling relay Aa , the registering of digits caused by depressing one of keys $Kb1$, $Kb2$, etc. takes place in the manner described in connection with Fig. 1.

The circuit $c2$, $c3$, $c4$, serving to energize relay N , as described in connection with Fig. 1, operates in the same manner as already described, but as it will be seen on Fig. 5, line $c3$ is indicated as connected to line $c4$ in connecting box PP for the purpose of enabling an automatic interrupter to be inserted between lines $c3$, $c4$, such automatic interruption being necessary in some cases which will be explained later.

Automatic transmission of digits registered in one register to another register

The digits registered in the multiple contact relays of one register unit may be automatically transmitted to a second register unit of the type illustrated on Fig. 5, and as this transmitting operation is one that forms an important step in calculating operations which may be performed on the calculating machine in accordance with my invention, the principles of said transmitting process shall now be described with reference to Figs. 5 and 7.

On Fig. 7 the blank squares indicated as I and II represent register units and associated relays in accordance with Fig. 5, and the blank square indicated as III represents a key board in accordance with Fig. 6. As will be understood these and similar blank squares represent features which are shown in detail in other figures; and in order to facilitate a reference to such figures, these

respective squares, in addition to bearing characters I, II, etc., bear the number of the figure showing them in detail.

- In accordance with the general principle 10 of transmitting, the ratchet mechanism of register II, to which digits are to be transmitted from register I in the multiple contact relays of which the digits have been stored by means of the locking armature contacts thereof, is made to perform automatically a stepwise movement identical with the movement which has been performed by the ratchet mechanism of register I, and during this stepwise movement the 15 contact spring AA connected with said ratchet mechanism closes circuits through the contacts of the same corresponding to BB of Fig. 1, said circuits passing successively through the locked armature contacts 20 in register I and to the coils of the multiple contact relays in register II, energizing said multiple contact relays which in turn cause energization of the ratchet operating magnet N, provision being made to maintain the 25 relay energized during the period in which a locking bar thereof is actuated by its ratchet mechanism and the bar is returned, so as to lock armature contacts in register II corresponding to the armature contacts locked 30 in register I, from which the registered impulses are transmitted; all of which will be more particularly explained hereinafter.
- In the following circuits and movements of parts on the registers I and II, which are 35 preferably identical in every respect, reference may be made in each instance to Fig. 5 which discloses the details in both registers I and II as indicated on Fig. 7. For example, corresponding lines and parts of 40 registers I and II being identical, where reference is made to a line or part in register I this detail will be found on Fig. 5, and likewise where a reference is made to a line or part of register II this detail may also be 45 found on Fig. 5. While registers I and II, Fig. 7, and registers X, XI and XII, Fig. 10a, etc. are preferably identical in construction, as will appear later, in certain combinations such as shown in Fig. 7, certain of the 50 features and lines shown in Fig. 5 may be omitted or remain disconnected from other circuits when this register is used as a primary or secondary register.

This automatic stepwise movement is 55 started in register II by depressing a transmitting key connected to that register (see also Fig. 10a) which is indicated on Fig. 7 as RR. This has the effect of connecting plus bar TT, with which key RR cooperates, 60 to line h so as to energize relay Bh associated with register II. Relay Bh should now be maintained in an energized state during the whole process of transmitting and should be 65 automatically cut out as soon as the said process has been performed. In order to

simplify the operation of the machine, the maintaining of relay Bh in an energized state and the de-energizing of the same after termination of the transmitting process, is performed automatically by means of a second 70 energizing circuit for the said relay, which is closed by means of a contact armature actuated by the relay itself.

The circuit by means of which a relay maintains itself in an energized state will be 75 termed hereafter "the self closing circuit" of the said relay.

The self closing circuit of relay Bh can be followed by reference to Figs. 5, 7 and 10a. On Fig. 7 (as well as on Fig. 10a) it will be 80 seen that the closing of the armatures in relay Bh with the stationary contacts thereof has the effect of making connection between the plus lead and line g1, which leads to register II. On Figs. 5 and 10a where this 85 is illustrated in detail, it will be seen that line g1 is connected with a contact spring UU, which cooperates for the present purpose with another contact spring VV located adjacent contact spring UU. Contact spring 90 UU tends to make contact with contact spring VV, but is prevented from doing so by means of a knob WW on sleeve U of the ratchet mechanism.

As it will appear from the following description, the energization of ratchet relay N and consequently the movement of sleeve U takes place shortly after the transmitting key RR is depressed, and this movement will have the effect of immediately causing contact to be made between contact springs UU and VV. This contact will be maintained 100 so long as sleeve U of the ratchet mechanism is out of its normal position. Line g2 is connected with line h by means of contact 105 springs UU and VV, and leads back to one of the contacts in relay Bh (Figs. 7 and 10a), the corresponding contact of which is connected with the coil terminal of said relay at the same point as line h above referred to, and in this manner this coil terminal is maintained connected to the + lead irrespective 110 of transmitting key RR and so long as sleeve U is out of its normal position (illustrated in Figs. 5 and 10a). The key RR must be 115 held depressed until plus has been applied to the holding line g2 across contacts in relay Bh and the contacts UU, VV.

The use of relays with self closing circuits constitutes an important feature in the present embodiment of my invention, and a number of the relays utilized are provided with self closing circuits of the kind referred to. Generally the self closing circuit of a relay is controlled either by means of a second relay or by means of a contact controlled by the ratchet mechanism of a register, so as to automatically control the duration of the energization period of a relay after the same 125 has been initially energized.

In the following description the representative circuit will be traced illustrating the manner in which digits are transmitted from one register (such as I) to another register (such as II). It is to be understood in this connection that the present invention provides means for transmitting from one register to the other in direct order without performing any calculations, or in transmitting in the reverse order without performing any calculation, or in performing one of various forms of calculations. In order to simplify an understanding of the general principles of such transmission in general there is illustrated on Fig. 7 a switching relay C_i , which is placed in circuit between the registers I and II as representative of any desired relay necessary in connection with the steps desired to be performed, i. e. this relay is representative of any one of the desired forms of relays necessary to perform the functions desired as will be more fully understood from the following description of the invention. Accordingly, the relay C_i is connected in circuit through suitable connection boxes such as GA, FA, OA and ZZ, and this relay is surrounded by dash lines to indicate that it forms no part of the specific embodiment of this invention other than as an aid to a preliminary understanding of the general circuits employed. Immediately following, there will be traced a representative circuit in which the digit is transferred from register I to register II over one digit line of one set of digit lines to one digit line of the other set of digit lines; it being again pointed out that since the relay C_i is a simple switching relay, the digit transferred from register I over one digit line of one set will be entered into register II over the corresponding digit line of the other set of digit lines.

To facilitate following the circuits, it should be noted that lines are grouped (usually in cables), and that in general these groups contain series of 5 and 10 lines each. The 5 line groups represent denominational digit values (since the machine of the present embodiment has a capacity of 5 denominations); and the 10 line groups represent digit values of the decimal system. Bearing this in mind, it will facilitate following a given circuit and understanding the effect which the impulse in this circuit will have.

In following the circuits to be traced following, in connection with Fig. 7, it is believed that Fig. 10 will be helpful; since the latter figure shows only the main circuit paths with the directional current flow indicated.

As will be seen on Fig. 7 and 10a, the energization of relay B_h has the effect of connecting the + lead to line j_1 , which leads to contact spring AA on the sleeve U of the ratchet mechanism of register II.

Contact spring AA of register II in its home position and before the first step is

started, makes contact through one of contacts BB Fig. 1, of which register II has a contact for the spring AA in its home position (see Fig. 5), with j_2 , which passes through the cables indicated as j_2-j_6 back to relay B_h (see Figs. 7 and 10a), and from the corresponding closed contact in said relay through cable j_8-j_{12} , through connecting box XX, through cable $j_{13}-j_{17}$, which passes through connecting box YY and $j_{18}-j_{22}$ to key board III (Fig. 6). Since relay A_a of said key board is energized, the current passes through the contacts thereof and further through cable k_2-k_6 , as indicated on Figs. 7 and 10a to register I, which is the register from which the current digit impulses are to be transmitted.

As this register is identical with register II to which the impulses are to be transmitted, the diagram on Figs. 5 and 10a may also be used for explaining the connections which take place in register I, as has been previously explained. The circuit from j_2 in register II is now connected to line k_2 in register I through cable k_2-k_6 , i. e. to the line connected to all the locking armatures under the first or left hand locking bar (not shown), cooperating with the multiple contact relays of that register.

It has been presumed that a contact armature has been locked in closed position in one of the relays under the said locking bar for registering a digit, and through that locked armature the current will pass to the corresponding stationary contact in the multiple contact relay in question, and on to one of the lines in cable k_8-k_{17} , which comprises one line from each of the ten multiples contact relays. Cable k_8-k_{17} leads, as will be seen on Fig. 7 to relay B_h and the current continues through one of the closed contacts of said relay to one of the leads in cable $j_{23}-j_{32}$ (which is one of the two sets of digit lines), by way of the closed contacts of the unenergized relay RT through connecting box ZZ and to relay C_i (see Fig. 7). As will be explained following, this relay is automatically energized through relay B_h when that relay is energized, and in the energized state of relay C_i the connection continues through one of the closed contacts thereof on to one of the leads in cable $j_{33}-j_{42}$ (which in this case is the other of the two sets of digit lines) to register II (see Fig. 5), where the connection passes through one of the closed contacts of the unenergized switch relay D_c and continues through one of the leads in cable $j_{43}-j_{52}$ (which are a continuation of the leads in cable $j_{33}-j_{42}$).

The ten lines in cable $j_{43}-j_{52}$ respectively constitute the energizing leads for the ten multiple contact relays A1 to A9 and A0 in register II, and consequently the relay in register II corresponding to the relay in register I, (in which a contact is locked under

the first locking bar representing a digit stored therein) will be energized, and this as will be explained below, will take place prior to and the relay will be maintained energized, when the first locking bar in register II is reciprocated by the first stepwise movement of sleeve U in register II.

The energizing of relay Ci referred to above, takes place upon closing the contacts in the energized relay Bh (Fig. 7) by connecting one of the armatures connected to the plus lead with the stationary contact connected to line i1 through a closed contact in the unenergized relay El to line i2, which goes to register II, and as will be seen on Fig. 5 (also Fig. 10a) line i2 is connected in the unenergized relay Fc to line i3, which is the energizing lead for relay Ci. It will be noted that relay Ci is maintained energized so as to close the circuit to one of the multiple contact relays of register II so long as relay Bh is energized and when relays El and Fc are unenergized.

When relay Bh is energized, it will be seen that one of the armatures in that relay connected to the plus lead forms a connection to line c1, which leads to register II, and as seen on Fig. 5 (also Fig. 10a) passes through relay Fc. In register II, c1 is also connected to contact spring DA which makes contact with another contact spring EA connected to line c10. Line c10, as will be seen on Fig. 7 is connected in connection box FA with lead c11, which forms a self closing lead for relay Ci, maintaining the same energized irrespective of circuit i1, i2, i3 specified above. In relay Ci, c11 is also connected to lead c12, which passes through connecting box GA to register II, where it forms the energizing lead for relay Fc, as will be seen on Fig. 5.

The energizing of relay Fc which takes place substantially simultaneously with the energization of the multiple contact locking relay, connects c1 with line c7, which is connected to a stationary contact in each of the multiple contact relays in the register. One of these stationary contacts is indicated on Fig. 5 with Ic7. The armature (which is a non-locking armature) co-operating with said contact (Ic7) is connected to the coil terminal of its relay so as to form a self closing lead for the relay, and also to a second non-locking armature, to the left, cooperating with another stationary contact connected to respectively corresponding contacts in each of said relays.

The line interconnecting all of the last named stationary contacts is indicated as c8, which is connected to c9 which forms the energizing lead for relay Dc. The energizing of relay Dc, which takes place immediately after energization of the multiple contact locking relay as will be seen on Fig. 5, has the effect of interrupting the energizing circuit through one of leads j43—j52 for the

energized multiple contact relay in the register, and the said multiple contact relay is therefore now maintained energized by means of the self closing circuit just described through stationary contact corresponding to Ic7.

In relay Fc, line c1 is also connected to line c2, as well as to line c7, with the effect of energizing ratchet relay N in the manner which has been described before (i. e. c2, 75 contact of energized multiple contact relay, c3, PP, c4, N), whereby the movement of the sleeve U of the ratchet mechanism is started. The movement of ratchet bar S in the direction of the arrow carries knob KA 80 which establishes connection between contact spring IA and contact spring JA (Figs. 5 and 10a), the former of which is connected to line c7, whereas the latter is connected to line c1. The relay Dc and the operating magnet N are energized simultaneously immediately subsequent to the closing of contacts in the energized multiple contact relay which closes the energizing circuits for the relay Dc and magnet N.

The connection c1, c7 established between contact springs IA, JA, as will be seen, is a parallel connection to the connection c1, c7 established in relay Fc; the object of the connection established between the contact springs IA and JA being to maintain the energization of the multiple contact relay and the relay Dc during the complete reciprocating movement of ratchet bar S irrespective of the energization of relay Fc.

Ratchet bar S besides knob KA is provided with another knob LA, and this knob, when the ratchet bar arrives nearly at the end of its stroke towards the right (Fig. 5), engages contact spring EA, so as to interrupt the connection between leads c1, c10 with the immediate effect as above described of simultaneously de-energizing relay Ci (see Fig. 7), and relay Fc (lead c12). The de-energization of relay Fc interrupts the connection between c1, c2 so as to de-energize ratchet relay N when ratchet bar S has performed a movement of a predetermined length in the direction of the arrow. Energization of the locking contact relay and relay Dc is maintained by the circuit over line c1, contact springs LA, IA and line c7.

When the ratchet bar approaches its normal position, the contact between springs IA, JA is interrupted, whereby the multiple contact relay energized in the register II is de-energized, having now its contact armature under the first locking bar locked in closed position. Interruption between contact springs IA, JA also causes the relay Dc to de-energize simultaneously with the multiple contact relay. The second transmission circuit may now come in over lines j43—j52.

The de-energization of relay Fc has the effect of energizing relay Ci through connec-

tion between lines $j2$, $j3$ (see Fig. 5), so that at the moment when relay Dc is de-energized owing to the interruption taking place between contact springs IA and JA , the circuits which have been described above in connection with contact spring AA and line $j2$ will now be automatically repeated in connection with contact spring AA and line $j3$ with which the said contact spring is now in engagement through the next contact BB . The transmission of the digit registered in register I under the second locking bar is now performed automatically in the manner described in connection with the transmission of the first digit; and the subsequent digits are transmitted in exactly the same manner until all the digits in register I have been transmitted in the same order to register II; all of which will be readily understood by those skilled in the art.

Reversing the order of registered digits during transmission from one register to the other

As has been explained heretofore, in the present embodiment, the digits registered in the first register by means of the keys, represent the digits of a number, and in the present embodiment, in order not to complicate the operation of the machine each locking armature in a multiple contact relay corresponds to a certain denominational value. This may be obtained by entering all numbers from the right to the left, that is by always starting with the unit digit of a number, then entering the ten's digit and so on, in which case the first locking armature in the register relays will correspond to units, the second to tens, the third to hundreds and so on. For practical purposes it is, however, desirable when typing numbers, to type them in the order from left to right, and if this is done, it will be understood that the first locking armature in each of the register relays will correspond to hundreds if a number comprising three digits is entered and so on.

Now, in order that a number when transmitted from the first register to another register always be registered in the said second register with the unit digit under the first locking bar, the ten's digit under the second locking bar and so on, I insert in the transmitting circuit from the first to the second register, heretofore described, a reversing device IV (Fig. 7), such as through connecting box XX, which is adapted to switch the first transmission circuit from register II which is over line $j2$ through a locked armature under the last actuated locking bar in the first register (I) to a relay in the second register (II) to cause locking of an armature under the first bar which corresponds in value to the last locking armature locked in the first register. The circuits closed under the transmitting process will consequently result

in transmitting a number from register I to register II where the digits will be registered in the reverse order.

The setting of the switching device IV by means of which this is accomplished, and which I term "the reversing device" (Fig. 8) is controlled by means of the ratchet mechanism of the first register, i. e. the ratchet mechanism of the register into which the digits have been entered from the key board, and from which register they are to be transmitted in reversed order to the other register.

I do not limit myself to the use of any particular kind of multiple contact reversing switch, as it will be easily understood that a purely mechanical as well as a purely electrical switching device may be used for the purpose, but I prefer to use an electrically operated reversing device comprising a number of magnetically operated multiple contact switches, said number corresponding to the highest denominational value for which the calculating machine is constructed. Thus, as it will be understood, as the embodiment of my invention here described is adapted for numbers with a maximum denominational value of five figures, I employ a reversing device comprising five multiple contact relays or magnetically operated multiple contact switches. The reversing device according to the present embodiment of my invention (indicated on the diagram Fig. 7 as IV) is adapted to be connected in series between the five line cable $j8-j12$ and the five line cable $j13-j17$ in the connection box XX, previously mentioned.

A diagram of the reversing device IV is illustrated on Fig. 8. The reversing device comprises five reversing relays $TR1$, $TR2$, $TR3$, $TR4$, $TR5$, adapted to be energized respectively by means of impulses in the lines $j8'$, $j9'$, $j10'$, $j11'$, $j12'$.

The contact armatures in the relay $TR1$ — $TR5$ are connected to the lines $j8''$, $j9''$, $j10''$, $j11''$, $j12''$ and the stationary contacts thereof are connected to lines $j13''$, $j14''$, $j15''$, $j16''$, $j17''$; also $j8''-j12''$ are connected (box XX, $j8-j12$, relay Bh , see Fig. 7) with $j2-j6$ from register II; and $j13''-j17''$ are connected in box XX with lines $j13-j17$ (box YY), $j18-j22$ in the transmission circuit described above; and also $j8-j12'$ are connected through box XB and lines $j8-j12$, as seen on Fig. 6, with $j3-j7$ from register I in the transmission circuit already described.

Reversing device circuit connections

In relay Aa (Fig. 6), $j1$ is connected to + and $j1$ goes to contact spring AA (Fig. 5) Reg. I, Fig. 7, and from there current passes through one of contacts BB , corresponding to the locking bar last actuated in register I, cable $j3-j7$, relay Aa , cable $j8-j12$ (register I), box XB, $j8'-j12'$ (see Fig. 7), en-

ergizing the reversing relay (Fig. 8) corresponding to this particular contact BB.

Owing to the fact that lines from different identical registers are shown in connection with the reversing device on Fig. 8, it has been found advisable in order to avoid confusion to provide the enumerations of the lines on this figure with differnt markings, which, however, do not appear on the general diagram Fig. 5; i. e. lines to respectively similar lines in registers I and II (Fig. 7) will be designated respectively by the prime (') and the secondary (") designations.

Therefore the cable comprising lines $j8'$ — $j12'$ will be seen on Fig. 7 as entering the reversing device IV from the key board III connected to register I; and the corresponding lines of register II enter the reversing device IV over the lines $j8''$ — $j12''$ (through relay Bh connected to register II).

The reversing device operates in the following manner:

Supposing that a number comprising five digits has been entered into register I by means of the key board, the ratchet device of said register will have arrived in its extreme position towards the right. Bearing in mind that this register I is connected with the key board illustrated on Fig. 6 in which relay Aa is energized, it will be seen that + passes through that relay to line $j1$ through contact spring AA , and the corresponding contact BB to line $j7$, and then through cable $j3$ — $j7$ through relay Aa (Fig. 6) on to line $j12$ in cable $j8$ — $j12$, on to line $j12'$ in cable $j8'$ — $j12'$, and continues as seen on Fig. 8 in line $j12'$, energizing reversing relay $TR5$.

The first transmission impulse derived from register II after the depression of key RR as has been described before, passes to the connecting box XX (Fig. 7) and on to the reversing mechanism through line $j8''$ in cable $j8''$ — $j12''$ and continues on the line $j8''$ (Fig. 8), which when relay $TR5$ is energized, is connected as will be seen on Fig. 8 to $j17''$, and further through connecting box XX to line $j17$ in the transmission circuit, thence through connection box XX to line $j22$ and continued on line $j22$, $k6$, across a locked contact under bar $M5$ of register I, and one of the lines $k8$ to $k17$ etc., and one of the lines $j33$ — $j42$ across a contact of relay Dc to one of the lines $j43$ — $j52$ and over the coil of a multiple contact relay in register II, thus registering under the first locking bar in register II, the digit (of lowest denominational value) registered under the last locking bar actuated during the entering of the number in question in register I.

The next circuit, i. e. the circuit closed by contact spring AA of the second register making contact through the second contact BB with $j3$ will enter the reversing device on line $j9''$ and will be switched in reversing relay $TR5$ to line $j16''$, and so on.

If a number comprising less than five digits has been originally entered in the first register by means of the key board, the ratchet device of the said register will energize, by means of a circuit through its contact spring AA , one of the other reversing relays $TR1$, $TR2$, $TR3$, $TR4$ in the same manner as has been described above, each reversing relay having exactly the same relative effect with regard to the digits to be transmitted as the reversing relay $TR5$, the function of which has been described above.

On Fig. 5 it will be seen that when register II, i. e. the register to which the impulses from register I are transmitted in reversed order, has performed a number of steps corresponding to the number of impulses to be transmitted, the contact spring AA thereof will stop over a contact BB corresponding to a locking bar under which no impulse has been registered in the first register and the line from that contact BB is connected in the energized reversing relay with a line $j7$ (see Fig. 8) which corresponds to line $j7$ on Fig. 5 (and is designated on Fig. 7 as $j7''$ leaving register II) and is the energizing lead for relay Uj (see Fig. 7), passing a connecting box JM on its way to relay Uj . The function of relay Uj will be set forth later.

Clearing and releasing after transmission

The transmitting process including reversing which has been described above, is the usual transmitting process in accordance with the present embodiment of my invention. It will be understood that in all normal calculating operations performed on the present machine, the first number is entered in direct order by means of the key board into one register and is then automatically transmitted in reversed order to the second register.

After this transmitting process has been concluded as above described, it is necessary to provide means for clearing that part of the second register which may not have been actuated so that no digits remain registered therein from previous calculating operations. In case the number transmitted to the second register has a denominational value corresponding to the full capacity of the register no special clearing will be required, the register, as has been explained before, being automatically cleared under each locking bar during the reciprocation of that bar. Consequently the transmitting of a digit to a locking armature under a locking bar in the second register will have the effect of not only locking an armature under the said bar corresponding to the digit transmitted, but also of releasing any locking armature previously locked under the same bar.

If a number transmitted from the first to the second register does not, however, comprise a number of digits equal to the full ca-

pacity of the second register, there will still be in that register locking bars which have not been actuated during the process of transmission; and before returning the ratchet mechanism of the said register to its normal position, any impulses which may remain registered under such locking bars, must be cleared out of the register, and this is performed in accordance with what has been said above 10 by automatically registering under the said remaining locking bars digits of zero value. The registering of zeros in the register in accordance with what has been said above will have the effect of clearing the register 15 from any other digits which may remain under the corresponding bars. After the clearing process referred to above has been concluded, the releasing relay O is automatically energized by circuits later described, so 20 as to return the ratchet mechanism to its original position.

The automatic clearing takes place by means of relay U_j (see Fig. 7 and also Fig. 10a), which as mentioned in the last paragraph describing the reversing process is energized by means of line $j7$ after the transmission has been concluded. It will be seen 25 on Fig. 7 that U_j is provided with a self closing circuit through line $g2$, which has been described under relay B_h : Consequently U_j will remain energized until the ratchet mechanism of register II has been returned to its normal position, whereby the contact 30 between UU and VV is interrupted as previously described.

As will be seen on Fig. 7, the energization of relay U_j connects + to line $o1$, which passes through a contact in the unenergized relay U_k to line $a2$, and through a contact in the unenergized relay E_7 to line $o3$, which is connected to line $j32$, which is connected to a stationary contact in relay C_i , whose corresponding armature contact is connected to the zero line in the transmission circuit described (42), energizing multiple contact relay A_0 in register II. As the current circuit $o1-o3$ just described is still closed, the process of registering zero under the successive remaining locking bars in register II will continue so long as there are locked armature contacts other than zero under any but the next adjacent of the remaining locking bars in the said register, as will be described later. The relay C_i is still energized through line $i1-i3$ whenever relay F_c is deenergized.

In case zero is already registered under all but the next adjacent of the remaining locking bars in the register, no clearing is required except of the amount under the next adjacent bar, and in that case the automatic registering of zeros in the register after registration of a zero under said next adjacent bar is interrupted by closing the following circuit.

From + the current continues through relay E_p when deenergized as is the case dur-

ing transmission (see Fig. 7) to line $k1$ which is connected in register II (see Fig. 5) with contact spring XA on the ratchet mechanism. From the stationary contact with which said contact spring XA is in engagement the current will pass through one of lines $k2-k6$ to relay F_c , and when this relay becomes energized as described under transmission, the circuit continues in F_c to one of lines $k17b-k17e$ back to the first locked contact armature in the relay A_0 in the order towards the right, then to the next line of the set $k2-k6$ through relay F_c to the next line in the set $k17b-k17e$ and so on until the circuit passes line $k6$, and through relay F_c on to line $k38$ passing through relay E_1 , which is not energized, and to line $k39$ through energized relay U_j to line $k40$, which is the energizing lead for relay U_k . It will be seen from Fig. 5 that the circuit for energizing relay U_k has connected in it, in series (through F_c when energized), all the locking armatures in the zero relay A_0 except the one next to the last one actuated during the transmitting process, so that relay U_k can only be energized in case all but the next adjacent of the remaining locking armatures in the zero relay A_0 are locked in closed position, that is, when the register does not contain any registered digits except the digits which have been last transmitted to the register and zeros under all but the next adjacent bar.

The circuit from $k1$ over the locked contacts in relays A_0 can be effected only after the relay U_j has picked up which occurs as the spring contact AA is moved to the right as the last digit is transmitted. At this time F_c is deenergized by moving contact EA away from DA which breaks the holding circuit for F_c and C_i . The impulse from $k1$ over XA and $k38$ cannot be effective until the relay F_c is again energized which occurs at the same time that relay A_0 is energized. The result is that the relays N and U_k will be energized simultaneously so that the releasing magnet O will be energized after the ratchet mechanism has functioned and a contact has been locked in A_0 under the next adjacent bar as will also appear later.

The set of lines $k17b-k17e$ together with line $k17a$, when relay F_c is not energized, are all connected to line $k17$ in cable $k8-k17$, which has been described under transmission. This connection is made in order to connect the stationary contacts under the locking bars in relay A_0 to line $k17$ in cable $k8-k17$. It will be seen that the other lines $k8-k16$ of the group $k8-k17$ are connected respectively to the corresponding stationary contacts in the relays A_1-A_9 . The particular connection of these contacts in relay A_0 through F_c is made in order to permit those contacts being connected in series as described immediately preceding in connection with clearing and releasing after transmission.

- 5 The energization of relay U_k , as above referred to, has the effect of interrupting circuit o_1, o_2, o_3 , whereby the automatic registering of zeros in register II is stopped, since line o_3 forms a part of the transmitting circuit, representing the zero digit value; it being remembered that o_3 was connected through box ZZ and relay C_i to the zero digit line $j42$. Also in relay $U_k +$ is connected to lines w and v which are the energizing lines for the releasing relay O in register II and register I respectively, so as to release both ratchet mechanism and return the same to their normal position.
- 15 One function of the relay U_j in transmission operations is to connect plus to the zero transmission line $j32$ after transmission over each of the circuits prepared in the reversing relays TR1 to TR5 has been concluded.
- 20 Another function is to prepare an energizing circuit for the relay U_k by connecting line $k39$ to line $k40$ so that the relay U_k may be energized under control of a circuit made from $k1$ over the locked contacts in relay A_0 as described above. The relay U_k applies plus to lines w and v to return the ratchet mechanisms of both registers to home position. As the sleeve U of register II reaches its home position it disconnects the holding line $g2$ from plus which causes all of the energized relays to release.

ADDITION AND SUBTRACTION

General introduction

- 25 In accordance with the process of transmitting which has been described above, a digit which has been entered into a register of the machine by means of the key board or the like, may be transmitted to a second register. This in accordance with the transmitting process described is obtained by closing a circuit which passes through the locked armature contact in the first mentioned register, and which serves to energize the corresponding multiple contact relay in the second register which closes an energizing circuit for the operating magnet N and a holding circuit for itself so that it remains energized when the locking bar engaging the corresponding locking armature in that relay is reciprocated.

- 30 The current circuits closed for this purpose through the locked armatures in the first register pass through a multiple contact relay (C_i , Fig. 7), which is energized during the process of transmitting. Now it will be understood, as has been heretofore mentioned, that if the multiple contact relay C_i is replaced by a relay of the same type, in which the circuits from the locked armatures in the first register I are connected up to circuits in connection with the second register II, which serve to lock armatures in that register corresponding to digits which differ

from the registered digits in the first register by a predetermined number, we will have an addition machine or a subtraction machine by means of which a certain predetermined number is automatically added to or subtracted from the number entered by means of the key board in the first register. 70

Now, in order to make use of this feature of my invention for the purpose of addition and subtraction in the present embodiment, I substitute for the multiple contact relay C_i in the transmitting circuit a set of ten multiple contact relays, all of which are connected in parallel in each of the ten transmitting circuits (i. e. such as $j23-j32$ and $j33-j42$) between the first and the second register. This is accomplished in Fig. 7 by disconnecting relay C_i , as heretofore explained, and connecting calculating relays V in box ZZ with the ten transmitting circuits. 80

In each of the said multiple contact relays, each transmitting circuit from the first register is connected up to the same or different actuating circuit for the locking armatures of the second register in accordance with the addition table. Thus, in the multiple contact relay corresponding to the digit value one all transmitting circuits from the first register will be connected up to circuits serving to actuate locking armatures in the second register representing a numerical value one unit higher than the first mentioned; in the multiple contact relay corresponding to the digit value two the difference between the numerical values will be two and so on. 90

100 As it will be understood, the connection established in the transmitting circuit will depend on the multiple contact calculating relay which is energized so as to have its contacts closed at the moment of transmitting an impulse corresponding to a certain digit.

105 The energization of the multiple contact relays above referred to is controlled by means of circuits passing through the contact armatures which are locked in closed position in the second register. Thus, if an impulse is transmitted from the first to the second register, and a locking armature corresponding to the numerical value 3 is locked in the second register under the corresponding locking bar thereof, a circuit will be closed through the said locked armature in the second register so as to energize a multiple contact calculating relay corresponding to the digit value three, in which all transmitting circuits from the first register are connected up to circuits actuating locking armatures in the second register with a numerical value three units higher than the numerical value represented by the transmitted circuits from the first register. 110

115 As there is no principal difference from a mathematical point of view between addition and subtraction, it will easily be understood, that the same principle which has been 120

described above for addition may also be used for subtraction. In accordance with the present embodiment of my invention, subtraction is performed by means of the same set of multiple contact calculating relays connected in accordance with the addition table, which has been described above; by connecting in the transmitting circuits from the first register to the set of calculating relays a multiple contact switch, by means of which each transmitting circuit may be switched on to a transmitting circuit representing the complementary numerical value of the first mentioned circuit, whereupon the said complementary numerical value is added in the ordinary manner to the numerical value of the corresponding digit registered in the second register.

DIGITS TRANSFER

20 General introduction

In cases where the sum of two digits is a number higher than 9, the ten's digit of the sum must be added to the sum of the next two digits, that is to the sum of the digits, which have the next higher denominational value. In order to achieve this transfer, I use in accordance with the present embodiment of my invention two relay operated multiple contact switches which are connected in parallel to each other and in series with the subtraction multiple contact switch in the transmitting circuit from the first register to the set of multiple contact calculating relays.

35 The energizing circuits of the said two relay operated multiple contact switches are each controlled respectively by the other multiple contact switch in such a manner that the closing of one of these switches will 40 always have the effect of opening the other. The relays controlling said multiple contact switches are energized by means of circuits closed at one point by means of contacts in the set of multiple contact calculating relays.

45 The contacts for closing the said energizing circuits are each connected in parallel with one of the contacts for closing the transmitting or calculating circuits in the calculating 50 relays. Now it will be understood that in each calculating relay the latter contacts may be divided in two groups.

The contacts of the first group are those adapted to close circuits from the first register representing a numerical value, which 55 added to the numerical value of the calculating relay in question gives a sum higher than 9. All of these contacts have parallel contacts adapted to close a circuit energizing 60 one of said relay operated multiple contact switches.

The contacts of the other group are the 65 remaining calculating contacts in the relay in question. These contacts are adapted to close circuits from the first register representing a numerical value which added to the

numerical value of the relay gives a sum not higher than 9. All these contacts of the second group have parallel contacts adapted to close a circuit energizing the other of said relay operated multiple contact switches.

70 In each case it will be understood from the above, that the multiple contact switch closed will remain closed until the other multiple contact switch is closed by energizing the relay thereof, whereby the relay of the first 75 mentioned switch is de-energized.

In the first mentioned multiple contact switch each transmitting circuit from the first register to the set of multiple contact calculating relays is switched on to a circuit 80 representing a numerical value one unit higher than the original circuit with the effect of automatically adding one unit to the sum of the next two digits in cases where the sum of the previous two digits is higher 85 than 9.

In the following specification the two multiple contact switches, which are utilized for transfer purposes, will be termed "transfer-switch" and "no-transfer-switch."

90 As according to the present embodiment of my invention I perform subtraction by addition of the complementary value of the subtractor, it will be understood that transfer must take place under subtraction in all cases where no transfer takes place under addition, and consequently I control the energizing circuits of the transfer and no-transfer-switch in such a manner, from the multiple contact subtracting switch above referred to, that the transfer and no-transfer-switch are substituted for each other in their respective circuits when the machine is set for subtraction.

105

Details of addition and subtraction

The set of calculating relays for addition and subtraction as well as the subtraction multiple contact switch and the transfer and no-transfer-switch are illustrated diagrammatically on Figs. 9 and 9a, and all elements included therein are indicated on Fig. 7 with the blank square V.

110 It will be understood that the functions of multiple contact relay C_i which has been described under the transmitting process, are now taken over by the addition and subtraction devices V, and relay C_i is no longer connected in the connecting boxes FA, GA, OA, ZZ with the other circuits indicated on Fig. 7. Line $j3$ is connected with line $k37$ as energizing lead for the zero relay $Bk0$ of the set of calculating relays (see Fig. 9) instead of C_i .

115 It will be seen on Fig. 9a that the cable $j23-j32$ comprising the ten transmission lines from register I (—Fig. 7— as $k8-k17$, which pass through relay Bh on to $j23-j32$ and thence through relay RT, box ZZ and 120 to V) pass through the contacts of transfer

125

130

switch DT and no-transfer-switch CT as well as through the subtraction switches Cn, Dn to the set of calculating relays Bk0, Bk1 etc., in each of which they are connected in accordance with the addition table with the several lines in cable j33—j42, leading to register II as described under transmitting. It will be understood that in the present embodiment j23—j32 represent one set and j33—j42 the second set of ten digit lines such as are referred to in my previous U. S. application Ser. No. 688,564.

The energizing current for calculating relays Bk0, Bk1 etc. comes from contact spring XA (see Fig. 5) in register II, said spring being connected with + through line k1 and relay Ep (not energized), as described under transmitting (see Fig. 7). From contact spring XA connection is made to one of lines k2—k6, which are each connected to the locking armatures under the five locking bars in the register. Through the locking armature locked in a multiple contact locking relay under the locking bar in question, the connection is further closed on to one of lines in cable k8—k17 (see Fig. 5) and then through relay Fc (not energized), to one of lines k18—k27, and then (see Fig. 7) through relay El (when energized) to one of the lines 30 in cable k28—k37 (see Figs. 7 and 9), so as to energize a calculating relay of the set Bk0, Bk1 etc.

Relay El is energized as will be seen on Fig. 7 by means of line l which is closed by depressing addition key RP. The energizing of relay El also serves to energize relay Bh by connecting lines h and l through a contact in relay El, and relay Bh, when energized, is maintained in an energized state 40 as described under transmitting, by means of its self closing circuit, so as to also maintain relay El energized irrespective of addition key RP.

The energization of each of the calculating 45 relays Bk0, Bk1 etc. through one of leads k28—k37 takes place in exactly the manner as the previously described energization of relay Ci, one of lines k28—k37 replacing the circuit i1, i2, i3 described in connection with 50 Ci.

The circuits for energizing the relays for the no-transfer and transfer switches are indicated on Fig. 9a as gj and jj. In subtraction relay Dn (Fig. 9a) j97 is connected to energizing line jj (through relay Dn) for the transfer switch DT when relays Dn and Cn are not energized, which is the case under addition. In the same manner j87 is connected to line gj (through relay Dn) which 55 is the energizing line for the no-transfer relay. The lines j97 and j87 as seen in Fig. 5 are connected over contacts of energized multiple contact relays in Reg. II to the lines in cables j78 to j86 and j88 to j96, Fig. 9.

When relays Dn, Cn are energized through

line n controlled by key RO (subtraction key). j97 in relay Cn is connected to line gj and j87 to line jj, whereby the two transfer relays are substituted for each other as above described. The self closing circuit for relay DT is established by means of the contact connecting line jj with line m1, which passes through a contact in relay CT to + when the latter relay is not energized. Energization of relay CT will immediately interrupt the connection in that relay between m1 and + and thereby de-energize relay DT.

In the same manner the self closing circuit gj, m2 for relay CT passes through a contact in relay DT connecting m2 to + when DT is not energized, so that energization of DT will automatically interrupt the energization of CT.

As it will be seen from Fig. 9a, the connection of lines j23—j32 in the transfer and no-transfer relays is made in the manner described above, so that when the transfer relay is energized, each of lines j23—j32 is connected in that relay with another line representing a numerical value one unit higher. Also as will be seen, (Fig. 9a), in the subtraction relay Cn the connections are so made as to connect each of the lines j23—j32 with a line representing the complementary value.

As will appear from the description above, the addition of one number to another in the present machine comprises the following steps:

(1) Entering the first number by means of the key board into the first register.

(2) Transmitting the first number from the first register through the reversing device to the second register, this function being performed automatically by depression of transmitting key RR.

(3) Entering the second number by means of the key board into the first register.

(4) Transmitting said second number through the reversing device and through the calculating relays to the second register, whereby the sum of the two numbers is automatically registered therein. This fourth step takes place automatically in the manner described by depressing key RP.

The first three steps are identical in subtraction. In the fourth step instead of depressing addition key RP, subtraction key RO is depressed, whereby the subtraction relays are energized, and the addition of the complementary numbers takes place in the manner described. This results in registering the difference between the first and the second number in the second register.

As it is necessary to prevent movement of the ratchet mechanism and interruption of the transmitting circuit at j1 and j2, j3 etc. of register II until the transfer relays have concluded their switching (if any), the energizing circuit c3, c4 for the ratchet relay N (Fig. 5) is connected in box PP to pass

through both transfer relays in parallel so that it is closed when either one of said relays is energized, but interrupted during the short period in which the armatures perform their movement (see Fig. 9a).

The circuits for the transfer and no-transfer for relays DT and CT prepared in the calculating relay Bk0 to Bk9 are completed by a contact in the energized multiple contact relay of Reg. II at the time the circuit for the ratchet operating magnet N and relay Dc is completed. If the circuit to DT or CT closed in the multiple contact relay is extended to the unenergized one of these relays, the relay picks up and disconnects lines c3 and c4 to prevent energization of the relay N. If the circuit extends to an energized relay DT or CT, then N will be picked up immediately after the multiple contact relay has picked up. The transfer and no-transfer lines do not pass through the relay Dc so that the full value of the transmitting current is switched to DT or CT after Dc is energized by a separate circuit.

25 *Releasing ratchet mechanism of both registers after addition and subtraction*

After a simple transmitting process, releasing as described above takes place after the number in question has been transmitted, provided there does not remain in the register registered numbers other than zero from previous processes except under the bar next adjacent to the bar operated when the last digit was transmitted.

An addition process is different from a simple transmitting process, in so far as the addition of the last digit from the first to the second register may cause transfer; and in case the digit of next higher denominational value in the second register is a 9, this transfer may be carried even past the last digit, i. e. the digit of highest denominational value, registered in the second register.

45 If for instance, 9 has been entered in the second register and 1 in the first register, the result of the addition will be 10, and consequently the transmitting of one digit from the first register to the second register in that case will necessitate two steps of the ratchet mechanism in the second register.

When the ratchet mechanism of the second register in an addition process has performed a number of steps, as described under transmitting, corresponding to the number of digits entered into the first register, the contact spring AA of the ratchet mechanism in the second register will make connection with one of lines j2-j7, as described under transmitting, so as to energize Uj by means of line j7 (Fig. 7).

The circuit from + to o1 and through relay Uk (not energized) to o2 is now switched on to line o4, as relay El is energized under addition as previously explained, and o4

leads to the transfer and non-transfer relays DT and CT (see Fig. 9a) and o4 is also connected in relay El back to o1.

In case the no-transfer relay CT is energized, that means that no further addition needs take place and in that case, as will be seen on Fig. 9a, o4 is connected to o5, which (see Fig. 7) is connected in Uj to k40, energizing relay Uk so as to close the releasing circuits for both ratchet mechanisms through lines w and v above described under transmitting. After the digits in register I have been added to those in register II and Uj is energized, the circuit on o5 causes the relay Uk to pick up which immediately closes the circuits through w and v for the releasing magnets O. As Uj picks up when the contact member AA moves to the right as the sum of the last digit in register I and a digit in register II is locked in register II and as line o2 is disconnected from line j32 in relay El no further transmission of sums is made to register II. In this case the ratchet mechanism of register II is returned immediately after the last addition has been made and the digits under higher order locking bars in register II will remain locked as a part of the new sum.

If on the other hand the transfer relay DT is energized, o4 is connected in that relay as will be seen on Fig. 9a, to j23 (the one digit line) with the effect as has been described under addition, of adding 1 to the number of next higher denominational value registered in register II. If, after this addition of 1 has been performed and the ratchet mechanism in register II has made one further step, the transfer relay DT is still energized, (which will be the case if the number to which 1 was added as above described were 9), the same process will be repeated until the transfer relay is de-energized and the no-transfer relay CT is energized, when releasing will take place as described above. The circuit to the no-transfer relay CT, in case no further transfers are necessary, is made at the same time that it is made to the operating magnet N which latter circuit is interrupted in relay CT and as the relay Uk and operating magnet are energized simultaneously and before the releasing magnets O are energized, the last sum is locked under a locking bar in register II after which the ratchet mechanisms are returned. The line j23 is disconnected from the line o4 in relay CT just before the latter is connected to the line o5 so that transmission circuits to register II are stopped.

Recording

As it will be easily understood, the numbers entered into the machine by means of the circuits closed by the keys of the key board may be automatically recorded by connecting in the several circuits relays serving

to actuate typing bars for the digits of the numerical system. If these relay operated typing bars cooperate with the carriage of a conventional typewriter, the numbers entered 5 into the machine by means of the key board will at the same time be recorded by means of the typewriter in the order from left to right.

For purposes of tabulation it is, however, 10 in most cases where addition and subtraction are to be performed, preferable to use suitable recording apparatus such for example as a typewriter of the kind in which the carriage may be caused to move both ways so as 15 to be able to type the numbers from right to left, that is, starting with the number of lowest denominational value. In that case it will be understood from the foregoing description, that the relays operating the type 20 bars of the recording device will have to be connected in the transmitting circuit described above, after the circuit has passed the reversing device and the locking armature contacts in the first register, and before 25 arriving at the calculating relays of the addition device (see Fig. 7).

On Fig. 7 one typing bar TB with actuating relay MT, and a suitable platen such as *tb*, of a suitable recording device is indicated 30 diagrammatically, the other elements being omitted for the sake of clearness. Devices in which the typing may be done from left to right and right to left are well known in the art, since it has heretofore been known as 35 shown in U. S. Letters Patents to S. A. Harrison, 977,448, Dec. 6, 1910, and R. A. Spurgin, 1,055,679, Mar. 11, 1913, to provide typewriters in which the platen was adapted for printing in either direction. In order to 40 facilitate an understanding of this, and more particularly for purposes of ready reference, suitable mechanism embodying this principle is more or less diagrammatically shown in Fig. 15. Referring to this figure, it will be 45 seen that the platen *tb* is mounted on a suitable frame designated as *tb'* which is connected to a platen gear rack PR in mesh with a platen gear PG mounted on a shaft *pg*. This gear and its shaft are adapted for 50 intermittent rotation in both directions; and means for driving this gear are provided as follows. The shaft *pg* carries two ratchets *Rr* and *Lr*, one on each side of the gear PG. The ratchet *Lr* is adapted to move the platen 55 for printing from left to right as on the usual typewriters, while the ratchet *Rr* is adapted to move the platen for printing from right to left. The ratchet *Lr* is driven by a pawl *Lp* actuated by an armature *aL*; while the 60 ratchet *Rr* is driven by a pawl *Rp* actuated by an armature *aR*. These armatures are adapted to be moved by impulses from the respective actuating relays LR and RL, which are energized in the manner to be later 65 described.

As will be seen on Fig. 7, lines *j23*—*j32* pass through a relay RT (the purpose of which will be explained later) and branch off as indicated to the relays MT of the recording device, only one relay MT being 70 shown on the drawings; it being understood that each type bar TB representing a digit value is provided with an individual actuating relay MT, only one being here shown for purposes of clarity. 75

The lines (such as T0—T9) to the recording device are provided with switches (such as JS) by means of which they may be connected either to lines *j23*—*j32* or to lines K0—K9, connecting the same with the transmitting circuits or direct with the keys K_{b1}—K_{b0} (Fig. 6) for recording without reversing. In the various digit cables designated, *k8*—*k17*, *j23*—*j32*, *j33*—*j42*, *j43*—*j52*, *k18*—*k27*, *k28*—*k37*, etc., the lowest numeral 80 designates the "one" line, the next the "two" line, etc. and the highest the "zero" line. The values of the lines of other cables as K0—K9, T0—T9, and of the relays A0—A9, B_{b0}—B_{b9}, etc. are designated by the numerical suffix. 85

The combination with a recording device of the type specified of a typewriter or a typewriting mechanism the carriage of which is adapted to move from the left towards the right when this is required during the recording process as well as in the reverse direction, forms an important feature in connection with the present embodiment of my invention; and therefore the relationship and circuits between this feature and the other parts of the apparatus will be further described immediately following. 90

In connection with Fig. 7, Fig. 15 has been referred to in connection with certain details of the type bars TB and associated mechanism. The energization of the actuating relays LR and RL will now be described in connection with suitable switching mechanism for adapting the recording device to record 100 numbers either directly from the key board or from one or more registers: with reference to Fig. 15 in which the interrupter JSi, together with the interrupting relay JSr and the contact key JSk correspond in general 105 to the switching device JS of Fig. 7. The digit keys K_{b1} to K_{b0} are also designated in connection with a suitable source of current 110 such as the battery BA. 115

The series of digit lines K0—K9 as well 120 as the line *mt* pass through an interrupting relay JSr which is adapted to be energized by depressing key JSk. The lines K0—K9 are adapted to be connected through relay JSr to lines T0—T9 respectively, which in turn serve to actuate the respective typing bars TB; these lines being normally open in this relay when de-energized. The lines *j23*—*j32* are normally connected in relay JSi 125 to the lines T0—T9 respectively, when this 130

relay is de-energized; energization of this relay being effected through line g_1 , to be described later.

We will assume that it is desired to record 5 digits directly from the digit keys K_{b1} to K_{b0} , and accordingly the key JS_k will be depressed: Then as the digit keys are depressed, impulses will be sent over the corresponding digit lines through the relay JS_r on to the corresponding one of the digit lines which is assumed as T_1 which will energize the particular digit relay MT and in accordance with the operation hitherto described will cause the corresponding digit 10 to be typed by the bar TB . Each type bar is provided with a circuit closing contact adapted to engage a fixed contact as the type bar is arrested by the usual rib or ridge on the type segment provided in well known 15 commercial typewriters, and as shown in the U. S. patent to Manning No. 612,858, October 25, 1898. The type is carried forward against the paper by its momentum and is immediately withdrawn by the spring tension 20 set up in the type bar. The contacts remain engaged during the time the type bar is in contact with the ridge on the type segment and as long as the magnet MT is energized. This closing of the contacts applies 25 plus to the line mt which will be closed in relay JS_r on to the line lr , thereby causing it to energize relay LR which will move the armature aL to the left causing the pawl L_p to engage the ratchet L_r which will carry 30 with it the gear PG which will move the rack bar PR , serving to move the platen tb one step to the left; and digits may be similarly entered and printed in a like manner until the desired number has been printed on 35 the paper carried on the platen tb from the left to the right.

Similarly, if the digits are desired to be recorded from one or the other of the registers the lines such as j_{23} — j_{32} will be connected through JS_i as above described and likewise will be printed, with the exception that the line rl will now be connected to + (in relay JS_r not energized) through mt etc. to thereby energize relay RL which will cause its corresponding armature aR to move to the left to thereby move its pawl R_p driving its cooperating ratchet R_r and carrying with it gear PG to move the rack bar PR , which will cause the platen tb to be moved from the left to the right, thereby causing the digits of the desired number to be printed from the right to the left.

Control

During the entering of a number from the key board into the first register, one of the lines in cable j_3 — j_7 and j_8 — j_{12I} corresponding to the denominational value of the 60 digits last entered, will be connected to the

+ line through contact spring AA , as has been described above.

This fact I utilize for the purpose of enabling the operator to ascertain at any time the exact number of digits which he has entered by means of the key board into the first register. The necessity for this may arise in case the operator is interrupted in his work during the entering of a number and before continuing wishes to make sure how many 70 digits of the number in question he had entered at the moment of being interrupted. This control I effect by connecting in the set of lines j_8 — j_{12I} (for instance in connecting box XB , see Fig. 7) optical signals such as 75 lamps XL with the effect that the lamps corresponding to the line under current will be lighted upon closing switches such as XS connecting the lamps with their respective lines. On Fig. 7 one of such lamps XL is 80 indicated with its switch XS and its connection to the — line of the battery. The switch XS may of course be dispensed with in cases where the current consumption of the control lamps is considered negligible. 85

Corrections

If an error has been made during the entering of a number into the first register, this register may be cleared again by directly 90 energizing the releasing relay O of the ratchet device of the said register. This energizing takes place by means of a key NJ which, as illustrated on Fig. 1 connects the energizing line f_2 of relay O with + when relay 95 A_a is energized (which is always the case when a number is entered). The corresponding connection has been omitted from Figs. 5 and 7 for purposes of clarity in the drawings; but it will be readily understood by 100 those skilled in the art that the line v of Figs. 5 and 7 correspond to f_2 on Fig. 1, and a suitable switch for connecting this line to + will 105 serve to clear the primary register I (Fig. 7). 110

Totals

The recording of a total registered in register II takes place by transmitting the digits registered in register II back to the same register through a transmitting circuit in 115 which the operating relays of the recording device are connected.

When the recording of a total from register II is to take place, relay E_p is energized by means of the recording key RE , and is maintained energized by means of a self closing circuit in the usual manner heretofore described, i. e. line g_2 through relay Z_2 (not energized) and g_3 . In relay E_p the lines 120 j_{13} — j_{17} of the transmitting circuit are normally connected with j_{18} — j_{22} over contacts in relay E_p (when not energized). The first mentioned lines from the reversing device IV (see Fig. 7) are switched over when relay 125 E_p is energized to lines j_{63} — j_{67} , which are 130

connected in relay S_j with lines $k2''-k6''$ leading to the locking armatures in register II (see Fig. 5), leaving that register in cable $k8-k17$ (on Fig. 7, $k8''-k17''$) and passing through energized relay E_p on to lines $j23-j32$.

Lines $j23-j32$, as has been explained under recording, actuate the recording device in the usual transmitting circuit to register

10 II, so that the digits are re-registered in register II after having been recorded. The energizing of relay B_h , which is effected in a transmitting process by depressing key RR is automatically effected under a recording

15 process by connecting line h with + in relay E_p .

In relay E_p line q which serves to energize relay R_q of the reversing device (see Fig. 8) is also connected to +. Relay R_q serves to 20 connect lines $j8''-j12''$ with lines $j13''-j17''$ in direct order in case none of the reversing relays $Tr1-Tr5$ are energized, the latter being always the case during total recording as register I is automatically cut out by 25 interrupting the energizing line a (see Fig. 6) for relay A_a .

The interruption of energizing line a takes place by means of a contact in relay E_p which is in series with this line and connected in box 30 SS (Fig. 6).

Releasing the ratchet mechanism of register II after totals will take place by direct energization of relay U_k , in which + is connected to line w (the energizing line for releasing relay O), when current passes line 35 $k38$ and $k39$, which is connected with $k40$ in relay E_p (see Fig. 7), energizing relay U_k as described under "transmitting". The releasing operation is the same as after a transmitting operation except that as line $k39$ is 40 connected to line $k40$ in relay E_p , it will not be necessary to provide a circuit to energize the relay U_j . The ratchet mechanism will make one more step than the number of 45 digits reregistered and then immediately thereafter the sleeve U will be returned.

Discarding digits of lowest denominational value and increasing the digit of lowest denominational value remaining by one

In a number of cases it may be desired to 50 discard from the result of a calculating operation a predetermined number of digits of lowest denominational value. This for instance, will be the case when calculating operations are performed involving monetary values, in which cases the digits of lowest denominational value in the result may correspond to fractions of the lowest monetary unit. In accordance with the present embodiment of my invention, I have therefore provided means for discarding from the result 55 any predetermined number of digits of lowest denominational value.

60 In case the digit of highest denominational

value thus discarded has a numerical value greater than a given predetermined value, in the present embodiment higher than 4, it is necessary that the digit of lowest denominational value remaining in the result should be 70 increased by one. This is also obtained in accordance with the present embodiment of my invention in a manner which will be explained below.

In order to discard from the result of a calculating operation a predetermined number of digits of lowest denominational value, I use a circuit which in principle is identical with the total recording circuit which has been described above, the difference between 75 the total recording circuit and the discarding circuit consisting therein, that whereas in a total recording circuit I transmit the digit registered in a register back to the same place in the same register, in a discarding circuit I transmit the digit of lowest denominational value, which I wish to maintain in the result, back to the place in the same register where the digit of lowest denominational value in the preliminary result has been originally registered, thereby automatically clearing the digit of lowest denominational value from its original place in the register. Thus, if I want to discard the two digits of lowest 80 denominational value from a preliminary result registered in a register, I perform this operation by transmitting the digit registered under the third locking bar of that register back to the same multiple contact relay in 85 the same register but under the first locking bar thereof.

Since during this transmitting operation the digit transmitted will have to be increased by one, in case the digit of highest denominational value discarded be higher than 4, 100 I provide means for energizing the transfer relay (through which as has been described, the transmitting circuit will then pass), in case such increase should take place. This I obtain by means of a circuit controlled by the locking armature of the digit of highest denominational value to be discarded, free armature contacts in the relays corresponding to numerical values higher than 4 being 105 connected in circuits which serve to energize the transfer relay or a separate relay RT before referred to having the same effect in the transmitting circuit as the transfer relay which has been described before.

The operation above referred to takes place 110 in the following manner, reference being had to Figs. 5, 7 and 8, (and also Fig. 16).

Assuming that the result of a calculating operation has been registered in register II 115 in the usual manner, and that it is desired to record the total while at the same time discarding the two digits of lowest denominational value and increasing the numerical value of the third digit in case the numerical 120

value of the second digit be higher than 4: instead of depressing total recording key RE (see Fig. 7) as has been described under the ordinary recording of totals, I then depress key FE (see Figs. 8 and 8a) energizing relay Fq, whereby the energizing circuit q to relay Rq which has been described under recording of totals, is interrupted, and relay Fq is automatically substituted for Rq in the total recording circuit.

In relay Fq the transmitting circuit for the registered digit of lowest denominational value is switched from j8" to j14", i. e. to the transmitting circuit corresponding to the digit of the next lowest denominational value registered in register II, that being in this case the digit of highest denominational value to be discarded.

The energizing of relay Ep (see Fig. 7) which takes place in an ordinary total recording process by the direct depression of key RE, in the present case takes place by means of a contact in relay Fq connecting energizing line p of relay Ep to +.

Line j8" in relay Fq is also connected to line j101, which (see Fig. 5) is connected with a free contact armature in each of the register relays A5—A9, i. e. in each of the register relays corresponding to numerical values higher than 4. If any of these relays be energized, i. e. if a locking armature is locked under the second locking bar in one of these relays (see under total recording), line j101 in that relay when energized as in total recording will be connected to line j102, which as will be seen on Fig. 7 is the energizing lead for relay RT, through which the circuits pass, as has been explained before.

Relay RT has a self closing circuit j103 connected through relay Fq to j8" and thence to + and when relay RT is energized it acts as an ordinary transfer relay, i. e. when it is energized the numerical value of the circuits passing through the same is increased by one. As will appear from the above, the first total transmission circuit closed as a result of the energization of relays Ep and Bh by depression of key FE has the effect of first energizing a relay A5—A9 under control of its locked armature under bar M2 and then after closing of the contact connecting line j101 to line j102, of energizing transfer relay RT, which owing to its self closing circuit will be maintained energized for the next total transmission circuit in case the number of highest denominational value to be discarded be higher than 4.

In an ordinary recording circuit the current through j14" (see Fig. 8) as has been described before, will ultimately have the effect of energizing a relay A0 to A9 and causing energization of ratchet relay N through lines c3, c4. But since in the present instance it is not desired that any move-

ment of the ratchet mechanism should take place till after the circuit for the first digit to be really recorded has been closed, I provide in relay Fq (see Fig. 8) a contact connecting + with line x1, serving to energize a relay Xx (see Fig. 7) being connected to the energizing lead x2 of that relay in relay Sj (when not energized).

Relay Xx comprises a contact connected in series in line c3 (in connecting box PP, see Fig. 5), so that the energizing current to ratchet relay N is interrupted by the energization, as above described, of relay Xx, and in relay Xx + is connected to the energizing line ss for relay Sj. Relay Xx is also provided with one self closing circuit through line g2, which does not, however, come into effect until the ratchet mechanism has started its movement (contacts UU, VV, Fig. 5). Another self closing circuit for relay Xx is indicated on Fig. 7 with sx, and is controlled by key FE (see Fig. 8). This second self closing circuit has the effect of maintaining the energization of relay Xx during the short interval of time which elapses before contact UU, VV has been closed.

Relay Sj through which, as has been explained before under totals, the transmitting circuits j63—j67 pass, is a transfer relay in which the transmitting circuits are connected in such a manner that when relay Sj is energized, the denominational value of each circuit is increased by one, i. e. a transmitting circuit for tens will be switched on to hundreds and so on. Accordingly the energization of relay Sj and relay Fq will have the immediate effect of switching the transmitting circuit corresponding to the first locking bar in register II on to the locking armature locked under the third locking bar of the same register with the effect as has been described before, of transmitting the digit locked under the third locking bar to the locking armature under the first locking bar in the same relay and the same register, except in case the transfer relay RT has been energized, as described above, when the transmitting circuit will go to the locking armature under the first locking bar in the register relay of next higher numerical value; it being remembered in this connection that relay Sj and Fq act as denominational value transfers; while relay RT acts as a digit value transfer.

Relay Sj comprises contacts connected in parallel with the contacts in series in line c3 in relay Xx which was interrupted by the energization of the latter relay, the said parallel contact in Sj being closed upon the energization of that relay so that the energization of relay N will now take place in the usual manner, as described under transmitting and recording, and the remaining digits of the registered number in register II

will be reentered in sequence, as described under totals.

As it is not desired that the digit of highest denominational value to be discarded should be recorded by means of the circuit controlled by that digit as described for the sole purpose of actuating (if necessary) transfer relay RT, I prefer to provide the energizing lines for the recording device with an automatic interrupter JS (Fig. 7), the relay of which is energized by means of a circuit gj passing over a contact in relay Fq (Fig. 8), which is closed when relay Fq is energized as well as over a contact in relay Sj , which is closed when relay Sj is not energized.

The movement of ratchet bar S , which takes place in all ordinary transmitting circuits, as has been explained, has the effect of interrupting the self closing circuit $c10$ — $c11$ to the calculating relays (i. e. in the zero relay $Bk0$) and the relay Fc which interrupts the self closing circuit $c7$ of the register relays. This function of the ratchet mechanism is performed during the first discarding circuit above referred to (during which no movement of the ratchet mechanism takes place) by means of a short interval interrupting contact in relay Sj . Line $c10$ (see Fig. 5) is connected to the armature contact of said relay, and line $c11$, as will be seen on Fig. 7, is connected to both stationary contacts cooperating with said armature. The energizing of relay Sj will consequently cause a short interruption between $c10$ and $c11$ corresponding to the interruption between contact springs DA, EA, which has been described under transmitting.

In accordance with the example described above, the two digits of lowest denominational value were discarded from the preliminary result registered, this being obtained by energizing relay Fq (in which line $j8''$ is connected to line $j14''$ instead of to line $j13''$, as is the case in relay Rg) and in connection with relay Sj (in which the denominational values are further increased by one).

Now it will be easily understood that if instead of connecting $j8''$ to $j14''$ it is connected to $j15''$, the result will be that three digits of lowest denominational value are discarded instead of two, and this may be obtained by energizing, instead of Fq , another relay as indicated on Fig. 8 as Gq , by means of a corresponding key FG ; and which in connection with Sj serves to accomplish this purpose.

By providing an adequate number of discarding relays of the type described, any predetermined number of digits may be discarded during the recording process; the principle of discarding having been sufficiently described hereinbefore for one skilled in the art to readily understand it.

Subtraction in cases where the numerical value of subtractor is higher than that of subtrahend

If in a subtraction process the subtractor has a higher numerical value than the subtrahend, the result registered in register II will be the complementary number of the result desired.

Thus, if a positive number is subtracted from another positive number of lower numerical value, the result should really be the negative number resulting from the subtraction of the subtrahend from the subtractor, whereas the result registered in register II is equal to $10n$ minus the numerical value of the said negative number if n be the denominational capacity of the machine (i. e. if the register be provided with n locking bars). The registering of the desired result in this case according to the present embodiment of my invention is obtained automatically, as will be understood by the following explanation.

As has been explained under subtraction, the transfer relay DT is energized each time a digit of higher numerical value is subtracted from a digit of lower numerical value. Consequently the transfer relay DT will remain energized in all cases after the process of subtracting a larger number from a smaller number has been concluded. In that case a circuit will be closed from contact spring XA and line $k7$ (see Fig. 5) through transfer relay DT and through the subtraction relays Cn , Dn (which at this moment are still energized), line $z1$ (see Figs. 7 and 16) relay Ep (not energized), line $z2$ through relay Yz (not energized), line $z3$, energizing relay Zz , which is then maintained energized by means of a self closing circuit through relay Yz .

In relay Zz line gj is connected to line n , which (see Fig. 9a) is the energizing line for the subtraction relays Cn , Dn .

These relays which become de-energized in the usual manner when the usual releasing process is started, will therefore be automatically energized (after return of sleeve U) again by means of contacts $g1$, (see Fig. 5) and gj , line n , through relay Zz (Fig. 7). This will have the same effect as the depression of the subtraction key RO , as previously described, except for the circumstance that relay El is not energized.

In relay Zz , gj is also connected to the energizing lead p of relay Ep , with the same effect as the effect of depressing transmitting key Re . A process of transmitting back to the same register will consequently now be automatically started, and will proceed just as described under recording of totals, except for the fact that the complementary values will be re-registered owing to the

circuits passing through the energized subtraction relays.

Also owing to the transfer relay D_t remaining energized, the process of transmitting back to the same register the complementary values of the digits first registered therein, will proceed until the ratchet mechanism has reached its extreme position towards the right. The circuit z_1, z_2, z_3 which was established (starting with k_7 and following through as hereinabove described) when the sleeve of the ratchet mechanism previously reached its extreme position towards the right, is now, owing to the energization of relay E_p as referred to above, (Fig. 7) switched on to z_4 from z_1 energizing relay Y_2 so as to interrupt the self closing circuit for relay Z_2 with the effect that the releasing process now takes place in the ordinary manner.

The energization of releasing relay U_k takes place through line k_7 , connected with z_5 after the interruption of line n in relay Z_2 as usual when the capacity of the machine is surpassed and the transfer-relay consequently is energized.

Standard registers

The register unit which is diagrammatically illustrated on Fig. 5 is a standard type of register unit, which I utilize in connection with the present embodiment of my invention. This unit is represented on Fig. 10 with squares "Reg", F_c and D_c .

As it will have been understood from the previous description, this standard register unit may be utilized for various purposes, such as for registering numbers directly entered therein by means of a key board, registering numbers transmitted to the same from another register unit by means of a transmitting circuit, as well as for registering the result of a sum or difference transmitted to the same by means of an addition or subtraction circuit, as previously described: and is also utilized in multiplication and division to be described later.

The connection with a standard register unit of a key board with ten digit keys is indicated in Figs. 5 and 6.

From Fig. 7 (and also Fig. 10) and in connection with the description of the transmitting, addition and subtraction processes, it will be seen that a register unit which is to be used for purposes of transmitting, addition and subtraction will have to be connected with a transmitting relay (B_h) and an addition switch relay (E_l), as well as with a reversing device in accordance with Fig. 8 and transfer and subtraction relays as illustrated on Fig. 9a. Further, in order to adapt the register unit for recording of totals, it will have to be connected, as indicated on Fig. 7 (and Fig. 10), with a total

recording relay E_p and with auxiliary relays and recording device.

In adapting the machine according to my present invention for various purposes of calculation, I employ a number of standard register units which are each provided in accordance with the purpose for which they are adapted with one or more auxiliary relays of the type described in connection with the transmitting, addition, subtraction and total recording processes.

It will be understood that by using an appropriate number of such registers it is possible on a machine according to my present invention, to perform various different calculating operations simultaneously. Thus a number entered into the first register unit of a calculating machine, i. e. such register directly actuated from a key board, may be transmitted from that register simultaneously to a number of other registers connected in parallel and each set for performing a different operation, such as simple transmitting, addition, subtraction and so on. This flexibility will be appreciated from a consideration of Fig. 10.

On Fig. 10 there is diagrammatically illustrated as a part thereof what will be termed in this specification or description of the invention a standard register assembly which comprises a register unit together with auxiliary relays and a set of calculating relays for addition purposes.

The following grouping of the component parts of the specific standard register assembly forming a part of the present preferred form of the invention is not to be understood as defining by limitation the term "standard register assembly" as used in some of the claims; since in its broader aspects this term is not intended to be so limited.

As will be seen, this standard register assembly comprises a register Reg , which is identical with the register unit illustrated and described in connection with Fig. 5. In connection with that register there is shown a relay A_a with connections as illustrated on Fig. 6. Further, the unit comprises a relay B_h (transmitting relay), connected and described in connection with the transmitting process and illustrated on Fig. 7. Further, a relay E_l , which cooperates with the transmitting relay B_h , as described under addition. Further, a relay E_p (totals recording relay) connected and adapted to operate as described under totals. Further, the figure comprises a set of calculating relays for addition, Add in connection with subtraction relay C_n, D_n and transfer relays CT, DT as illustrated on Fig. 9a and described under addition and subtraction.

Further, relays S_j, RT, X_a for the purpose of discarding decimals; Y_2, Z_2 for changing from positive to negative values in subtraction; and U_k, U_j for releasing, etc., as has

been described in connection with Fig. 7. By comparing Fig. 10 with Fig. 7, it will be seen that a standard register assembly, as illustrated on Fig. 10, differs from Fig. 7 principally in that it only comprises one registering device. It will be obvious from an understanding of Fig. 10 that a plurality of units or groups of units may be utilized in place of the corresponding single units or groups of units; whereby through such combinations any desired type of machine may be produced. For example, by way of illustration, a plurality of keyboards or/and a plurality of recorders may be used; also a plurality of register units may be used if desired. Furthermore a plurality of register assemblies may be used, as will be more particularly pointed out.

When a plurality of register assemblies, as heretofore defined, are employed as is the case in most practical or desirable embodiments of my invention, it will be understood that all registers and their auxiliary relays are connected in parallel between the same sets of lines. Thus all incoming lines to the several contacts and relays in one register are connected also to the corresponding contacts and relays in the other register or registers or register assembly or register assemblies. This is an important feature which must be borne in mind during the description of the multiplication and division operations. Therefore in order to facilitate an understanding of these interconnections between the various standard register assemblies more detailed line connections have been illustrated in Fig. 10a.

On this figure (10a), in order to show all of the line circuits in detail, it has been necessary to represent the standard register device in more or less representative fashion, only the outlines of the relays N and O together with the ratchet bar mechanism and one of the register relays (representing the series of relays A0—A9) are shown. Also the lines belonging to the cable comprising numerous lines have in most cases been shown by a single heavy line, and this heavy cable is designated as being connected to a single armature contact connection, which it is to be understood represents a plurality of armature contact connections one for each individual line (the complete layout of the standard register unit and all connections being clearly shown in detail on Fig. 5). Furthermore, the calculating relays Bk0—Bk9 which are shown in detail on Fig. 9 are indicated on Fig. 10a by one relay at the left hand bottom of the figure which is designated Bk0—Bk9. Furthermore, the subtraction relays Cn and Dn, shown in detail on Fig. 9a, are designated on Fig. 10a as a single relay; it being obvious that in practice these two relays may, if desired, be incorporated in a single relay having two rows

of stationary contacts in accordance with the principle on which relay RT is constructed. One of the purposes of this figure is to indicate the manner in which various standard register assemblies may be connected together, as will be more fully described later.

Fig. 10a shows the connections in the standard register assembly in detail and the interconnecting lines from this register assembly extend to the edges of the figure, therefore adapting a plurality of these figures to be placed together or in combination with other figures in accordance with the system to be described following in connection with Figs. 16, 17 and 18.

Fig. 16, comprising Fig. 15, two sheets of Fig. 10a and Fig. 8a, illustrates a suitable machine for the purposes of addition, subtraction, transmitting, the taking of totals with or without discarding, recording and indicating when a larger number is subtracted from a smaller, etc. The principles of this arrangement have been described heretofore in connection with Fig. 7 and are schematically illustrated on Fig. 10.

Later on, under multiplication and division, there will be described the manner in which this machine may have certain units added thereto to adapt it for multiplication and division in addition to the above mentioned operations.

MULTIPLICATION

General introduction

As has been explained under addition, the two numbers to be added are entered in two separate registers (for example I and II, Figs. 7 and 16), and the transmitting circuits passing between these registers are closed in series with a set of calculating relays connected in accordance with the addition table.

If the set of calculating relays in this addition circuit be replaced by a similar set of relays in which the digit lines are connected in accordance with the multiplication table, multiplication will take place in exactly the same manner as addition. If for instance the digits in the respective registers controlling the circuits be 2 and 3, the result in case the calculating relays connected in the circuit be connected according to the addition table will be 5, whereas if they be connected in accordance with the multiplication table, the result will be 6.

As the product of two digits will, however, in most cases be a number comprising tens as well as units, the transmitting circuit when multiplication is to take place, is caused to pass two sets of contacts of the calculating relays, in one of which sets the digit lines are connected in accordance with the unit's side of the multiplication table, whereas in the other of which they are connected in accordance with the ten's side of the mul-

tiplication table, the resulting impulses being caused to influence locking armatures under two locking bars of consecutive denominational value in the register in which the result is to be registered.

In case a number comprising several digits is to be multiplied with a single figure, the operations which have to take place consist in multiplying the digits of the first mentioned number in sequence with the single figure starting with the digit of lowest denominational value and consecutively adding the ten's digit of each partial product to the unit digit of the following partial product. In order to obtain this, the impulse from the ten's side of the set of multiplication relays is caused to energize a relay of corresponding numerical value in a set of addition relays through which the impulse from the unit's side of the set of multiplication relays in the following circuit is caused to pass, the resulting sum being transmitted in the ordinary manner to the register in which the product is to be registered.

After the digits of this product have been transmitted to and registered in the last mentioned register, a multiplication of the same number with another single figure may take place, and the result of that multiplication may be transmitted through an addition circuit to the register in which the first result has been registered: in which case we will obtain the registration in the result register, of the product of the first number with a number comprising two digits and so on.

Details of multiplication

The principle of the multiplication process according to the present embodiment of my invention will now be explained with reference to the diagrammatic plan on Fig. 11, where **X**, **XI**, **XII** represent standard register units of the type illustrated on Fig. 10a and described above: **IV** represents a reversing device as illustrated on Fig. 8, and **XIII** represents a set of calculating relays connected in accordance with the ten's and unit's side of the multiplication table as illustrated diagrammatically on Fig. 12: **MD** is a multiple contact switching relay adapted to connect the several sets of lines of the machine for multiplication purposes: and **OM**, **ND**, **Ua**, **Uc**, **Ud**, **Ue**, **Uf**, and **Fcm** are auxiliary relays for various purposes, which will be described below. A key for connecting the machine for multiplication is designated as **KM**, i. e. for energizing multiple contact switching relay **MD**.

The multiplication circuits and operation will be described in connection particularly with Fig. 11, since it is believed to be easier to follow the principles of this system on one sheet; and the main circuits between the units may be followed out on Fig. 13. For a more complete comprehension of the complete

mechanism, reference may be had to Fig. 17 which contains the same units shown in Fig. 16 with the addition of the units of Fig. 11a; and another register assembly **10a** is added to the two shown in Fig. 16, these three standard register assemblies being designated **X**, **XI**, and **XII**.

It will be understood that if the internal connections in the various units schematically represented on Fig. 11 are desired to be followed, this may be done by referring to Fig. 10a (standard register assembly), Fig. 8 (reversing and discarding relays), and Fig. 12 (multiplication relays): it being borne in mind that three of the standard register assemblies as illustrated on Fig. 10a are utilized in multiplication, in accordance with the respective designations on Fig. 11 as **X**, **XI** and **XII**.

Since the multiplier and multiplicand are entered into their respective registers in the same manner heretofore explained, the key board has been omitted from this diagram (Fig. 11), it being understood that one such key board is common to all registers.

With reference to Fig. 11: when a multiplication process is to be started, relay **Aa** of register **X** is energized as described in connection with Fig. 6, and is connected to the key board in the manner illustrated on Fig. 6. Then the operation takes place in the following manner:

First, the first factor is entered in the usual manner into register **X**, by depressing the digit keys.

Second, by depression of key **RR** in register assembly **XI**, it is transmitted through the reversing device to register **XI** in the usual manner as described under transmitting from register **I** to register **II** in connection with Fig. 7.

Third, then the second factor is entered in the same manner into register **X**, by depressing the digit keys.

It will be understood that after the two factors have been registered in the manner described in register **XI** and **X** respectively, the ratchet mechanism of register **XI** will have been released and returned to its original position, whereas the ratchet mechanism of register **X** into which the second factor has been entered will be in a position corresponding to the denominational value of the second factor. Also it will be understood, as described under reversing, that the reversing relay corresponding to the said denominational value will be energized (cable **j3-j7**, **j8-j12**, **j8'-j12'**, Figs. 6 and 8).

Fourth, the actual multiplication is started by depressing key **KM** energizing multiple contact switch relay **MD** through line **dm** (see Fig. 11) which is maintained energized in the usual manner by a self closing circuit (line **g2** from register **X**).

In relay **MD**, the energizing lead **hXII** for

relay B_h in register XII is connected to +, thereby setting that register for transmitting as described in connection with the transmitting process.

5 In switch relay MD line $k37XI$ from register XI, which is the energizing lead for addition relay $Bk0$ in that register, is connected with line $g7$ from register XII, line $g7$ being connected in said register (the ratchet mechanism of which is in normal position) with $g1$ through a contact on the same contact spring as the contact for line gj , but insulated from the latter. In register XII, $g1$ is connected to + in the energized relay B_h as

10 10 described under transmitting. Consequently, the zero addition relay ($Bk0$) in the set of addition relays in register XI is energized.

The lines $k8-k17$ from register XI pass through multiple switch relay MD, as seen

20 20 on Fig. 11, and when that relay is energized, are switched off from their ordinary course as described under addition and on to cable $k45-k54$, which contains the energizing leads for the multiple contact calculating relays of the multiplication device XIII. The set of multiplication relays and their connections is illustrated on Fig. 12, the ten relays are indicated as $Mk1-Mk0$, and each relay has two sets of each ten contacts which serve

25 30 to connect the two sets of each ten digit lines in accordance with the ten's side and unit's side of the multiplication table in the manner as previously explained.

The energizing of multiple contact switch

35 35 MD as will be seen from the above, has had the effect of energizing relay B_h in register XII, and consequently the zero relay in the set of addition relays for register XII has been energized as described under transmitting (i. e. + battery, B_h , $i1$, E_l , $i2$, F_c , $i3$).

40 Further, the zero relay in the set of addition relays for register XI has been energized through lead $k37$, and lines $k8-k17$ from register XI have been connected to the energizing lines $k45-k54$ for the multiplication

45 45 relays with the effect of energizing the multiplication relay corresponding to the numerical value of the digit of lowest denominational value registered in register XI.

50 50 A transmitting process to set up partial products is now started from register X to register XII owing to the energization of relay A_a in register X and of relay B_h in register XII, as described under transmitting,

55 55 the reversing mechanism being set as described under reversing (one of the lines in cable $j8'-j12'$), in accordance with the last digit entered into register X.

Lines $k8-k17$ from the locking contacts

60 60 in register X (which in the addition circuit between registers I and II, as described in connection with Fig. 7, passed through a set of addition relays) are in the present instance connected through energized relay MD, with lines $j104-j113$ (Fig. 11), being

one of the sets of digit lines connected on the unit's side of the multiplication relays: and these lines are also connected with lines $k0-k9$, the latter being the energizing lines for the relays of register X.

As the multiplication relay corresponding to the digit of lowest denominational value registered in register XI is energized, the transmitting circuit entering on one of lines $j104-j113$ will proceed through a line corresponding to the unit's side of the product of the digits of lowest denominational value in register X and of lowest denominational value in register XI.

70 75 Lines $j23-j32$ from the multiplication relays pass to the addition relays of register XI in the manner illustrated on Figs. 9a and 9, and as the zero relay ($Bk0$) is energized, no addition will take place, and the impulse will proceed as described under transmitting to the relays of the same register (see Figs. 9a, 9 and 5) ($j33-j42$, $j43-j52$).

80 85 Lines $j33-j42$ from register XI are also connected in the multiple contact switch relay MD with lines $j23-j32$ for register XII, passing through the set of addition relays in that register, and as the zero relay is energized, no addition takes place even here, and the impulse proceeds to the corresponding energizing lead for the relays in the same register in accordance with the usual transmitting process, energizing in register XII the relay, the numerical value of which corresponds to the units of the product of the digits of lowest denominational value of the two factors.

90 95 The energization of a multiple contact relay in register X and XI has no effect on the armatures locked therein, as the line $c4$ for these registers is interrupted by means of relay MD (Fig. 11) so that no energization of relays N for X and XI can take place (Fig. 5).

100 105 The object of energizing the multiple contact relay in register X is to close a second circuit to the addition relays in register assembly XI with the object of transmitting the ten's digit of the first partial product as will be described more particularly following. The sole object of energizing the multiple contact relay in register XI is to close, in the manner which has been described before, the ordinary transfer circuit to energize the transfer or no-transfer relay cooperating with the addition device of the same register.

110 115 In register XII, where relay B_h is energized, as has been mentioned before, the energization of ratchet relay N will take place through the usual circuit, +, B_h , $c1$, F_c , $c2$, $c3$, $c4$, as described under transmitting, with the effect of causing the ratchet mechanism to make one step. As described under transmitting, the movement of ratchet bar S has the effect of interrupting near the end of its

stroke the contacts DA, EA (Fig. 5) between lines c1—c10.

Line c10—c11 from register XII is connected in multiple switch relay MD with line c10—c11 from register XI, with the effect that contact DA, EA in register XII serves to maintain the energization of the energized calculating relay in the addition device of register XI, as well as in register XII, and both of these relays as well as relays Fc in registers XI and XII are accordingly de-energized by the movement of the ratchet mechanism of register XII. Further, line c7 from register XII is connected in MD with c7 from register XI, with the effect that the contact IA, Ja closed by the movement of ratchet mechanism of register XII will maintain the energization of the energized multiple contact relays in register XII, as well as in register XI during the reciprocation of ratchet bar S in register XII.

From the foregoing description it will be understood how the unit's digit of the first partial product has been registered in register XII. The ten's digit of the same product is not immediately transmitted to register XII, but has energized the corresponding relay in the addition device of register assembly XI in order to be automatically added to the unit digit of the next partial product when the impulse corresponding to this unit digit passes register XI in accordance with the transmitting circuit described above. In order to obtain this provisional registration of the ten's digit by means of an energized addition relay in register XI, a second circuit is established through the same multiple contact relay in register X immediately after the conclusion of the circuit which has been described above, and which had the result of registering the unit digit of the first partial product in register XII.

Lines j87 and j97 from register X are connected to + through relay MD. Lines j87 and j97 are the same lines which are otherwise used for transfer purposes, and as has been described under transfer, they are connected in each of the multiple contact relays with a line leaving said register through one of cables j88—j96 and j78—j86 respectively.

Since it is only necessary to have one line for each of the multiple contact relays, of the two series of lines j78—j86 and j88—j96 only the 10 lines j78—j86 and j96 (one from each relay) will be utilized for this purpose; these lines already being present for one purpose will be used for the present additional purpose.

During the transmitting of the first impulse (unit's digit of the first partial product) relay Fcm, which through its energizing line c12 is connected in parallel with relay Fc (Fig. 5) of register XII, has been ener-

gized, whereby the lines j78—j86 and j96 are interrupted in Fcm from connection with plus (Fig. 11). When relay Fc is de-energized as described under transmitting by interrupting the connection between contact DA, EA, Fcm will also be de-energized, interconnecting cables j78—j86 and j96 so as to close a circuit from each multiple contact relay in register X through lines j114—j123 and further on to the multiplication relays, see Figs. 11 and 12.

In register X the multiple contact relay corresponding to the numerical value of the impulse just transmitted, is maintained energized by means of the following circuit: +, relay ND (when not energized); line c7 (register X), maintaining energization of the relay previously energized by means of a self closing circuit in register X.

Further, in relay MD + is connected to line y1 connected to line y2 in relay Fcm when that relay is not energized, serving to energize relay ND, and being also connected in relay MD with line c7 from register X. From the above it will be understood that so long as relay Fcm is energized, the self-closing or holding circuit for the multiple contact relay in question of register X will extend through relay ND. This circuit will be interrupted in ND and at the same time (or strictly speaking one instant before) it will be closed in relay Fcm, by means of y2 connected through MD to c7 when that relay is de-energized, as described above.

At this moment, i. e. immediately after the conclusion of the first transmitting circuit described, i. e. by the first de-energization of Fcm, the circuit will be closed from + through one of lines j87 or j97, and the energized multiple contact relay in register X (i. e. the multiple contact relay in which the digit of lowest denominational value of the second factor is registered).

As previously explained the ten lines j78—j86 and j96, each corresponding to one multiple contact relay, are now connected (relay Fcm) to lines j114—j123, and as seen on Figs. 11 and 12, go on to the multiplication relays where they form the digit lines on the ten's side of those relays, so that the impulse entering will leave the multiplication relays XIII on one of lines k28—k37 corresponding to the numerical value of the ten's digit of the first partial product, it being remembered that the multiplication relay corresponding to the digit of lowest denominational value registered in register XI is energized. The said impulse through k28—k37 passes to register XI as seen on Fig. 11 to the set of addition relays in register assembly XI (see Fig. 9) energizing the addition relay therein corresponding to the numerical value of the ten's digit of the said product.

The circuit just described is closed during the reciprocating movement of ratchet bar S

in register XII, serving to move the ratchet sleeve thereof one step towards the right, and is maintained closed so long as relay F_{cm} remains unenergized. The self closing circuits for the addition relays in register XI and XII are interrupted as described above by means of contacts DA, EA in register XII, and upon the return of the ratchet bar S of register XII to its original position, the contacts JA, JA between c_1 and c_7 is interrupted so as to interrupt the self closing circuit for the multiple contact relays in registers XI and XII.

As has been described above, the zero relay 18 in the addition device of register XII and the relay corresponding to the ten's digit of the first partial product in the addition device of register XI are energized, and accordingly relay F_e and F_{cm} will be energized 20 through the connection c_{11} , c_{12} , described under transmitting, whereby the self closing circuit through relay F_{cm} , y_1 , y_2 and c_7 to the multiple contact relays of register X is also interrupted. At the same time, as will 25 be remembered from the description of the transmitting circuit, relay D_e is de-energized (by the de-energization of the multiple contact relays in the corresponding registers), thus starting a new transmitting circuit from 30 register X to the locking armature under the second locking bar in register XII.

This transmitting circuit operates in exactly the same manner as the one described before, with the exception that in the addition 35 relays in register assembly XI the relay corresponding to the ten's digit of the first product is energized instead of the zero relay as was the case during the first circuit, and consequently the numerical value of this ten's digit will be automatically added to the numerical value of the unit digit of the second partial product during the passage of the circuit through the calculating relays of register XI, the sum being transmitted to the 40 second place in one of the multiple contact relays of register XII. On its way to the multiple contact relays of register XII the impulse, as has been described before, passes through the calculating relays of register XII 45 of which, however, at present the zero relay is energized as described, so that no addition will take place.

When the registration in register XII of the partial product of the digit of lowest denominational value registered in register XI with the factor registered in register X has proceeded so far that the impulse corresponding to the ten's digit of the last partial product has energized the corresponding addition 50 calculating relay in register assembly XI, it is necessary in order to complete the multiplication process, that this impulse should be transmitted on to and be registered in register XII. In accordance with the present embodiment of my invention I obtain this by

transmitting a zero impulse, through the ordinary transmitting circuit described, to register XII, and to this zero impulse the impulse corresponding to the energized addition relay of register XI will be added in the usual 70 manner before arriving at register XII.

The zero impulse above referred to, is obtained by switching the releasing circuit (register assembly XII) j_7 in relay MD (see under transmitting) on to line j_32 leading 75 to register XI, thus obtaining an impulse in the usual zero transmitting circuit. The releasing circuit which is established under addition through the reversing relays and j_7 , is established in this instance after completing the next step of the ratchet mechanism in register XII, through j_{124} (see Fig. 8) which (see Fig. 11) is connected through relay MD with the coil of relay U_a so as to energize the latter.

Line k_{39} from register XII, which is connected to + in the manner described under transmitting when the unoccupied part of that register is found to be cleared, is connected in relay U_a with the energizing lead for relay U_e in which + is then connected directly to the energizing line w for releasing relay O in register XII.

Relay U_e which, as will be noted performs in this instance the same function as relay U_h , as described under transmitting, is also provided with a self closing circuit in the same manner as relay U_h and controlled by the sleeve of register XII.

The multiplication of the digit of lowest denominational value of the factor registered in reversed order in register XI in the manner described, with the factor directly entered into register X proceeds in the manner above described until the complete product of the digit of lowest denominational value of the first mentioned factor with the whole of the second factor has been registered under the respective locking bars in register XII.

After the conclusion of this process, it is necessary that the ratchet mechanism in register XI should make one step in order to energize in the manner described above, the multiplication relay corresponding to the second digit of the factor registered in register XI, and also, as the digit of lowest denominational value in the product which is now to be transferred to register XII has a 115 denominational value one higher than the digit of lowest denominational value of the product already registered in register XII, it is necessary, as will be understood, that the ratchet mechanism of register X should make one further step in order to energize the reversing relay of next higher denominational value.

The stepping movement of the ratchet mechanism in register XI is caused by the energization of relay U_e as described above,

by connecting the energizing lead $c4$ for the ratchet relay of register XI directly with +.

A + impulse is sent through relay Uc to register X in the same manner as to the ratchet relay N, and also to the zero multiple contact relay of the register, in order to make sure that zero be substituted for any digit which might remain registered under the locking bar in question from a previous calculating operation.

Through a contact in relay Uc + is also connected directly to line l for the addition relay El in register XII, so as to set this register for addition, as previously described.

The connections described above take place during the backward stroke of the sleeve in register XII, and when the sleeve arrives in its normal position, the self closing circuits to relays Ua , Uc are interrupted (contacts VV, UU), and the multiplication of the factor entered into register X with the second digit of the factor registered in register XI commences, a zero having been added as described, to the factor entered in register X in order to increase the denominational value of the next product accordingly.

The multiplication of the second digit (the ten's digit) of the factor registered in register XI with the factor registered in register X now takes place, comprising exactly the same sequence of operations as described under the multiplication of the unit digit of the first factor with the second factor, with the difference that register XII, as described above, has now been set for addition, so that the impulses transmitted to register XII from the addition relays of register XI are now automatically added to the impulses which are already registered in register XII.

After the multiplication of the ten's digit of the first factor with the second factor has taken place in this manner, the same processes take place as described, (after the conclusion of the multiplication of the first digit of the first factor with the second factor and so on), until the complete product of both factors has been registered under the locking bars in register XII.

As the first factor has been transmitted originally to register XI by means of an ordinary transmitting process, it will be found in accordance with the description of the transmitting process that zero is registered under all remaining locking bars (if any) in register XI. $k39$ will be connected to + over XA , pass through MD and energize relay Ud in which + is directly connected to the releasing relays of all registers returning the ratchet mechanisms thereof to their original position.

When the ratchet mechanism of register X has returned to its original position, the self closing current for relay MD as well as for relay Ud is interrupted by means of contact VV, UU in that register, returning all parts

of the machine to their original position with the product of the two factors in question registered in register XII.

In the following general impulse circuit in multiplication will be recapitulated with reference to the diagrammatic Fig. 13, in which for the sake of clearness all auxiliary relays and lines have been omitted.

The circuit starts from $j1$ over contacts in BB (see Figs. 5 or 10a) on one of the lines $j2-j6XII$ through engaged contacts in the Bh relay associated with register XII, proceeds through cable $j8-j12XII$ to the reversing relays TR1-TR5 (one of which has been energized from register X through cable $j8-j12X$). From the reversing relays the circuit proceeds through cable $j13-j17X$ to register X, from which register two impulses, for the units and tens respectively, pass out.

(1) The unit impulse circuit proceeds through engaged contacts in relays A0-A9 X, line $k8-k17X$ and through the multiplication relays MK0-MK9 one of which has been energized from a corresponding locking contact in register XI through cable $k45-k54XI$. From the multiplication relays the impulse proceeds through cable $j23-j32XI$ through the addition relays $Bk0-Bk9$ of register XI (one of which is energized) and through cable $j33-j42XI$ and cable $j23-j32XII$ through the addition relays $Bk0-Bk9$ of register XII, and through cable $j33-j42XII$ to the multiple contact relays A0-A9 of register XII. The multiple contact relays of register XI are energized through cable $j33-j42XI$, which branches off from the impulse circuit described, behind the addition relays of register XI; and the addition relays of register XII are energized through cable $k28-k37XII$ from register XII.

(2) The ten's circuit from register X which is closed immediately after the unit's circuit, by one of the multiple contact relays A0-A9 X through cable $j43-j52X$, passes through cable $j114-j123$, through the set of tens contacts of the multiplication relays MK0-MK9 and on through cable $k28-k37XI$ energizing the addition relays of register XI.

Capacity of the machine in multiplication

As it will be understood from the foregoing description, the capacity of the machine in multiplication is principally restricted by the reversing mechanism which is set by means of register X after each multiplication of the second factor with a digit of the first factor. Thus, if the second factor (the factor entered in register X) comprises three digits reversing relay TR3 will be energized for the multiplication of that factor with the first digit of the first factor. For the next digit of the first factor reversing relay TR4 will be en-

ergized, and for the third digit of the first factor reversing relay TR5 will be energized. If the first factor comprise more than three digits, the multiplication can then not be completed.

As register XII has a capacity of five digits, it is obvious that no product comprising more than five digits can be registered therein, but for practical purposes it may often 10 be sufficient to obtain correctly the five first digits of a product comprising more than five digits.

This object may be obtained in accordance 15 with the present embodiment of my invention by providing the fifth reversing relay TR5 (Fig. 8) with an auxiliary contact connected in series with a contact in relay MD in the energizing circuit *om* for an auxiliary multiple contact switch, *Om* (Fig. 11) 20 through which the connections from all the contacts BB in register XII to the two sets of lines *k*2—*k*7 and *j*2—*j*7 pass.

The said switch is adapted when energized 25 to connect the contact BB (and the contact spring *XA*) corresponding to the first locking bar in the register through line *k*2 with the line *k*3 corresponding to the second locking bar in the register and so on, and at the same time to connect the line *j*3, whose contact 30 is under contact spring *AA* corresponding to the second locking bar of the register, with the line *j*2, corresponding to the first locking bar of the register and so on, whereas the first contact under contact spring *AA* instead of being connected to line *j*2 is connected 35 in the said relay when energized with the ordinary zero transmitting circuit *j*32 as previously described.

It will be understood that this switching 40 will have the effect of adding the impulse registered under the second locking bar in register XII to the impulse transmitted in the ordinary multiplication circuit to a contact armature under the first locking bar of register XII, whereas at the same time the impulse which was already registered under 45 the first locking bar in register XII and which represents the digit of lowest denominational value in the preliminary product is discarded.

In this manner it will be understood that 50 the capacity of register XII is always utilized for registering the digits of highest denominational value in any product comprising more digits than the number of locking bars in register XII.

Recording the result after multiplication

It will be understood that for practical 60 reasons the connection illustrated on Fig. 7 to the recording device is always interrupted automatically or otherwise during the multiplication as one does not generally desire a recording of the partial and preliminary products. This interruption if it is to take

place automatically, can be effected by means of a contact in relay MD serving to connect + to *qj* (Fig. 11a) energizing the relay JSi (Fig. 15) serving to interrupt the type bar circuits, as heretofore described (see also Fig. 11).

The recording of the result registered in register XII may take place in the manner already described under recording of totals, energizing totals recording relay *Ep* of that 75 register, by closing circuit *p* either by means of key *RE* or by means of one of keys *FE* or *FG* illustrated on Fig. 8 (in the case of discarding decimals).

The energization of totals recording relay 80 *Ep* may, however, also take place automatically as follows:

Releasing relay *Ud* which, as described above, is energized after the multiplication process is finished, comprises a contact connecting + to energizing lead *u*10 for an auxiliary relay *Ue*, having a self closing circuit through an unenergized relay *Uf*, so that relay *Ue* will remain energized after *Ud* has been de-energized so long as *Uf* is not energized (see Figs. 11 and 11a).

The energizing line *p* for the totals recording relay *Ep* of register XII is connected through a contact in the energized relay *Ue* and through a contact in relay *Ud* (when that relay becomes de-energized) with the + line so as to energize totals recording relay *Ep* of register XII automatically at the moment when *Ud* is de-energized, which as has been explained above, takes place when the ratchet mechanisms have been returned to their normal position.

Now the recording process takes place in the manner which has already been described.

The releasing process after recording from 105 register XII takes place in the usual manner as described by means of a circuit passing line *k*38 over relay *E*XII as *k*39 closed in relay *Ep*XII with *k*40 which from register XII, as will be seen on Figs. 11 and 11a, passes through the energized relay *Ue* to the energizing line *u*11 for relay *Uf*, the energization of which interrupts the energization of *Ue* so as to return both relays to their original position.

Automatic continuous sequence of operations

After the termination of a multiplication process as previously described the recording of the product in register XII is started by energization of relay *Ue* by circuit *U*10 which is closed by *Ud* which is the releasing relay after multiplication. If desired to automatically record after any other calculating process, *Uk* is utilized to close circuit *u*10 for energizing relay *Ue* or its equivalent. The effect will be that the recording process from the register assembly, (Fig. 10a) in which relay *Ep* is energized by the circuit *p*, will automatically be started. The termina- 120 125 130

tion of this automatic process may, if desired, start a new recording process if the releasing relay U_k for that assembly is utilized for the energization of another relay with the 6 function of U_e and so on.

From the above it will be readily understood that if, after multiplication, instead of connecting line p in relay U_e to +, line h (the energizing line for relay B_h , the energization of which results in transmitting) and line q (the energizing line for relay TR_5) of any particular register assembly be each connected to + in relay U_e , then the result in a register assembly where the relay A_a is 10 energized will be automatically transmitted without reversing to the register assembly 15 containing the particular relay B_h whose energizing line has been thus connected to + in relay U_e .

20 Similarly, if instead of line h , line l (the energizing line for relay E_l —which relay closes line h with + to thereby energize relay B_h —the energization of which two relays results in addition) of any particular register assembly be connected with + in relay U_e , then the result will be automatically added 25 to the register assembly containing the particular relay E_l whose energizing line l has been connected to + in relay U_e .

20 Also, in like manner, if a subtraction operation is desired following multiplication, instead of an addition operation, then line n is connected to + in relay U_e simultaneously with the connection between lines l and q 25 to + in relay U_e ; thus serving to simultaneously energize subtraction relays DT and CT together with relays E_l , D_h and TR_5 . This results in a subtraction operation in which the result is simultaneously subtracted from the 30 number in the particular register assembly containing the relay E_l .

Likewise successive operations following any given operation may be automatically effected by closing contacts in a switching relay such as U_e associated with any desired register assembly, + to the desired lines for effecting such successive operations in any desired register assemblies; the energization of the switching relay such as U_e being effected, as above described, by means of the releasing relay associated with the register assembly whose last operation is to be succeeded by the successive automatic operation.

Thus it will be readily appreciated by those skilled in the art that in the simple manner above described a machine is provided, according to my invention, which is adapted to perform any predetermined sequence of continuous operations automatically. From this it naturally follows that if instead of said operations being predetermined it is desired to perform them selectively, this may easily be effected by insertion of suitable switches connecting one or more of the switching relays 45 such as U_e with the desired releasing relay

associated with the register assembly in question.

In order to have available at this point a ready reference to the various relays normally utilized to start the various operations, 70 as well as the releasing relays which are normally utilized after any given operation, and which latter relays serve to energize the switching relays such as U_e , through which medium the relays utilized at the commencement of any given operation are energized by closing their lines with +, the two sets of respective relays normally so used will now be set forth. For effecting totals, the relay E_p commences the process; for effecting trans- 75 mittal to a given register, the relay B_h commences the process; for effecting addition and subtraction, the relay E_l commences the process; for effecting multiplication, the relay MD commences the process, said four last mentioned relays and their operation having been previously described; for division, the relay DM commences the process, said last mentioned relay and its operation being more fully described hereinafter. After transmitting, addition or subtraction, the relay U_k is utilized for releasing the circuit; after multiplication, the relay UD is utilized for releasing the circuit, the said relays and their 80 operation having been previously described; and after division a suitable relay is utilized for releasing the circuit, said relay and its operation being referred to more fully hereinafter.

DIVISION

100

General introduction

If it be supposed that after the conclusion of a multiplication process the registers X and XI , in which the two factors have been 105 registered, remain in the position they took up immediately before releasing, and that the calculating mechanism connected with register XII be then set for subtraction instead of addition, a multiplication and transmitting process to register XII , as described, may take place in reversed order provided the ratchet mechanisms of X and XI were adapted to step backwards, in which case the products of the digits of the first factor with the second factor would be subtracted from the number registered in register XII , instead of being added in that register as described under multiplication. However, I prefer in the 110 present embodiment to effect this reversal by a set of relays RT_2 — RT_5 (Fig. 8a), which accomplishes the same results as above mentioned.

When this reversal of the multiplication 115 process has been finished, the result in register XII will be zero, and the operation which has really taken place consists in the division of the number registered in register XII with the number registered in register X , the quo- 120

125

tient being the number registered in register XI.

From this it will be seen that in principle the division process is identical with the multiplication process, except for the fact that the calculating mechanism of register XII is set for subtraction instead of for addition.

In carrying out a division process in accordance with the present embodiment of my invention, I register the dividend in register XII by means of the usual transmitting process after having first entered the same into register X, whereupon I enter the divisor in register X as described under multiplication. As was explained in connection with the transmission of a number from one register to another, the register into which the number is transmitted will be cleared of any digits it may contain with the result that the contacts of the zero relay will be closed in all denominational orders higher than that of the highest denominational order digit transmitted. As will be explained later, the zero next to the highest denominational order digit of the dividend will be used as the highest denominational order digit of the dividend.

The object of the division process now is to find the digits of the quotient and to register the same in register XI.

The digits of the quotient I find in accordance with the present embodiment of my invention by a process which is termed in the following specification "the selection process."

In order to carry out the said selection process automatically, I may employ in addition to the three register units which I have illustrated in connection with the multiplication process, a fourth register, the ratchet mechanism of which is adapted to make ten steps, i. e. a number of steps corresponding to the units of the numerical system in question.

For ordinary purposes it is, however, not necessary to use a complete register unit as the automatic selection process may take place by means of a ratchet mechanism as referred to above, without the usual multiple contact relays.

A ratchet mechanism of the kind which I prefer to utilize for this purpose is illustrated on Fig. 14b and somewhat diagrammatically on Fig. 14a, and as it will be noted, this mechanism differs from the ratchet mechanism illustrated on Fig. 1 in that the sleeve on Fig. 1 is adapted to make five steps; while the sleeve on Fig. 14b is adapted to make ten steps in order to make connection with ten different stationary contacts BB. Now, in accordance with the present embodiment of my invention, I carry out the selection process automatically by causing the said ratchet mechanism to perform a series of steps, making connection in succession with the several stationary contacts BB (Fig. 14b).

Further, I connect the said ratchet mecha-

nism in accordance with the principles of my invention described under multiplication in such a manner with register X and register XII, that when the contact spring of the sleeve of said ratchet mechanism makes connection with the first stationary contact a multiplication circuit is closed by means of which the two digits of highest denominational value of the divisor entered into register X are multiplied with 9, and the product transmitted to register assembly XII, the calculating device of which as mentioned above has been set for subtraction.

In said register XII a subtraction is caused to take place of the two digits of the said product from corresponding digits of highest denominational value in the dividend.

In case the said two digits of the product of 9 and the two digits of highest denominational value of the divisor form a number higher than the number constituted by the corresponding digits of highest denominational value in the dividend, the subtraction process will cause energization of the transfer relay, and in that case it has been proven as will be shown that the digit of highest denominational value of the quotient is lower than 9.

I utilize the closed transfer circuit to cause the division ratchet mechanism referred to above (Fig. 14b) to perform a second step, closing a similar multiplication circuit with 8 as multiplier, and if the subtraction of that product in the same manner as described above has also the effect of causing transfer, the stepping movement of this division ratchet mechanism is continued.

When the aforesaid part of the product of a number connected in the division ratchet mechanism, and the two digits of highest denominational value of the divisor is equal to or lower than the corresponding digits of highest denominational value of the dividend, no transfer will be caused by the subtraction process referred to, and this will have the effect of closing the circuit for the no transfer relay, which circuit I utilize for the purpose of causing the complete multiplication process of the digit in question and the divisor to be carried out, the product being transmitted in the usual manner to register assembly XII and automatically subtracted therein; then releasing the division ratchet mechanism so as to return the same to its original position and also registering the digit in question (which is the digit of highest denominational value of the quotient) in register XI.

When the first digit of the quotient has been found in the manner described, the selection process with regard to the next digit is started automatically, and the process is continued so long as the capacity of the machine permits.

As the selection process in accordance with the present embodiment of my invention

- does not have any other object than to cause one or the other of two different circuits to be closed according to whether or not a particular digit is a correct digit of the quotient, 5 it will be understood that no movement of the ratchet mechanism in either register takes place during the selection process and accordingly the interval of time necessary for carrying out the selection process with regard 10 to one digit, is extremely short, being dependent only on the movement of contact armatures in a limited number of multiple contact relays.

As I have described above, I utilize for selection purposes only the two digits of highest denominational value of the divisor, in accordance with the usual procedure in long hand division. This also is with the object of saving time during the period of selection.

- 20 In case the product with a certain selected quotient digit and the two digits of highest denominational value of the divisor be equal to the corresponding digits of highest denominational value of the dividend, it may 25 happen that the multiplication of the said quotient digit with the complete divisor will give a product with a higher numerical value than the dividend, and for this contingency I have provided means to reduce the numerical 30 value of the quotient digit selected by one, and at the same time adding the numerical value of the divisor to that of the dividend.

It will be understood that when I speak of the dividend in this connection, I refer either 35 to the dividend originally registered in register XII, or to the rest remaining therein at the moment.

- As the product of 9 and the two highest digits of a divisor may in some cases be a 40 number of two figures and in other cases a number of three figures, it is necessary in order to automatize the selection process that the said product should always be made up into a number of three figures. Consequently, 45 in case the number has only two figures, I introduce a zero before the number so as to form the hundred's digit of the same. Accordingly I can always utilize two digits of identical denominational value of the product 50 obtained in accordance with the selection process for the purpose of subtraction from the corresponding highest digits of the dividend.

In subtracting the said product from the 55 digits of highest denominational value of the dividend it will be found that in some cases the product is a number of three figures, the two figures of highest denominational value of which constitute a number of lower numerical 60 value than the two figures of highest denominational value of the dividend. In that case it is necessary in order to obtain a correct result to consider the digit of highest denominational value of the dividend as the 65 digit of second highest denominational value

in the number from which the number constituted by the two digits of highest denominational value in the product should be subtracted, and although this preliminary step in the selection process is only necessary in 70 the case last referred to, I prefer to perform this step in all cases in order to standardize the sequence of steps in the selection process.

Thus, on carrying out the selection process I always complete the product of 9 and the 75 two digits of highest denominational value of the divisor so as to form a number of three figures by introducing a zero before the product as the hundred's digit of the same in case it be originally a number of two figures, 80 and I then always utilize the hundred's digit and the ten's digit of that three figured number.

Also as the first step in the selection process I always subtract the two figured 85 number obtained in this manner from a two figured number of which the unit's digit is constituted by the digit of highest denominational value of the dividend, whereas the ten's digit is constituted by a zero. 90

It will be understood from what has been said above about the selection process that during the selection process a sequence of multiplication circuits are closed, and each of these circuits is identical with the multiplication circuits described under multiplication with the exception that the division ratchet mechanism illustrated on Fig. 14 is substituted in the circuit for the multiple contact relays of register XI, the first contact 100 under the ratchet mechanism corresponding to a locking armature locked in the relay corresponding to 9, the second to 8 and so on. 105

Reversing circuits in division

As has been explained in connection with the ordinary process of reversing, the set of reversing relays TR1—TR5 are controlled from the ratchet mechanism of a register in 110 such a manner that the first reversing relay is energized in the normal position of the ratchet mechanism (corresponding to first locking bar), the second reversing relay is 115 energized by the ratchet mechanism in its position over the second locking bar, and so on, the transmitting circuits being so connected in the reversing relays, that when the n 'th reversing relay is energized, the circuit 120 through the n 'th digit in the register from which the reversing device is controlled is switched on to a locking armature in another register under the first locking bar thereof, whereas the circuit corresponding to the 125 $(n-1)$ 'th locking bar in the first register is switched on to an armature under the second locking bar in the other register and so on.

During the division process the reversing device is controlled by the ratchet mechanism

of register XI, i. e. the register in which the digits of the quotient are registered.

In the original position of register XI the reversing device has to be set for the purpose of connecting the circuit corresponding to the digit of highest denominational value of the divisor (i. e. the circuit through a locked armature under the first locking bar in register X) to the circuit corresponding to the digit of highest denominational value of the dividend and so on.

When the ratchet mechanism of register XI has made one step, the connection from the digit of highest denominational value of the divisor has to be connected with the circuit corresponding to the digit of next lower denominational value of the dividend as originally registered in register XII. This as will be noted, is what one would obtain by means of the ordinary reversing mechanism if it were controlled by a ratchet mechanism adapted to step backwards instead of forwards as has been explained under the introduction to the description of the division process.

In order to avoid the necessity of providing an auxiliary backwards stepping ratchet mechanism for controlling the reversing device in this manner, I provide, as previously stated, a set of auxiliary relays RT2, RT3, RT4, RT5 (see Fig. 8a). The energization of these auxiliary relays is controlled in accordance with the denominational value of the dividend entered in register XII. I prefer to effect the said energization from register X and I obtain this by entering into register X besides the divisor a number of zeros so as to register the same number of figures in the divisor as in the dividend.

The energizing circuits for the ordinary reversing relays from the ratchet mechanism of register XI are switched in the energized auxiliary reversing relays (division reversing relays) in such a manner that the circuit closed in the first position of the ratchet mechanism of register XI serves to energize the ordinary reversing relay corresponding to the last locking bar actuated in register XII (in which the dividend is registered).

The circuit closed in the second position of the ratchet mechanism of register XI serves to close through the auxiliary reversing relays the energizing circuit for the ordinary reversing relay corresponding to the last but one locking bar actuated in register XII and so on.

DIVISION

Details

The circuits closed in order to carry out the selection process will be described in the following with reference to the figure utilized for describing the multiplication circuits in connection with Figs. 14, 14b and 18 (particularly Fig. 14a).

On Fig. 14b the division ratchet mechanism is illustrated in detail, whereas the multiple contact relays are illustrated diagrammatically on Fig. 14a, it being understood that these relays are of the same general type as all the other multiple contact switch relays illustrated, except the locking relays. A complete machine for division and multiplication is shown in Fig. 18, it being understood, as will be easily seen from the foregoing description, that this machine can also be utilized for purposes of addition and subtraction etc. as previously described.

When starting a division process, the dividend is first registered in the usual manner in register XII through register X and the ordinary reversing relays, and the divisor is entered directly in register X together with a number of zeros, as described, to make up the same number of figures as the number of figures in the dividend.

The depression of division key KD (see Fig. 14a) now causes energization of multiple contact switch relay DM, which is provided with a contact for circuit dm through unenergized relay Uo to energize relay MD shown on Fig. 11a. Both relays DM and MD are maintained energized by the same self closing circuit g2X as described under multiplication.

Further, the energizing leads j8'-j12' (see Fig. 8) leading from register X to the usual reversing relays are switched in relay DM on to leads j8-j12X, which as will be seen from Fig. 8a, are the energizing leads for the auxiliary reversing relays RT2-RT5, no auxiliary reversing relay being needed in case of the first ordinary reversing relay TR1, which is energized directly from lead j8, as will be easily understood by reference to Figs 8 and 8a.

Further, + is connected in relay DM to j1 of Reg. XI and the set of lines j2-j6 from register XI are connected in relay DM to lines j8-j12XI, which pass through the auxiliary reversing relays and serve to energize the ordinary reversing relays TR1-TR5 as described above.

Further, lines k45-k54, which pass according to the multiplication diagram to the multiplication relays Mk0-Mk9, are for division purposes connected over relay DM (Fig. 14a) in which they are interrupted when this relay DM is energized, and at the same time + is connected in relay DM to the contact spring AAd (through line aad) of the division ratchet mechanism (Figs. 14a and 14b), the corresponding contacts BB9-BB0 of which are connected to the corresponding relays in the set of multiplication relays.

Selection process in division

Further, + is connected in energized relay DM to lines lXII and nXII, (Figs. 14a and

18) so as to set register XII for subtraction as described under the subtraction process.

Further, + is connected in energized relay DM to the energized line *dd* for multiple contact relay SD1, hereafter termed "first selection relay". Energizing line *dd* passes through contacts in relay *Su* when that relay is not energized.

Further, in relay SD1 the cable *j8-j12* passing to the reversing device, is interrupted, and + is directly connected to line *j9* in that cable (Fig. 14). Line *j9* corresponds to line *j9'* on Fig. 8, and is the line which would in the usual reversing process be connected to the circuit corresponding to the digit of next highest denominational value registered in registered X. In relay SD1, however, the lines *j13-j17* for the reversing device, through one of which the + current switched on to line *j9* will pass, are switched off from register X and connected with lines *k2-k6XII*, the connection in relay SD1 between lines *j13-j17* and *k2-k6* being arranged so as to increase the denominational value of the circuit by one, with the effect of connecting the circuit through the locked armature contact of highest denominational value in register XII (see Fig. 5), and then on to one of lines *k8-k17*, *k18-k27*, which are connected in relay *El* with lines *k28-k87XII* (see Fig. 18), energizing in register assembly XII the addition relay corresponding to the digit of highest denominational value registered in register XII.

Further, in relay SD1 + is connected to line *j14* passing relay *Ep* to line *j19* connected in *Aa* to *k3X* passing through a locked contact armature under the second locking bar in register X (see Fig. 10a), i. e. through the locked armature corresponding to the digit of next highest denominational value of the divisor leaving register X through one of lines *k8-k17X*, which are connected (see Figs. 14 and 14a) in relay SD1 with lines *j78-j86*, *j96*, which are connected (Fig. 11a, *Fem*) with lines *j114-j123* being the set of digit lines connected in the multiplication relays on the ten's side thereof, as described under multiplication.

The addition relay in register XI corresponding to the ten's unit of the product of 9 and the digit of next highest denominational value in the divisor consequently becomes energized, as multiplication relay *Mk9* is energized directly from the division ratchet mechanism through contact spring *AAd* and contact *BB9*.

The circuit *c10*, *c11* and *c12*, which, as described under multiplication, is closed when an addition relay in both of registers XI and XII has received current, energizes relay *Fem* (see Fig. 11a), and in that relay + is connected to line *de*, which passes through a closed contact in the unenergized relay *Su* (Fig. 14a) and energizes relay SD2, which

will be termed hereafter "the second selection relay". Relay SD2 has a self closing circuit *df* passing through unenergized switch relay *Sp* to contact *SL* in the division ratchet mechanism through which contact it is connected to + when ratchet bar *S* is in its normal position (see Fig. 14b). Line *df* is connected in relay SD2 (when energized) with line *dg*, which is the energizing line for switch relay *Su*, with the effect of energizing switch relay *Su* as soon as the self closing circuit for SD2 is established.

In relay *Su* the energizing lines *dd* and *de* for the first selection relay and the second selection relay respectively are interrupted so that the first selection relay is de-energized, whereas the second selection relay is maintained energized by means of its self closing circuit.

In the second selection relay SD2, circuit *j13* is connected in relay *Ep* with *j18* over *Aa* to *k2X* which is connected to +, while at the same time lines *j8-j12* (register XII) are interrupted, and as the connection between *k8-k17X* and *j114-j123XIII* in relay SD1 has now been interrupted, the circuit will pass through *j18* connected in *Aa* to *k2X* in accordance with the usual transmitting circuit as described under multiplication through register X, unit's side of the multiplication relays, addition relays of register XI, addition relays of register XII to the multiple contact relays of register XII (see Fig. 14), and as the addition relays of register XII have been set for subtraction, the impulse transmitted, which (in accordance with the multiplication transmitting circuit described under multiplication) represents the unit's digit of the sum of the ten's digit of the product of 9 and the digit of next highest denominational value in the divisor and the unit digit of the product of 9 and the highest digit in the divisor, will be subtracted from the highest digit of the dividend causing the transfer relay in register XI to be energized in case the said sum be higher than 9, and causing the transfer relay in register XII to be energized in case the digit subtracted from the highest digit of the dividend be higher than the said dividend.

The energizing circuit *c4 XII* for the ratchet mechanism of register XII is interrupted in relay *Su* (see Fig. 14a) so that no movement of the ratchet mechanism of register XII takes place. *c4 XII* at the same time is connected, however, in relay *Su* with line *sc* serving to energize switch relay SD3, which will be termed hereafter "the third selection relay".

By means of this second step in the selection process it will be noted that the ten's digit of the three figured number resulting from the multiplication by 9 of the two digits of highest denominational value in the divisor has been subtracted from the digit of

highest denominational value in the dividend.

The third selection relay now serves to close circuits by means of which the hundred's digit of the said three figured number is subtracted from the zero introduced in Reg. XII before or during transmission of the dividend as mentioned before, as the digit of highest denominational value of the dividend in connection with the first step of the selection process.

Relay SD3, as will be seen on Fig. 14a, has a self closing circuit s_6 so connected to + in relay SD2 so as to maintain SD3 energized so long as SD2 is energized.

In relay SD3 the self closing circuit c_{10} , c_{11} and c_{12} for the addition relays and relay F_c in register XI and XII and the relay F_{cm} in register XII is interrupted with the effect of de-energizing the energized relays, above enumerated, in both registers.

Further, relay SD3 serves to energize S_m which is a switch relay serving to interrupt circuit c_7 for registers XI and XII, c_7 being as described before, the self closing circuit for the multiple contact relays of said registers, so as to de-energize the energized multiple contact relays in both registers.

Further, in relays SD3 + is connected to j_8 leading to the reversing relays, in exactly the same manner as was done in connection with j_9 in relay SD1, consequently energizing the addition relay in register XII corresponding to the zero which has been introduced that is, the zero in Reg. XII in front of and next to the highest denominational order or first significant digit of the dividend. It will be understood that during the subsequent selection processes, the digit corresponding in the remainder of the dividend registered in register XII, to the zero introduced as the highest digit of the dividend during the first selection process, may have any numerical value between 0 and 9.

Further, in relay SD3 + is connected to k_2X in exactly the same manner as was the case with k_3X in register SD1 with the effect of energizing the addition relay in register XI corresponding to the ten's unit of the product of 9 and the highest digit of the divisor.

Further, + is still connected (in SD3) to $j_{32}XI$, which forms part of the zero multiplication transmitting circuit as described in connection with Fig. 14. The + on line $j_{32}XI$ has the same effect as if a zero were inserted before the highest digit of the divisor and the trial quotient were multiplied by 0 and the units of such product were added to

tens of the product of the trial quotient by the highest significant digit of the divisor. Plus on line $j_{32}XI$ continues across DT or CT of Reg. XI and across the B_k relay of Reg. XI representing the tens of the product of 9 by the highest digit of the divisor, en-

ergizing a relay A of Reg. XI corresponding to such tens of the product or the sum of such tens plus a carry of one. In the case in which any relay A other than the zero relay of Reg. XI is energized, a significant number will be transmitted to Reg. XII and subtracted from the zero in effect inserted before the highest digit of the dividend. This will cause the DT relay, Reg. XII, to be operated. The relay DT, Reg. XII, will also be operated in case the zero relay A of Reg. XI is operated and the DT relay, Reg. XII, was operated when subtraction was made from the highest significant digit of the dividend. The operation of the relay DT, Reg. XII, indicates that the quotient is too large. In the case in which the zero relay A of Reg. XI is operated and zero is transmitted to Reg. XII in which the CT relay is operated, the relay CT, Reg. XII, will again be operated after subtraction has been made from the zero inserted before the highest digit of the dividend. This indicates that the trial quotient is small enough.

The effect of applying plus to line $j_{32}XI$ is to transmit the tens of the product of the highest digit of the divisor by a trial quotient, with or without a carry, to Reg. XII. In the case of a two digit product, this circuit will transmit a zero to Reg. XII to be subtracted from the zero in front of the highest digit of the dividend. This in effect inserts a zero before a two digit product.

As stated before, in order to automatize the operation, a zero is inserted in effect in front of the highest digit of the dividend and the highest two digits of a product which is always made a three digit product by the insertion of a zero in front of a two digit product, is subtracted from a number comprising the highest digit of the dividend and the zero inserted in front of such digit. This is necessary as in cases in which the highest two digits of the dividend are slightly larger than those of the divisor and in which the correct quotient is one, the quotient would be found to be 9 if the highest two digits of a three digit product were compared with the highest two digits of the dividend. In all cases the dividend remainders in which the above relation of numbers is found, a zero constitutes the highest digit of the new dividend.

To recapitulate: The selection process which has been described above comprises the closing in succession of the first, second and third selection relays, thereby closing the circuits for carrying out the multiplication of 9 with the two highest digits of the divisor making the product up to a number of three figures by inserting a zero before the first number digit of the product if such product comprises but two digits, and after having inserted a zero in front of the highest registered digit to act as the digit of high-

est denominational value of the dividend, then subtracting the two digits of highest denominational value of the product from the thus formed two highest digits of the dividend. After transmission of the dividend into Reg. XII has been effected a zero will be found in front of the highest registered digit of the dividend. The selection relays switch the circuits to the contacts of Reg. XII in such a manner that the sum of the tens of the product of the trial quotient by the units digit of the divisor and the units of the product of the trial quotient by the tens digit of the divisor will be subtracted from the highest significant digit of the dividend and that subsequently the tens of the product of the trial quotient by the tens digit of the divisor will be subtracted from the zero in front of the highest significant digit of the dividend.

As mentioned above, the subtraction in register XII will either have the effect of energizing the transfer relay or no-transfer relay for that digit.

In the latter case (energization of no-transfer relay) 9 is provisionally considered as the first digit of the quotient and the first selection process is terminated. In the former case (energization of transfer relay) it has been proven that the first digit of the quotient is lower than 9, and a new selection process is automatically started with 8 as multiplier instead of 9, but otherwise identical with the selection process described above, comprising the successive energization of the first, second and third selection relay.

The automatic repetition of the selection process with 8 as multiplier instead of 9 takes place by means of a circuit from + in the third selection relay (energized) through line *st*, which is connected through contacts in the transfer relay of register XII (see Figs. 9a and 14a) with line *st*, energizing the ratchet relay of the division ratchet mechanism XIV (see Fig. 14). This ratchet mechanism will accordingly be energized if transfer has taken place in register XII.

The movement of the ratchet bar X of the division ratchet mechanism, as described above interrupts the self closing circuit for the second and third selection relay (circuit *df*), and as relay *Su* is energized from relay SD2 (second selection relay), relay *Su* is de-energized with the effect of energizing the first selection relay (circuit *dd*), and the selection process is repeated with 8 as multiplier.

The repetition of the selection process with successive digits 9, 8, 7, 6 and so on, is now automatically continued in the manner described until none of the transfer relays in register XI or XII are energized after the conclusion of the selection process, in which case the multiplier last tested is provisionally considered as the first digit of the quotient

and the division process proper takes place.

When the no-transfer relays in both register XI and XII are energized, the line *st* (Fig. 9a) in one register is connected in series through contacts in said relays to line *ts*, in the other register (it being understood as hereinbefore described that each of the standard register assemblies X, XI and XII comprise relays *Cn*, *Dn*, *CT* and *DT*—Fig. 10a), energizing relay *Us* (see Fig. 14a).

In relay *Us* + is connected to energizing line *ps*, energizing relay *Sp* and to line *dg*, energizing relay *Su*.

The energization of relay *Sp* interrupts the self closing circuit for the second and third selection relay in the same manner as contact *SL* of the division ratchet mechanism XIV, being connected in series with said contact, as described before. The energization of relay *Su*, which is maintained by means of relay *Us* serves to maintain relay SD1 (first selection relay) unenergized.

As the selection relays are consequently now switched out of the multiplication circuit, a multiplication will take place in the ordinary manner in accordance with the diagram illustrated on Fig. 11 of the complete divisor with the digit corresponding to the contact BB9—BB0, with which the contact spring of division ratchet mechanism XIV is in engagement. (See Fig. 18.)

The product of the divisor and the said digit will be automatically subtracted from the dividend as described in the introduction to the division process, owing to the fact that the calculating relays of register XII have been set for subtraction by energizing relay *DM*.

The result of the said subtraction will be registered in register XII instead of the dividend originally registered therein.

Registering quotient

Relay *Us* (see Fig. 14a) has a self closing circuit from the sleeve actuated contact *g2XII* and *g2XIV* in register XII and in the division ratchet device respectively, and is accordingly maintained energized so long as one of the said sleeves is out of its normal position.

The releasing circuit *j124* as described under multiplication is switched in relay *DM* to the energizing lead for relay *Ub*, which accordingly becomes energized immediately after the conclusion of the multiplication and subtraction process referred to above. In relay *Ub* the ten lines *k45*—*k54* from contacts BB9—BB0 in the division ratchet mechanism XIV are connected with the energizing line *j33*—*j42XI* for the multiple contact relays in register XI, whereby these energizing lines are directly connected with the energizing lines *k45*—*k54* (Fig. 12) for the multiplication relays. Simultaneously in relays *Ub* + is connected to line *c4XI*, which

is the energizing line for the ratchet relay of register XI.

Consequently the multiple contact relay in register XI corresponding to the contact 5 BB9—BB0, at which the division ratchet device has stopped, will be energized, and as the ratchet mechanism is caused to make a step, the armature in the said relay under the first locking bar in register XI will be 10 locked, thus registering as the first digit of the quotient the digit corresponding to the last digit tested during the selection process.

In Ub + is connected to the energizing 15 line $wXII$ for register XII, returning sleeve u of register XII to its normal position: whereby + goes over contact $g7XII$, relay Ub to $wXIV$, releasing the division ratchet device. When said ratchet device has 20 turned to its normal position, the self closing circuit for Us is interrupted, deenergizing Us and also Ub . Hereby Sp is also de-energized, as well as relay Su , the de-energization of the latter causing the first selection 25 relay to be energized again (circuit dd), so as to start a new selection process from 9 on with the remainder of the dividend substituted for the dividend originally registered in order to find the second digit of the 30 quotient.

As has been described before, the auxiliary reversing relays (Fig. 8) are controlled by the movement of the ratchet mechanism in register XI, so that the circuits for the new 35 selection process are reversed correctly in accordance with the denominational value of the rest of the dividend.

If the result of the subtraction tested in the selection process be 0, the no-transfer relays in registers XI and XII will be energized, and ordinarily the quotient digit found 40 would in that case be registered.

As the test has, however, only been carried out with the two highest digits of the divisor, 45 and the corresponding highest digits of the dividend, it may happen in that case, that the complete product of the divisor with the quotient digit found by the selection process is nevertheless higher than the dividend, in 50 which case the quotient digit found should not be registered, the correct digit being one unit lower.

In accordance with the present embodiment of my invention, I have provided means for 55 automatically adding the divisor to the result of such erroneous subtraction so as to obtain a registered result in register XII corresponding to the product of the divisor with a quotient digit one unit lower than the one 60 found by the preliminary test, at the same time decreasing the numerical value of the quotient digit found with one before registering the same in register XI.

This object I attain by means of the circuit 65 $k7XII$ $z1$ (see Fig. 9a) described in connec-

tion with the subtraction circuit, $z1$ being switched in the energized relay DM (see Fig. 14a) to energize a relay ZM , having the same self closing circuits as Us (from ratchet device XII and XIV).

The ordinary releasing circuit $j124$ is provided with interrupting contacts (Figs. 10a and 9a) controlled by the transfer relay DT of register XII.

Relay ZM closes the energizing circuit oo 70 for relay Uo , which serves to interrupt the self closing circuit for the multiplication relay MD (Fig. 11), as well as for the division relay DM (see Fig. 14a) whereby all connections established for division purposes are interrupted.

At the same time relay Uo connects + to a line IXII so as to energize relay El in register XII, the effect of energizing this relay 85 being, as described under addition, to start an ordinary addition transmitting circuit from register X (in which register relay Aa is energized, see Fig. 16).

The numerical value of the divisor registered in register X is accordingly transmitted and added to the number registered in register XII, the latter being the result of subtracting from the dividend originally registered a product of the divisor and a quotient digit one unit too high.

Lines $k45$ — $k54$ are also connected in relay ZM with the energizing lines for the multiple contact relays in register XI ($j33$ — $j42XI$) in such a manner as to connect each line in the set $k45$ — $k54$ with a line in the other set having a numerical value one unit lower, with the effect that a quotient digit one unit lower than the one found by the preliminary test is registered in register XI.

A relay ZN receives an energizing impulse 100 through line $k7XII$, said line being connected through relay Uo to relay ZN .

The energization of relay ZN also closes + to the energizing line for a relay ZP and to the energizing line for DM . In relay ZP the self closing circuit for Uo is interrupted, and when the ratchet mechanism of register XII returns to its original position, the self closing circuit is interrupted even for ZN , 110 and a new selection process is started, with the result of finding the second digit of the quotient and so on.

Termination of division

The automatic division process described above will continue until interrupted by a current impulse energizing the releasing relays O of all ratchet mechanisms.

Said current impulse may be obtained after 120 the registration in register XI of a predetermined number of quotient digits by connecting the energizing line for a switch operating relay with one of contacts BB in register XI.

This releasing relay is not shown since its 130 function, mode of connection and operation

will be readily understood due to the fact that it is quite similar to the releasing relay U_d , used for releasing the machine after multiplication, and also to the releasing relay U_k , used for releasing the machine after addition, subtraction or transmitting. This relay may be energized by a line connected to a contact which is adapted to slidingly engage the contacts BB XI; the contact to which the energizing line for this relay is connected is therefore adapted selectively to be placed in contact with the desired one of the contacts BB XI, so that after any predetermined denominational value of the quotient has been reached the mechanism will be automatically released. This relay will carry contacts which will be adapted to close the circuits in all of the lines w and v for all of the releasing mechanism relays O in registers X, XI, XII and XIV, when the relay is energized. It will therefore be seen that when this relay is energized, the relays O for all of the ratchet mechanisms will be energized, thereby serving to release the various ratchet devices of the entire mechanism. It will likewise be obvious that since this relay is adapted to be energized by any predetermined contact BB, the releasing after division may take place after any predetermined number of denominational digits has been entered in register XI. The connections are so obvious from the above description in connection with similar units heretofore fully described that details in the drawings showing this relay are superfluous and will tend to further complicate the drawings.

This releasing relay is the one referred to heretofore under the heading "automatic continuous sequence of operations".

40 The said current impulse for stopping the division process may be closed automatically in accordance with the difference in denominational value of dividend and divisor, i. e. in accordance with the number of zeros entered after the divisor as described in register X, so as to always obtain a quotient comprising only whole figures or a quotient having a predetermined number of decimals.

It will be understood that in division as well as in other calculating processes, the tabulating mechanism of the recording device is adjusted in accordance with the numbers of decimals in the result.

In case continuous division is desired, i. e. 55 in case it is desired to obtain a quotient with an unlimited number of figures, the impulse corresponding to the digits of the quotient are connected directly to operate the recording device instead of being connected as described above, to a register, such as register XI.

Continuous division necessitates the alternating use of two registers for the dividend, the remainder remaining after each subtraction process in a register being always trans-

mited to the other register with its digits transposed one step in the direction of higher denominational value in the course of each transmitting. In this manner the digit of highest denominational value in any remainder of the dividend will always be registered under the locking bar under which the digit of highest denominational value in the original dividend was registered.

The reversing device as will be understood, 75 remains stationary when continuous division takes place as described above.

Multiplication and division with constant factor or divisor respectively

As it will be easily understood, it is possible in accordance with the present embodiment of my invention to substitute for the register in which the last factor or divisor is entered a multiple contact switch, 85 the contacts of which perform the same function as the locked armature contacts of the register, and which is set for a predetermined constant factor or divisor.

A plurality of relay operated contact switches set for constant factors or divisors may be employed in connection with my machine.

Instead of a simple multiple contact switch of this kind I may also employ for the same 95 purpose a register with manually operated contacts by means of which any predetermined constant factor may be drawn into the calculating operation.

In accordance with the embodiment of my invention specified above, I have described the use of a plurality of auxiliary switching relays, and for the sake of making the principles of the invention better understood, I have to a large extent illustrated one relay 100 for each particular purpose.

It will, however, be easily understood that in the practical embodiment of my machine a large number of the various relays may be combined so as to form multiple contact relays of a standard type.

Also relays which are used for one particular purpose in connection with one calculating process may be utilized for a different purpose in connection with another calculating process in order to decrease the number of relays.

OPERATION

Addition

120

In describing the various circuits prepared or completed during an operation in which two or more numbers are to be added together reference will be made to Fig. 7 which shows the general wiring diagram of a machine comprising a keyboard, a primary register in which numbers are stored under control of the keyboard, and a secondary register to which the numbers from the primary register may be transmitted and registered and 125 130

in which the sum of the numbers in the primary and secondary registers which are added together in the adding mechanism may also be registered.

- 5 As the circuits are being traced on Fig. 7, it will be assumed that Fig. 6 has been substituted for the square III, that Fig. 5 has been substituted for the squares I and II, that Fig. 8 has been substituted for the square IV, 70 and that Figs. 9 and 9a have been substituted for the square V, and also that the relay Ci has been omitted.
- 10 Fig. 7 shows the various lines that enter and leave the primary register, (Reg. I), and 75 the various lines that enter and leave the secondary register, (Reg. II).

- Fig. 5 shows the type of register that may be used for both primary and secondary registers. When the machine is equipped with 20 only two registers and is wired so that only one of the registers is under control of the keyboard the only circuits and contacts which are necessary in Reg. I are the circuits and contacts corresponding to those shown in 25 Fig. 1. For example, each multiple contact relay A1 to A0 arranged in Fig. 5 in the order A0 to A9, may be provided with five contacts for a five denominational machine, and one free contact corresponding to the contacts Hc2', Ic2', Fig. 1. The ratchet mechanism will be provided with a movable contact member AA and five contacts j3—j7, Fig. 5, corresponding to contacts BB, Fig. 1. These contacts are connected to the wires in the 30 cable j3—j7 leading to the relay Aa, Fig. 6. Connected to the movable contact member AA is a line j1 which, in Fig. 6, may be connected across a make contact in relay Aa to plus. The energizing lines j43—j52 for the 35 relays A1 to A0 coming from the keyboard, Fig. 6, enter Fig. 5 at the lower end of this figure. Reg. I also includes a ratchet operating magnet N and a restoring or ratchet releasing magnet O. None of the other contacts, circuits and relays in Fig. 5 are necessary in Reg. I. Registers which are connected to receive numbers both under control of the keyboard and by transmission, include all 40 of the relays, contacts and lines shown in Fig. 5, as indicated in Fig. 10a.

- 50 It may be stated that the relays in Reg. I, Reg. II and the adding relays are arranged in the order 0, 1, 2, 3, 4, 5, 6, 7, 8, 9 while the digit lines in the cables are arranged in the 55 order 1, 2, 3, 4, 5, 6, 7, 8, 9, 0.

The following example will be assumed:

$$\begin{array}{r}
 4699 \\
 + 5291 \\
 + \quad 25 \\
 \hline
 10015
 \end{array}$$

The first number, 4699, is set up in Reg. I in the following manner:

- 55 I—The switch 0I, Fig. 6, is closed.

(1) A circuit is closed from plus across the contact bar NN, over switch 0I, over line a, and over the coil of the connecting relay Aa to minus causing the relay Aa to pick up. The relay Aa prepares and closes the following circuits:

(1a) A circuit is prepared from plus across an operated contact of relay Aa, and over line j1 to the movable contact member AA. This circuit will not be continued when the contact member is in its home position as there is no j2 contact necessary in Reg. I (Fig. 7).

(1b) The lines j3—j7 from Reg. I are connected across operated contacts in relay Aa to lines j8—j12 which are connected to the energizing leads j8'—j12', Fig. 8, for the reversing relays TR1—TR5.

(1c) Lines j18—j22 which are adapted to be connected to the lines j13''—j17'', Fig. 8, are as shown in Fig. 6 connected across operated contacts in relay Aa to lines k2—k6 which, as shown in Fig. 5 in which they enter at the bottom of the figure, are connected to the movable contact members under the locking bars M1 to M5 in Reg. I.

(1d) Lines K1—K0, Fig. 6, which may be connected to plus by depression of the respective numeral keys Kb1—Kb0 are connected across operated contacts in relay Aa to lines j43—j52 which are the energizing leads for the multiple contact relays A1—A0, (A0 to A9) Fig. 5, and are shown as entering near the bottom of the figure.

(1e) A circuit is also prepared from plus across an operated contact of relay Aa to line c2 which is connected to a stationary contact in each of the multiple contact relays A0—A9, as shown in Fig. 5, and which is indicated by the reference character Ic2' in Fig. 1. None of the circuits described in paragraphs 1a—1e is completed at this time.

II—The key Kb4, Fig. 6, is depressed first as in this machine the highest denominational digit is entered first.

(1) Depression of the key Kb4 completes a circuit from plus across the contact bar NN, across the key Kb4, over line K4, over an operated contact in relay Aa to line j46 in the cable j43—j52 which in Fig. 5 is shown entering the lower portion of this figure. The circuit continues over the coil of the multiple contact relay A4, Fig. 5, to the minus line which causes this relay to pick up.

(1a) As the relay A4 picks up it extends the circuit "1e of I" over the movable contact Hc2' (Fig. 1) of relay A4 (Fig. 5) to line c3, across the connection box PP, and across the coil of the ratchet operating magnet N to the minus line. As the magnet N picks up it moves the ratchet bar S to the right, Figs. 1 and 5, and through its engagement with the arm T on the sleeve U moves the sleeve U and the arm X to the right, Fig. 1, thereby camming the locking bar M1 down-

- wardly, Fig. 1. This releases all the locked contacts under this bar and permits the movable contact member in the energized relay A4 to move outwardly and prepare a circuit with the corresponding fixed contact member which circuit is a part of a circuit used in transmission, as will be described later. After the arm X passes the end of the bar M1 the bar is returned by the spring FF into its home position to lock the movable contact member in relay A4 in closed position and the movable contact members in the other relays in open position, and to prevent return movement of the sleeve U. The relay A4 and the operating magnet N remain energized as long as the key Kb6 is held depressed. When the key is released these relays will be deenergized and the ratchet bar S will return to the left so that its second tooth will engage behind the arm T on the sleeve U. The contact member AA now engages the first of the BB contacts (Fig. 1) which, in Fig. 5, is indicated by the reference character j3, so that the following circuit was established when the ratchet bar S was moved to the right, namely, the circuit "1a in I" is extended across contact j3, line j3 of cable j3—j7, across an operated contact, Fig. 6, of relay Aa, to line j8 of cable j8—j12 which, in Fig. 7, extends across the connection box XB to line j8' of cable j8'—j12' which line j8, on Fig. 8, is the energizing lead for the reversing relay TR1, energizing this relay. As this relay is energized the line j8'' of the transmission cable j8''—j12'' which comes from the units position in Reg. II, as will be later described, is connected to line j13'' of the cable j13''—j17'' which, as shown in Fig. 7, is connected across the connection box XX to j13 and across connection box YY to line j18 of the cable j18—j22 which on the Fig. 6 is connected to line k2 of the cable k2—k6 which on Fig. 5 is shown as connected to all the movable contacts under the locking bar M1 in Reg. I. In relay A4 in which the contact under the locking bar M1 is closed, the circuit is continued to line k11 of the cable k8—k17 which will be traced further in the description of transmission and addition. The circuit just described is not activated during the entry of numbers in Reg. I as Reg. II is not under current during this operation.
- III—The digit 4 is now locked under the first locking bar M1 in Reg. I. The relay A4 and the operating magnet N are deenergized, the relay Aa is energized, and the reversing relay TR1 is energized. As the next digit 6 is entered various similar circuits are and will be prepared but it is not thought necessary to trace out all of these circuits.
- (1) Depression of the key Kb6 closes a circuit from plus across the contact bar NN, across the key Kb6, line K6, across an operated contact of relay Aa to line j48 in the cable j43—j52 which line on Fig. 5 is shown as the energizing lead for the relay A6, Reg. I. The relay A6 picks up and connects the line c2 to the line c3 which is connected to the energizing lead c4 of the operating magnet N completing the energizing circuit for this magnet which causes the magnet to operate and to shift the ratchet bar S and through the sleeve U to cam the locking bar M2, Fig. 1, downwardly which releases all the locked contacts under this bar and permits the movable contact in relay A6 to close. After the ratchet S has moved to the right the locking bar M2 is returned by a spring FF and locks the movable contact under this bar in relay A6 in closed position and also prevents return of the sleeve U and holds it in position to operate the locking bar M3, upon subsequent depression of a key. The movable contact member AA is now in contact with the contact of line j4 connected across relay Aa to line j9 (j9', Fig. 8) which causes the relay TR2 in Fig. 8 to pick up and to connect the line j8'', which comes from the units position in Reg. II, to line j14'' which is connected to line j19, Fig. 6, across the relay Aa to line k3 which leads to the movable contact members under bar M2 of Reg. I. Relay TR2 also connects j9'' to j13''. Upon release of the key Kb6 the relay A6 and the operating magnet N are released.
- IV—The next digit 9 is entered by depressing the key Kb9 which, as is now well understood, will cause the relay A9 of Reg. I to pick up and to close the energizing circuit for the operating magnet N which operates the locking bar M3 releasing all the movable contacts under this bar and permitting the movable contact in relay A9 to close. When the bar is released as the arm X moves past the end of the bar M3 the bar locks the contact in relay A9 in closed position and holds the sleeve in the moved position so that it is in position to operate the locking bar M4 when a numeral key is subsequently depressed. When the key is released the relay A9 and the operating magnet N will be released as before. The new circuit prepared from j1 over the movable contact AA and the contact j5 over line j10' causes the relay TR3 in Fig. 8 to pick up and to connect the line j8'' to the line j15'' which is connected across the relay Aa to the line k4 which in turn is connected to all of the movable contacts under the locking bar M3 in Reg. I so that the first transmission circuit from Reg. II will be continued over a closed contact under the locking bar M3 of Reg. I in case no other digits are entered.
- V—When the key Kb9 is depressed to enter the last 9 of the number 4699 the relay A9 will be picked up as before causing the operating

magnet N to pick up and operate the locking bar M4. As the bar M4 is moved forwardly all the movable contacts under this bar will be released permitting the movable contact in relay A9 to close. As the bar returns it locks the movable contact under this bar in relay A9 in closed position and prevents return of the sleeve U so that the sleeve U is in position to enter a subsequent digit under the bar M5. The movable contact AA connects line j1 to j6 connected across relay Aa to j11 (j11', Fig. 8), which causes energization of the reversing relay TR4. This connects j8'' to j16'', etc. As the last digit of the number has been entered in Reg. I no further movement of the sleeve U will be necessary. Upon release of the key Kb9 the relay A9 and the operating magnet N will deenergize.

20 Condition of Reg. I

In Reg. I a contact is locked under bar M1 in relay A4, under bar M2 in relay A6, and under bars M3 and M4 in relay A9. The movable contact member AA in Reg. I (Figs. 5 and 7) is now in contact with the fixed contact j6 connected to line j6 of the cable j3-j7. The line j6 is connected across an operated contact of relay Aa, Fig. 6, to line j11 of cable j8-j12 which on Fig. 7 is connected across the connection box XB to line j11' of the cable j8'-j12' which on Fig. 8 is the energizing lead for the reversing relay TR4. The relay TR4 is picked up and connects the line j8'' which is energized from the units position in Reg. II to line j16'' of the cable j13''-j17'' which on Fig. 7 extends through the connection box XX to line j16 of cable j13-j17 and across line j21 of cable j18-j22, across an operated contact of relay Aa to line k5 of the cable k2 to k6 which enters Reg. I and as shown in Fig. 5 is connected to the movable contacts under locking bar M4 associated with the relays of this register. This circuit is extended across the locked contact in relay A9 to line k16 of the cable k8-k17 but this circuit is not activated as the Reg. II is not under current at this time.

The reversing relays TR1 to TR5 which, as stated, are successively energized as the contact member AA moves successively into contact with corresponding contacts j3 to j7, are immediately deenergized as the contact AA moves off the corresponding contacts j3 to j7. The last relay TR1 to TR5 energized during the entry of a number will remain energized as long as the current is on and the contact AA remains in its moved position.

60 Transmission from Reg. I to Reg. II

Transmission from Reg. I to Reg. II is preferably performed under control of the key RR, Fig. 7, which controls the mechanism so that the amount in Reg. I will be

added to zero regardless of the amount that may be in Reg. II, but if it were known that there was no amount in Reg. II then the transmission might be made under control of the RP key which is the regular adding key. ⁷⁰

The condition of the machine, after entry of the number 4699, is as follows:

The relay Aa, Fig. 6, is energized and the circuits described in paragraphs 1b, 1c, 1d, 1e are prepared and the circuit described in paragraph 1a is completed over the movable contact AA and line j6, Reg. I, and over the coil of relay TR4, Fig. 8, so that the lines j8''-j12'' are connected to the lines j13'' to j17'' in such a manner that line j8'' is connected to line j16'' and j12'' is connected to line j7. In Reg. I contacts under bars M1 and M2 are locked in relays A4 and A6 and contacts under bars M3 and M4 in relay A9 are locked so that various transmission circuits are prepared over these contacts. ⁸⁰

VI—Depression of the transmission key RR closes a circuit from plus over the contact bar TT to line h, over the coil of the transmission relay Bh which picks up and closes or prepares the following circuits:

It connects lines j2-j6 coming from Reg. II, Fig. 7, to the lines j8-j12 (j8''-j12'' in Fig. 8). It connects lines k8-k17 from Reg. I to lines j23-j32 leading to the adding mechanism in Figs. 9a and 9. It connects the line h to the holding line g2. It connects plus to the lines g1, j1, c1 and i1 of the secondary register, Reg. II. ⁹⁵

(1) The plus on line g1 continues over the contact UU, Fig. 5 to line gj, over the coil of the no-transfer relay CT, Fig. 9a, to minus to energize this relay and deenergize the transfer relay DT if necessary. ¹⁰⁰

(2) Deenergization of relay DT disconnects c3 from c4 of the operating magnet N of Reg. II to prevent operation of magnet N as this change is being made. ¹⁰⁵

(3) The plus on g1 after closing of the contacts UU, VV, during the operation of the ratchet mechanism, continues to supply current to the line g2 which is connected over an operated contact in the relay Bh to the line h to hold the relay Bh energized during the whole operation of transmission after the key RR is released and until the contacts UU, VV are opened upon return of the sleeve U. ¹¹⁰

(4) The plus on i1, Fig. 7, continues across a pair of normally closed contacts in relay El to line i2 which in Fig. 5 is connected across a normally closed contact in relay Fc to the line i3 connected to k37, Fig. 7, which in Fig. 9 extends over the coil of adding relay Bk0 to the minus line. The relay Bk0 picks up and connects line c11 to c12. ¹²⁰

(5) The plus on c1 continues across the contact members DA, EA to line c10 connected over the normally closed contact of relay Sj to line c11 which is connected in the adding relay Bk0, Fig. 9, to line c12 which ¹³⁰

energizes the relay F_c , Fig. 5. As this relay picks up it breaks the connection between $i2$ and $i3$ but the relay $Bk0$ will be held up by its holding circuit from the line $c11$. After the relay F_c is picked up line $c1$ is connected to line $c7$, line $k6$ is connected to line $k38$, and the lines $k8-k17$ are disconnected from the lines $k18-k27$ for purposes later referred to. Relay El remains deenergized so that the adding mechanism in Fig. 9 will not be controlled from any locked contacts in Reg. II.

(6) The current on $c11$ continues over a closed contact in relay $Bk0$ to the energizing lead of this relay to maintain it energized after the F_c relay breaks the connection between $i2$ and $i3$.

(7) The plus over line $j1$ of Reg. II, Figs. 7 and 5, continues over line $j2$ in the cable $j2-j6$ across an operated contact of relay Bh to line $j8$ of the cable $j8-j12$ across the connection box XX to line $j8''$ of the cable $j8''-j12''$, Fig. 8, across a closed contact in relay $TR4$, Fig. 8, to line $j16''$ of cable $j13''-j17''$ which, on Fig. 7, is shown as connected across the connection box XX to cable $j13-j17$ connected across the connection box YY and the normal closed contacts of relay Ep to the cable $j18-j22$ so that the circuit on line $j16''$ continues on line $j21$ across the relay Aa , Fig. 5, to line $k5$ of the cable $k2$ to $k6$ which continues over the closed contact in relay $A9$ of Reg. I under bar $M4$ to $k16$ of the cable $k8-k17$, Figs. 5 and 7, which is connected across an operated contact of relay Bh to line $j31$ of the cable $j23-j32$ which is extended across a normal closed contact of relay RT and the connection box ZZ to Fig. 9a in which line $j31$ is connected across the no-transfer relay CT , across the normal closed contact of relay Dn to line $j31$, Fig. 9, which in the energized relay $Bk0$ is connected to line $j41$ of the cable $j33-j42$ which extends across a normal closed contact of relay Dc , Fig. 5, to line $j51$ of the cable $j43-j52$ to the coil of the relay $A9$, Reg. II.

The relays $A9$ and F_c are energized simultaneously immediately after $Bk0$ is energized.

(8) In relay $A9$, line $c7$ which in energized relay F_c is connected to line $c1$, is connected to the energizing lead for the relay $A9$ constituting a holding circuit for this relay.

(9) The line $c7$ is connected to the line $c8$ in relay $A9$ which line $c8$ is connected to the energizing lead $c9$ of the relay Dc so that the relay Dc picks up and disconnects the lines $j33-j42$ from lines $j43-j52$ immediately after the relay $A9$ is picked up.

(10) The line $c2$ which is connected to the line $c1$ in energized relay F_c is connected in relay $A9$ to the line $c3$ which is connected across the connection box PP to the energizing lead $c4$ of the operating magnet N whereupon the operating magnet picks up and moves the ratchet bar S to the right, Fig. 5.

The magnet N picks up at the same time as relay Dc picks up.

(11) As the ratchet bar S moves it breaks the connection between $g1$ and gj so that if addition were performed the transfer relay DT , Fig. 9a, could be energized.

(12) Movement of the ratchet S connects line $g1$ to line $g2$ which, as stated before, is connected across an operated contact of relay Bh to the energizing lead h for this relay so that this relay will remain energized until the sleeve U has returned to its home position after the transmission operation has been completed.

(13) As the ratchet bar S moves, it connects the line $c1$ to the line $c7$ so that the holding circuit for the relay $A9$ and the relay Dc is independent of the connection between lines $c1$ and $c7$ over the relay F_c .

(14) As the ratchet bar S approaches its right hand position it disconnects $c10$ from $c1$ which simultaneously deenergizes the adding relay $Bk0$, Fig. 9, and the relay F_c , Fig. 5. As the relay F_c deenergizes it disconnects the line $c2$ from the line $c1$ causing deenergization of the operating magnet N . The relay F_c also connects the lines $i2$ and $i3$ which causes the relay $Bk0$ to pick up as at the beginning of the operation. As the ratchet bar S starts its return movement it connects the line $c10$ to $c1$ which establishes a holding circuit for the relay $Bk0$ which was energized as the lines $i2$ and $i3$ were connected. As before, the relay $Bk0$ connects lines $c11$ and $c12$ to cause the relay F_c to pick up.

(15) When the ratchet bar S returns to its home position the switch member IA is disconnected from JA which disconnects the line $c7$ from the line $c1$ causing the relays $A9$ and Dc to release simultaneously, relay Dc again connecting the transmission circuits $j33-j42$ to $j43-j52$ to permit a second transmission circuit to be made to the relays in Reg. II.

(16) As the ratchet S moved to the right it moved the locking bar $M1$ downwardly, Fig. 1, which released any contacts that were locked under this bar and permitted the contact in relay $A9$ under this bar to be closed under the energization of this relay. As the arm X , Fig. 1, moved past the end Z of the bar $M1$ the bar $M1$ was returned by its spring FF to lock the contact in relay $A9$ in closed position and to prevent the return of the sleeve U as the ratchet S was returned upon deenergization of the operating magnet N . As the ratchet bar S moved to the left its second tooth moved past the arm T , Fig. 1, so that for a subsequent operation of the operating magnet N the bar $M2$ will be operated.

The condition of the machine is as follows: A contact in relay $A9$ of Reg. II under bar $M1$ has been locked in closed position and any digit previously entered under bar $M1$

has been cleared out of the register. The sleeve U is now in position to operate the second locking bar M2 and the movable contact AA is now in contact with the fixed contact connected to the line j3 of the cable j2-j6. The transmission of the second number was started immediately upon deenergization of the relays A9 and Dc, Fig. 5, which were simultaneously deenergized as the bar S disconnected the line c7 from the line c1.

All the main circuits activated during transmission of the 9 in the tens position, which is locked under the bar M3 in Reg. I, will be traced out briefly. The circuits involved in transmitting the 9 in the tens position will be exactly the same as those involved in transmitting the 9 in the units position, except that the main transmission circuit will be changed and will be as follows:

From plus the circuit continues over a closed contact in the relay Bh to the line j1, over the contact AA, Reg. II, to the line j3 in the cable j2-j6 which is extended across a closed contact in relay Bh to line j9, Fig. 7, to line j9'', Figs. 7 and 8, across a closed contact in relay TR4 to line j15'' which is connected to line j20, Fig. 7, and across the relay Aa, Fig. 6, to line k4 which is connected across a closed contact in relay A9, Reg. I, under bar M3 to line k16, Figs. 5 and 7, and across the relay Bh to line j31 passing over a closed contact in relay RT and connection box ZZ to Fig. 9a in which it is connected across the relays CT and Dn to line j31, Fig. 9, which is connected across the relay Bk0 to line j41 connected in Fig. 5 across the relay Dc to line j51 and over the coil of relay A9 (Reg. II) to minus.

As the relay A9 picks up it closes various circuits, one of which is the energizing circuit for the relay Dc to disconnect the lines j33-j42 from the lines j43-j52. It closes a holding circuit for itself and it closes the energizing circuit for the operating magnet N. The ratchet bar S is operated and the bar M2 is moved to release the contacts under this bar and to permit the contact in relay A9 to close. As the bar returns it locks this contact in closed position and prevents the return of the sleeve U so that the sleeve will be in position to operate the bar M3 when the next transmission takes place.

The various circuits referred to as controlled by the bar S during transmission of the units digit 9 are repeated and thereafter transmission is started over the line j4, Reg. II, Fig. 5, to transmit the number in the hundreds position which is represented by the locked contact in relay A6 under the bar of M2, Reg. I.

The transmission circuit for transmitting the number 6 in the hundreds position under bar M2, Reg. I, is as follows:

From plus over the closed contact in relay Bh, over line j1, contact AA, Reg. II, line j4,

Figs. 5 and 7, over a contact in relay Bh to line j10, over connection box XX to line j10'', across a contact in relay TR4, Fig. 8, to line j14'' across connection box XX, Fig. 7, to line j14 across connection box YY and closed contacts of relay Ep to line j19 which, in Fig. 6, is connected across a contact in relay Aa to line k3 connected across the contact under bar M2 in relay A6 of Reg. I to line k13, Fig. 5, which is connected across relay Bh to line j28, connected across a normal contact relay RT to line j28 which is connected across the connection box ZZ to line j28. Line j28, Fig. 9a, is connected across the no-transfer relay CT and the relay Dn to Fig. 9 in which it is connected across the energized relay Bk0 to line j38 which, in Fig. 5, is connected across the relay Dc to line j48 which is the energizing lead for the relay A6, Reg. II, so that this relay will pick up.

The operation of the various relays in Fig. 5 will be the same as in the case of the transmission of the other digits and after the operation of the operating magnet N a contact will be locked under bar M3 in relay A6, Reg. II, and the sleeve U will be in position to operate the locking bar M4 and to control the transmission over line j5 to transmit the units digit from Reg. I to Reg. II.

As transmission is started over the contact AA in its fourth position the plus over line j1 continues over the contact AA, Reg. II, line j5, Figs. 5 and 7, over a contact in relay Bh to line j11 connected through the connection box XX to line j11'', across a contact in relay TR4, Fig. 8, to line j13'', across the connection box XX, Fig. 7, to line j13, across the connection box YY and closed contact of relay Ep to line j18 which in Fig. 6 is connected across a contact in relay Aa to line k2 which is connected to the contacts under bar M1 of Reg. I and across a closed contact in relay A4, Fig. 5, to line k11 which is connected across a contact in relay Bh, Fig. 7, to line j26 connected across a normal contact in relay RT to line j26 connected across the connection box ZZ to line j26 in Fig. 9a, which is extended across the relays in this figure as before to Fig. 9 in which it is connected in relay Bk0 to line j36 which in Fig. 5 is connected across the relay Dc to line j46 which is the energizing lead for the relay A4 of the Reg. II.

The relay A4 picks up causing the energization of the relay Dc to disconnect the cable j33-j42 from j43-j52 and it also causes the operating magnet N to operate as before to cause a contact to be locked under bar M4 in relay A4 in Reg. II and to move the sleeve U into position to operate the bar M5.

The next transmission circuit over the contact AA, Fig. 5, Reg. II goes out over line j6, j12, j12'', and as before across the relay TR4,

Fig. 8, in which it is connected to the line $j7$ as no further transmissions are to be made from Reg. I. Line $j7$ in Fig. 7 causes the relay Uj to pick up which connects plus to line $O1$ directly across normal contact in relay Uk to line $O2$ connected across normal contact in relay $E7$ to line $O3$ which is connected to the line $j32$ which is the zero digit line in Figs. 9a and 9. The circuit is continued across the adding relay $Bk0$ to line $j42$ across the relay Dc , Fig. 5, to line $j52$ which is the energizing lead for the relay AO of Reg. II. After energization of the relay AO the operating magnet N will be energized and a contact under bar $M5$ in relay AO will be locked.

The contact XA now engages the contact to which line $k6$ is connected. As the relay Fc picked up, a circuit was completed from + across relay Ep , line $k1$, XA , line $k6$, across relay Fc , line $k38$, across relay $E7$, line $k39$, across relay Uj and line $k40$ to the coil of relay Uk . This relay picked up and applied + to the lines u and w causing the returning magnets of Reg. I and Reg. II to return the sleeves U after the zero contact under bar $M5$ was locked. If fewer than five digits are transmitted, and zeros are registered in Reg. II, or a number comprising fewer, equal, or but one more digit than the number of digits of the number transmitted, is registered in Reg. II, the circuit for relay Uk will be made as above and the sleeves will be returned to home positions after the sleeve of Reg. II has made one more step than the number of digits in the number transmitted. As the sleeve U of Reg. II is returned it disconnects the holding circuit $g2$ from the line $g1$ thus causing the relay Bh to deenergize.

The machine is now in the same condition that it was when the number "4699" was entered except that this number is now locked in Reg. II, the lowest denominational number 9 being locked under the bar $M1$ in Reg. II. In Reg. I the various contacts remain locked but certain of these will be released as the next number is entered.

VII—Entry of the number 5291 in Reg. I.

When the keys 5, 2, 9, 1 are depressed successively contacts will be closed respectively under the bar $M1$ in relay $A5$, under the bar $M2$ in relay $A2$, under bar $M3$ in relay $A9$, and under bar $M4$ in relay $A1$. As the numeral 1 is entered under bar $M4$, and as this number contains four digits the same as the first number entered, the relay $TR4$, Fig. 8, will be energized and switch the lines $j8''$ — $j12''$ from Reg. II to the lines $j13''$ — $j17''$ which lead to the contacts under the bars $M1$ — $M4$ of Reg. I, and to line $j7$, in the same manner in which these connections were made when the first number was entered.

VIII—As the number in Reg. I is to be added to the number in Reg. II transmission

is controlled by the adding key RP , Fig. 7. In the first transmission under control of the key RR the amount in Reg. I was added to zero and Reg. II was cleared of the amount it contained. In adding the amounts together the circuits successively extended through the Reg. I must be switched in Fig. 9 under control of corresponding circuits simultaneously prepared over contacts in Reg. II. For this reason it is necessary to break the connection between the lines $i1$ and $i2$ so as to prevent the relay $Bk0$ in Fig. 9 from being energized unless such energization is effected under control of the locked contact in relay AO of Reg. II. In order that such control may be effected lines $k18$ to $k27$, Fig. 5, which are connected across the relay Fc to the lines $k8$ — $k17$ must be connected to the lines $k28$ — $k37$, Fig. 9. This is effected by energizing the relay $E7$, Fig. 7, which also disconnects the lines $i1$ — $i2$.

(1) When the key RP is depressed a circuit is made from plus across the contact bar TT , over the line l , over the coil relay $E7$ to minus, Fig. 7. The relay $E7$ picks up and connects the lines $k18$ — $k27$ to the lines $k28$ — $k37$, disconnects the lines $i1$ from $i2$ and connects the line l to the line h which is the energizing lead for the relay Bh . Both of these relays will be held up from the holding line $g2$ which is connected to plus across the contacts UU , VV in Reg. II, Fig. 5, after the sleeve U moves out of home position.

(2) The following circuits are established under the control of the relays $E7$ and Bh . A circuit extends from plus across a contact in relay Ep to line $k1$, Fig. 7, as before, across the movable contact XA , Reg. II, across the locked contact under bar $M1$ in relay $A9$ of Reg. II to the line $k16$ which is connected across the relay Fc , Fig. 5, to line $k26$ which in Fig. 7 is connected across an operated contact in relay $E7$ to line $k36$ which in Fig. 9 is extended to the coil of the adding relay $Bk9$.

The operation of the machine during transmission under control of the key RP is the same as under control of the key RR except that in Fig. 9 the relays that will be energized will correspond to the locked contacts under the locking bars in Reg. II, whereas in transmission under control of the RR key these relays will not energize under control of the contacts in Reg. II, but the relay $Bk0$ is energized under control of a separate circuit established over the lines $i1$ and $i2$, Fig. 7.

(3) A circuit is established from plus across a contact in relay Bh to line $g1$ across contacts UU , VV , Fig. 5, to line gj to the coil of the no-transfer relay CT , Fig. 9a, to minus as during transmission. This relay deenergizes the transfer relay DT in case this relay was energized.

- (4) The first transmission circuit extends from plus across a contact of the relay B_h , over line j_1 , movable contact AA , Reg. II, over line j_2 , over a contact in relay B_h to line j_8 , Fig. 7, through the connection box XX to line j_8'' , across a contact in relay TR_4 to line j_6'' , Fig. 8, through the connection box XX , Fig. 7, line j_6 , across the connection box YY and the closed contacts of relay Ep to line j_21 , across closed contact of relay Aa , Fig. 6, to line k_5 , across the locked contact under bar M_4 in relay A_1 (Reg. I) to line k_8 , Figs. 5 and 7, across the relay B_h to line j_23 , across a normal contact of relay RT to line j_23 , across the connection box ZZ , across the relay CT , Fig. 9a, to line j_23 , Fig. 9, in which it is connected over a closed contact in relay B_k9 to line j_42 which, in Fig. 5, is connected across the relay D_c to line j_52 which is the energizing lead for the relay AO . The various circuits are established as during transmission and after an operation of the operating magnet N the contact in relay AO under bar M_1 of Reg. II will be locked in closed position and the sleeve U will be in position to operate the bar M_2 when the next transmission is made.
- (4a) The line j_23 in the relay B_k9 , Fig. 9, is also connected to line j_96 which extends through the cable j_88-j_96 to Reg. II across a closed contact in relay AO to line j_97 which on Fig. 9a is extended across a normal closed contact in relay D_n to the line jj which is the energizing lead for the transfer relay DT .
- (4b) As this relay picks up it deenergizes the relay CT and connects the lines j_23-j_32 coming from Reg. I to the lines j_23-j_32 leading to Fig. 9 in such a manner that the value of the transmission line will be increased by one. The relay DT closes the holding circuit with the plus line and the construction is such that the relay DT will remain energized until the relay CT is energized.
- (5) The second transmission circuit which controls the addition of "9" under the locking bar M_3 , Reg. I, to "9" under locking bar M_2 , Reg. II, and also the addition of a unit of transfer is as follows: From plus across a contact in relay B_h over line j_1 , over contact AA , Reg. II, line j_3 , contact in relay B_h , line j_9 , connection box XX , line j_9'' , Fig. 7, across a contact in relay TR_4 to line j_15'' , Fig. 8, across connection box XX , Fig. 5, line j_15 , connection box YY and relay Ep to line j_20 , Fig. 7, across a contact in relay Aa , Fig. 6, to line k_4 , across a locked contact in relay A_9 , Reg. I, to the line k_16 , across a contact in relay B_h , Fig. 7, to line j_31 , across a contact in relay RT to line j_31 , through connection box ZZ to line j_31 , across the relay DT , Fig. 9a, to line j_32 which is connected across relay B_k9 , Fig. 9, to line j_41 connected across the relay D_c , Fig. 5, to line j_51 to the coil of relay A_9 , Reg. II.

The relay B_k9 was energized under the control of a locked contact in relay A_9 , Reg. II, by the following circuit: +— Ep — k_1 — XA (Reg. II)— A_9 — k_16 — F_c (Fig. 5)— j_26 — El — k_36 —* B_k9 —(-) The operating magnet N is energized and releases the contact under locking bar M_2 in relay A_9 of Reg. II and as the bar returns this contact is again locked closed under energization of relay A_9 .

(5a) Line j_32 in relay B_k9 is not connected to any of the transfer or no-transfer lines. No connection between this line and the line j_97 over the relay A_9 is necessary as the transfer relay DT remains energized until it is deenergized by one of the no-transfer lines j_78-j_86 , as will be described later.

IX—When the next digits "2" in Reg. I and "6" in Reg. II are added together the circuits made may be indicated as follows:

(9a) +— Ep — k_1 — XA (Reg. II)— A_6 — k_13 — F_c — k_23 — El (Fig. 7)— k_33 (Fig. 9)—* B_k6 —(-)

(9b) +— B_h — j_1 — AA (Reg. II)— BB — j_4 — B_h — j_10 (Fig. 7)— XX — j_10'' — TR_4 — j_14'' — XX — j_14 — YY — j_19 (Fig. 7)— Aa (Fig. 6)— k_3 — A_2 (Reg. I)— k_9 — B_h — j_24 — RT — j_24 — ZZ — j_24 — DT (Fig. 9a)— j_25 — B_k6 (Fig. 9)— j_41 — D_c — j_51 (Fig. 5)—* A_9 (Reg. II)—(-). As the relay A_9 picks up it closes the circuit for the operating magnet N which operates the locking bar M_3 to lock the contact in relay A_9 closed.

(9b-1) Line j_25 in B_k6 is connected to the line j_86 of the cable j_78-j_86 to Reg. II, Fig. 5, which in relay A_9 at the time it was energized was connected to line j_87 which in Fig. 9a is connected across a closed contact in relay D_n to the line jj which is the energizing lead for the no-transfer relay CT . As the relay CT picks up it connects the lines j_23-j_32 entering this figure respectively to the lines j_23-j_32 leaving this figure. It also causes the deenergization of the transfer relay DT and establishes a holding circuit for itself.

X—The next transmission is for the purpose of adding "5" under bar M_1 in Reg. I to "4" under bar M_4 in Reg. II. The transmission circuit is as follows:

(10a) +— Ep — k_1 — XA (Reg. II)— A_4 — k_11 — F_c — k_21 (Fig. 5)— El (Fig. 7)— k_31 —* B_k4 (Fig. 9)—(-)

(10b) +— B_h — j_1 — AA (Reg. II)— BB — j_5 — j_11 (Fig. 7)— XX — j_11'' — TR_4 — j_13'' — XX — j_13 — YY — j_18 — Aa — k_2 — A_5 (Reg. I)— k_12 — Ph — j_27 — RT — j_27 — ZZ — j_27 — CT (Fig. 9a)— j_27 — B_k4 — j_41 (Fig. 9)— D_c — j_51 (Fig. 5)—* A_9 (Reg. II)—(-)

As the relay A_9 picks up it causes energization of the operating magnet N and the locking of the contact under bar M_4 in relay A_9 and moves the sleeve U in position to operate the next bar M_5 . As the last addition of "4" and "5" does not require a transfer operation the next transmitting circuit will cause the

release relays O of both registers to operate and to restore the ratchet mechanisms to home position.

(a) The circuit over contact AA is continued over line j_6 which enters Fig. 8 on line $j_{12''}$ in which it is connected by a contact in relay TR4 to line j_7 which, in Fig. 7, is shown as the energizing lead for relay U_j .

(b) Plus continues across the contact of the relay U_j to the line O1 which in relay El is connected to line O4 which in Fig. 9a when the relay CT is energized, as when no transfers are necessary, is connected to line O5 which on Fig. 7 is extended across a contact in relay U_j to line k_{40} which is the energizing lead for the relay U_k . With the relay U_k picked up plus is connected across the contacts in relay U_k to the lines w and v which are the energizing leads for the restoring magnets O in Reg. II and Reg. I respectively.

The condition of the machine is as follows:

In Reg. I the ratchet mechanism is restored so that another number may be entered. In Reg. II the ratchet mechanism is restored and contacts are locked in relay A9 under bars M4, M3 and M2 and a contact is locked in the relay AO under the bar M1.

XI—The number 25 is entered in Reg. I as follows:

(a) Key Kb2 is depressed and the following circuits are made:

(a1) $+\text{NN}-\text{Kb2}-\text{K2}-\text{Aa}-j_{44}-*\text{A2}$
(Reg. I)—(—)

(a1—a) $+\text{Aa}-c_2-\text{A2}-c_3-\text{PP}-c_4$
(Fig. 5)—*N (Reg. I)—(—)

The operating magnet N moves the locking bar M1 and causes a contact to be locked under this bar in relay A2. When the key is released the relay A2 and operating magnet N will deenergize and the sleeve U will be in position to operate the locking bar M2.

(b) Depression of the key Kb5 causes the following circuits to be made:

(b1) $+\text{NN}-\text{Kb5}-\text{K5}-\text{Aa}-j_{47}-*\text{A5}$
(Reg. I)—(—)

(b1—a) $+\text{Aa}-c_2-\text{A5}-c_3-\text{PP}-c_4$
(Fig. 5)—*N (Reg. I)—(—)

The operating magnet N moves the locking bar M2 and upon return of the locking bar a contact in relay A5 will be locked in closed position and the contact member AA will be over the second of the BB contacts which is connected to the line j_4 . A circuit from j_1 continues over the contact AA and line j_4 to line $j_{9'}$, Fig. 8, causing the reversing relay TR2 to pick up and to connect line $j_{8''}$ to the line $j_{14''}$ and line $j_{9''}$ to line $j_{13''}$.

A contact under bar M1 in relay A2 and a contact under bar M2 in relay A5 in Reg. I are now locked in closed position and the reversing relay TR2, Fig. 8, is energized. The number 25 is now set up in Reg. I.

XII—The following circuit was made as

the digit 5 of number 25 was entered in Reg. I and the circuit is as follows:

$+\text{Aa}-j_1-\text{AA}$ (Reg. I)—BB— j_4-
 $\text{Aa}-j_9-\text{XB}-j_{9'}-*\text{TR2}-(-)$

Key RP, Fig. 7, is depressed and closes the following circuit:

(1) $+\text{TT}-l-*\text{El}-(-)$
(1a) $+\text{El}-h-*\text{Bh}-(-)$

(1b) $+\text{Ep}-k_1-\text{XA}$ (Fig. 5, Reg. II)—
 $*\text{AO}-k_{17a}-\text{Fc}-k_{17}-\text{Fc}-k_{27}-\text{El}-k_{37}-$

$*\text{Bk0}$ (Fig. 9)—(—)

(1a—1) $+\text{Bh}-g_1-\text{UU}, \text{VV}$ (Fig. 5)—
 $g_j-*\text{CT}$ (Fig. 9a)—(—)

(1a—2) $+\text{Bh}-j_1-\text{AA}$ (Reg. II)—
 $\text{BB}-j_2-\text{Bh}-j_8-\text{XX}-j_{8''}-\text{TR2}-j_{14''}$

(Fig. 8)—XX— $j_{14}-\text{YY}-j_{19}$ (Fig. 7)—
 $\text{Aa}-k_3$ (Fig. 6)—A5 (Reg. I)— k_{12} (Figs.

5 and 7)— $\text{Bh}-j_{27}-\text{RT}-j_{27}-\text{ZZ}-j_{27}-$
 CT (Fig. 9a)— $j_{27}-\text{Bk0}-j_{37}-\text{Dc}$ (Fig.

5)— $j_{47}-*\text{A5}$ (Reg. II)—(—)

(1a—2a) $+\text{Bh}-c_1-c_7-\text{Fc}-c_2-\text{A5}$

c3—PP—c4—*N (Reg. II)—(—)

This causes locking of the first contact in relay A5, Reg. II, i. e. the first digit of the sum $(9990+25)=5$ is locked in Reg. II.

The following circuit is made as circuit 1a—2 is made:

$+\text{Bh} \dots j_{27}-\text{Bk0}-j_{82}-\text{A5}$
(Reg. II)— $j_{87}-\text{Dn}$ (Fig. 9a)— $g_j-*\text{CT}$

(—)

After the ratchet mechanism in Reg. II has made one step the circuits are as follows:

(1) $+\text{Ep}-k_1-\text{XA}$ (Reg. II)—A9—
 $k_{16}-\text{Fc}$ (Fig. 5)— $k_{26}-\text{El}-k_{36}-*\text{Bk9}-$

(—)

(2) $+\text{Bh}-j_1-\text{AA}$ (Reg. II)—BB—
 $j_3-\text{Bh}-j_9-\text{XX}-j_{9''}-\text{TR2}-j_{13''}-\text{XX}-$

$j_{13}-\text{YY}-j_{18}-\text{Aa}-k_2-\text{A2}$ (Reg. I)—
 $k_9-\text{Bh}-j_{24}-\text{RT}-j_{24}-\text{ZZ}-j_{24}-\text{CT}-$

$j_{24}-\text{Bk9}-j_{33}-\text{Dc}-j_{43}-*\text{A1}-(-)$ (Reg. II)

(2a) $+\text{Bh}-c_1-c_7-\text{Fc}-c_2-\text{A1}-c_3$

PP—c4—*N (Reg. II)—(—)

This causes locking of the second contact in A1, Reg. II, so that two digits of the sum $(9990+25)=15$ are now locked in Reg. II.

The following circuit is made as circuit (2) is made: from $+\text{Bh} \dots j_{24}-$

$\text{Bk9}-j_{88}$ (Fig. 9)—A1 (Reg. II)— $j_{97}-$
 $\text{Dn}-j_j-*\text{DT}$ (Fig. 9a)—(—)

The circuits for adding the units of transfer to 9 are as follows:

(1) $+\text{Ep}-k_1-\text{XA}$ (Reg. II)—A9—
 $k_{16}-\text{Fc}-k_{26}-\text{El}-k_{36}-*\text{Bk9}-(-)$

(2) $+\text{Bh}-j_1-\text{AA}$ (Reg. II)—BB—
 $j_4-\text{Bh}-j_{10}-\text{XX}-j_{10''}-\text{TR2}$ (Fig. 8)—

$j_7-\text{JM}$ (Fig. 7)—*Uj—(—)

(2a) $+\text{Uj}-o_1-\text{El}-o_4-\text{DT}$ (Fig. 9a)

$j_{23}-\text{Bk9}-j_{42}-\text{Dc}$ (Reg. II)— $j_{52}-*\text{AO}$

(Reg. II)—(—)

(2a—1) $+\text{Bh}-c_1-c_7-\text{Fc}-c_2-\text{AO}$

c3—PP—c4—*N (Reg. II)—(—)

This causes locking of the third contact in relay AO, Reg. II, so that three digits of the sum $(9990+25)=015$ are now locked in Reg.

II. The transfer relay DT remains energized.

Sleeve U (Reg. II) has made three steps after which the circuits will be as follows:

- 8 (1) +—Ep—k1—XA (Reg. II)—A9—k16—Fc—k26—El—k36—*Bk9—(—)
 —j42—Do—j52—*A0 (Reg. II)—(—)
 (2a) +—Bh—c1—c7—Fc—c2—AO—c3—
 10 PP—c4—*N (Reg. II)—(—)

This causes locking of the fourth contact in relay AO, Reg. II, that is, the four digits of the sum $(9990+25)=0015$, have been locked in Reg. II.

12 Sleeve U has made four steps of movement after which the circuits will be as follows:

- (1) +—Ep—k1—XA (Reg. II)—AO—k17e—Fc—k17—Fc—k27—El—k37—*Bk0 (Fig. 9)—(—)
 20 (1a) +—Uj—o1—El—o4—DT—j23 (Fig. 9a)—Bk0 (Fig. 9)—j33—Dc (Fig. 5)—j43—*A1 (Reg. II)—(—)
 (1a—1) +—Bh—c1—c7—Fc—c2—A1—c3—PP—c4—*N (Reg. II)—(—)

25 This causes locking of the fifth contact in A1, Reg. II. The sum $(9990+25)=(4699+5291+25)=10015$ is now locked in Reg. II.

As the transmission circuit (1a) was made the line j23, Fig. 9, was continued across the relay Bk0 to line j78 in cable j78—j86 which in Reg. II, as shown in Fig. 5, is connected across a contact in relay A1 to the line j87 which in Fig. 9a is connected across a closed contact of relay Dn to the line gj which is the energizing lead for the relay CT. As this relay picks up it deenergizes the transfer relay DT and connects the line o4 to the line o5.

As the contact member AA is in the fifth position in Reg. II it extends the current

40 from line j1 to line j7 which is the energizing lead for the relay Uj, Fig. 7. This relay however is already picked up and has connected plus to line o1 which is connected across the energized relay El to line o4 which

45 is now connected across the no-transfer relay CT, Fig. 9, to the line o5 which is connected across the relay Uj to the line k40 which is the energizing lead for the relay Uk. In the relay Uk the plus is connected to the lines w,

50 v which are the energizing leads for the release relays O of the Regs. I and II. As the relays O operate, the sleeves U in Reg. I and Reg. II are rotated and returned to home position. The sleeve U of Reg. II opens the holding circuit g2 for the relay Bh thus deenergizing Reg. II.

The sum of the numbers assumed in this problem are now locked under the locking bars of Reg. II in which the contacts are 60 locked as follows:

A contact is locked in relay A5 under bar M1, contact in relay A1 under bar M2, contacts in relay A0 under bars M3 and M4 and a contact in relay A1 under bar M5 which 65 represent the number 10015.

Printing

The numbers that are entered into the primary register (Reg. I) may be printed as they are entered into the register or, preferably, as they are transferred from the primary register (Reg. I) to the secondary register (Reg. II). As shown in Figs. 7 and 15 the transmission lines j23—j32 on which current transmissions indicate the digit values of the number in Reg. I are branched off across contacts in relay JS, Fig. 7, JS₄, Fig. 15, to lines T0 to T9 which are the energizing leads for printing magnets MT which when energized operate their respective type bars TB. Immediately after the digit has been printed a circuit is made from plus, Fig. 15, across the line mt across a normal make and break contact in relay JS₄ to line rl which is the energizing lead for the magnet RL. The magnet picks up and through the pawl Rp moves the platen tb to the right, Fig. 15, so that the digits of the number, as they are transmitted in ascending denominational order, will be printed from right to left.

If it is desired to print the numbers as they are being entered in Reg. I the key JS₄, Fig. 15, will be depressed which energizes the relay JS₄ which connects the line mt to the line lr and the lines k0—k9 to the lines T0—T9. As the digits of the number are entered by means of the keys K_{b1}, K_{b0}, Fig. 15, the corresponding printing magnets MT are energized which applies plus to the line lr which energizes the magnet LR and causes the platen tb to move from right to left so that the digits will be printed in the proper order.

Total printing

The total, 10015, which is locked in Reg. II 105 may be printed and the total may be re-registered in Reg. II. This operation is performed by depressing the key RE, Fig. 7. Circuits are established as follows:

(1) From plus across the contact bar TT to line p across the coil of relay Ep to minus. The relay Ep picks up and establishes the following circuits and conditions:

(a) A circuit is established from plus across a contact in relay Ep to line h across the coil of the relay Bh which establishes the same circuits as it did during transmission. It connects plus to the line il, causes energization of the relay Bk0 in the adding mechanism, and after an operation of the ratchet mechanism it connects plus to the holding line g2. This relay operates exactly as it does during transmission.

(b) Relay Ep closes its holding circuit 125 from line g2 across a contact in relay Z₂ to line g3 which is connected across the relay Ep to the energizing lead of this relay.

(c) Relay Ep also connects the lines j13—j17 to lines j63—j67 and disconnects the lines 130

13—j17 from the lines j18—j22 which, in Fig. 7, during transmission extend to Reg. I. (d) Relay Ep also connects lines k8''—k17'' from Reg. II to the transmission lines j23—j32.

14 (e) It also applies plus across an operated contact to line q which in Fig. 8 is extended across the coil of relay Rq to minus.

15 (e-1) Relay Rq connects the lines j8''—j12'' from Reg. II respectively to lines j13''—j17''.

16 (f) Relay Ep interrupts the circuit in line a and de-energizes the relay Aa thus disconnecting Reg. I from the keyboard.

17 (g) Relay Ep also disconnects the line k1 leading to the contact member XA, from plus.

18 With the relays in Figs. 5, 7 and 8 controlled as stated above and with the mechanism in Fig. 15 in normal position the first transmission circuit will be as follows:

19 (2) From plus, Fig. 7, current will continue across a closed contact in relay Bh to line j1, to contact XA, Reg. II, to line j2, Fig. 5, of cable j2—j6, Figs. 5 and 7, across a contact in relay Bh to line j8, through connection box XX to line j8'', across a contact in relay Rq, Fig. 8, to line j13'', across the connection box XX to line j13, through connection box YY, across an operated contact of relay Ep to line j63 of the cable j63—j67, across a normal contact in relay Sj to line k2'' of cable k2''—k6'' which leads to the movable contacts under bar M1, Reg. II, and across a closed contact in relay A5 to line k12'' of cable k8''—k17'' which is connected across a contact in relay Ep to line j27 which is connected across the relay RT to line j27, Fig. 15, which causes the printing magnet MT operating the type bar TB carrying the "5" digit type to pick up and print the numeral 5 after which the spacing magnet RL is operated to move the platen tb to the right. The units digit 5 has now been printed and the platen is in a position to receive the imprint of the tens digit to the left of the imprint of the digit 5.

20 The line j27, Fig. 7, extends across the connection box ZZ and across Figs. 9a and 9b of which the relay Bk0 is energized to the line j37 which is connected across the relay Dc, Fig. 5, to the energizing lead j47 of the relay A5, Reg. II, to cause this relay to pick up and to lock the contact of this relay under bar M1 in closed position. This part of the operation is the same as any ordinary transmission. The sleeve U is now in position to operate the second bar M2 and to cause a transmission impulse to go out over the line j3.

21 (3) The next transmission circuit is as follows: From plus across a contact in relay Bh, to line j1, across contact XA, Reg. II, Fig. 5, to line j3 in cable j2—j6, across a contact in relay Bh to line j9, across connection

box XX to line j9'', across a contact in relay Rq, Fig. 8, to line j14'', across connection box XX, Fig. 7, to line j14, across connection box YY, across a contact in relay Ep to line j64, across a contact in relay Sj to line k3'' 70

71 which in Fig. 5 is in the cable k2—k6 and which extends to the movable contacts under the second locking bar M2 of which the contact in relay A1 is closed so that the circuit is extended over line k8 of cable k8—k17, 75

76 which is k8'' in Fig. 7, across contact in relay Ep to line j23 which is extended across a normal closed contact in relay RT after which it is branched to the printing mechanism and to the adding mechanism as in the case of the transmission of the units digit number.

77 This causes the printing magnet MT, Fig. 15, which operates the one digit type bar to pick up and to print the digit one and to cause the carriage to move to the right. A branch of the circuit extending across the adding mechanism continues on line j23 across the connection box ZZ across

78 Figs. 9a and 9b of which the relay Bk0 is energized and continues on line j33 across the relay Dc, Fig. 5, to the line j43 which is the energizing lead for the relay A1.

79 As this relay picks up it closes various contacts to control the energization of the operating magnet N, etc. as in ordinary transmission

80 operations. This causes the bar M2 to release the contact in the relay A1 of this register and to lock the contact in relay A1 again closed. After this operation the line

81 j1 will be connected to the line j4 over the contact AA so that the next transmission will take place over the line j4.

82 (4) The units digit 5 and tens digit 1 have now been printed and have been reentered in Reg. II. The transmission circuits made

83 during the printing and re-registering of the hundreds, thousands and tens of thousands digits will be indicated as follows:

84 For the 0 digit in the hundreds position the transmission circuit will be as follows:

85 *Printing circuit*

86 +—Bh—j1—XA—j4—Bh—j10 — XX—
j10''—Rq—j15''—XX—j15—YY—Ep—
j65—Sj—k4''—AO (Reg. II)—k17c—Fc—
k17''—Ep—j32—RT—j32—JSi (Fig. 15)—
T0—*MT0—(-) 115

87 *Re-registering circuit*

88 +—Bh . . . (as above) . . . —j32—ZZ—
Bk0—j42—Dc—j52—*A0 to minus.

89 The above described circuits cause the 0 in the hundreds position to be printed and to be re-registered under bar M3 in Reg. II.

90 At the completion of this operation the sleeve U, Reg. II, will be in position to operate the bar M4 and the contact member XA connects the line j1 to line j5.

91 For the 0 digit in the thousands position the transmission circuit will be as follows:

Printing circuit

25   +—Bh—j1—XA—j5—Bh—j11—XX—
         j11''—Rq—j16''—XX—j16—YY—Ep—
         j66—Sj—k5''—AO—k17c—Fc—k17''—Ep
         —j32—RT—j32—JSi—T0—*MT0—(-)

Re-registering circuit

26   +—Bh . . . (as above) . . . —j32—ZZ—
         Bk0—j42—Dc—j52—*A0 to minus.

27   This causes the zero in the thousands position to be printed and the carriage to be shifted to the right and a contact to be locked under bar M4 in relay A0. It also connects the line j1 to line j6.

28   The transmission circuit for printing the tens of thousands digit one and re-registering it will be as follows:

Printing circuit

29   +—Bh—j1—XA—j6—Bh—j12—XX—
         j12''—Rq—j17''—XX—j17—YY—Ep—
         j67—Sj—k6''—A1 (Reg. II)—k8''—Ep—
         j23—RT—j23—JSi—T1—*MT1—(-)

Re-registering circuit

30   +—Bh . . . (as above) . . . —j23—ZZ—
         Bk0—j33—Dc—j43—*A1—(-)

These circuits cause the numeral 1 to be printed in the fifth position and to be re-registered and to remain registered under the locking bar M5 in Reg. II.

31   As this transmission takes place over k6'' the circuit is branched off across a contact in relay Fc to line k38 which in Fig. 7 is extended across a contact in relay El to line k39

32   which is extended across a contact in relay Ep to line k40 the energizing lead for the relay Uk. This relay picks up and connects plus to the lines w and v of which w is the energizing lead for the releasing magnet O of Reg. II. The ratchet mechanism in Reg. II is returned to its normal home position and as it reaches home position it causes de-energization of the relay Bh and various other relays that were energized following a depression of the key RE.

33   The number that was in Reg. II has been printed and re-registered in this register. If it is desired to add other numbers to it they may be set up in Reg. I and transmitted to Reg. II under control of the adding key RP. If it is desired to clear the register of this number this may be done by transmitting the first number of the next series to be added or 34 subtracted under control of transmitting key RR. As the transmission takes place the number registered in Reg. II will be cleared out as described previously under transmission.

35   *Discarding digits of lowest denominational value and increasing the digit of lowest denominational value remaining by one.*

36   In this operation it is assumed that the 37 number 6192 is locked in Reg. II.

When the key FE, Fig. 8, is depressed it connects plus across the contact bar TT and over the lead line fe and the coil of relay Fq to minus and the relay picks up and establishes circuits as follows:

(a) It connects the line j8'' which is the units transmission line from Reg. II, to lines j14'', line j101 and line j103.

(b) It also connects the holding line g2 to the lead line fe.

(c) It interrupts the line q which is the energizing lead for the relay Rq.

(d) It connects plus to line X1.

(e) It connects plus to line qj which, as shown in Fig. 7, causes the relay JS to pick up and disconnect the printing circuits T0 to T9 from the transmission circuits j23—j32.

(f) It also connects plus to the line p which, as shown in Fig. 7, is the energizing lead for the relay Ep which establishes the following circuits:

(f-1) The holding line g3 is connected to the energizing lead p.

(f-2) It connects plus to the line q which, however, is interrupted in the relay Fq.

(f-3) It disconnects the line k1 from plus.

(f-4) It connects the lines k8''—k17'' coming from the locking contacts of Reg. II to the transmission lines j23—j32.

(f-5) It disconnects the lines j13—j17 from j18—j22 and connects them to lines j63—j67.

(f-6) It interrupts the line a to deenergize the relay Aa, Fig. 6.

(f-7) It connects the line k39 to k40.

(f-8) It connects plus to the line h which is the energizing lead for the transmission relay Bh, Fig. 7.

As Bh picks up it establishes the same circuits as it does under ordinary transmission.

The circuit across relay Bh to line i1 causes the relay Bk0, Fig. 9, to pick up.

The circuit across Bh on j1 continues over line j2 to line j8'', Fig. 8, across the relay Fq to line j14'' through connection box XX, YY, Fig. 7, across the relay Ep to line j64 across normal closed contacts of relay Sj to line k8'' which is connected to the movable contact members under bar M2 of Reg. II, Fig. 5. As a contact in the relay A9 under this bar is locked the circuit continues over line k16 of the cable k8—k17 which cable is indicated as k8''—k17'', Fig. 7, across the contacts of relay Ep to line j31 across the normal closed contacts of relay RT across the connection box ZZ to Figs. 9a and 9 where it continues across a closed contact in relay Bk0 to line j41 which in Fig. 5 is connected to line j51 which is the energizing lead for the relay A9 of Reg. II. As the relay A9 picks up it connects the line j102 to the line j101 which latter line is connected to line j8'' in relay Fq. The impulse on line j102 energizes the relay RT, Fig. 7, which

has the effect of increasing the digit value of the lines $j23-j32$ by one. The relay RT is held over its contact by the current on line $j8''$ extending over a contact in relay Fq to the lead line for the relay RT.

* (d) As the transmission described above is made the current on the line X1 continued over a closed contact in relay Sj to the line $x2$ and caused the relay Xx to pick up and 10 interrupt the line $c3$ which prevented energization of the operating magnet N as the relay A9 in Reg. II was energized.

* (d-1) As the relay Xx picked up it closed a holding circuit with the line Xx which is connected to plus by the key FE and it also prepared a holding circuit to line $g2$. It also connected plus to line SS which is connected across the coil of relay Sj to minus. The relay Sj picked up and interrupted the 20 circuit from $c10$ to $c11$ temporarily and closed it again. The interruption of the circuit $c10$ to $c11$ has the same effect as the interruption of the circuit $c1-c10$, Fig. 5, which is effected as the ratchet bar S moves to the 25 right, that is, it causes deenergization of the energized multiple contact relay.

The relay Sj completes the circuit $c3$ so that in a subsequent transmission the ratchet operating magnet N of Reg. II may be energized.

Relay Sj interrupts the circuit $g1$ which deenergizes the relay JS and connects the transmission circuit $j23-j32$ to the printing lines T0-T9.

Relay Sj disconnects the lines $x2$ from the line X1 but the relay Xx will be held up over the line Sx .

Relay Sj also connects the lines $j63-j67$ to the lines $k2''-k6''$ in such a manner that 40 the transmission circuit on the lines $j63-j67$ will be advanced one denominational order.

The circuit on line $j8''$, Fig. 8, which comes from plus across the line $j1$ and continues over line $j14''$ . . . to line $j64$ is now 45 connected across the relay Sj to the line $k4''$ which is connected to all the movable contacts in Reg. II under locking bar M3. Contact in relay A1 is closed and the circuit continues to line $k8$ designated $k8''$ in Fig. 7 across the relay Ep to line $j23$ which is now 50 connected in relay RT to $j24$.

The current on $j24$ continues to the coil of the printing magnet MT operating the type bar TB corresponding to the digit "2". The current on 55 $j24$ continues across the connection box ZZ to Figs. 9a and 9 and across the energized relay Bk0 to line $j34$ which, in Fig. 5, is shown as extending across the relay Dc to the line $j44$ which is the energizing lead for the 60 relay A2 of Reg. II.

As the relay A2 picks up, and as the line $c3$ is now connected across the relay Sj, Fig. 7, the contacts connecting the line $c2$ to the line $c3$ in relay A2 will complete the energizing 65 circuit for the ratchet operating magnet

N causing this mechanism to operate and to free the locked contact under locking bar M1 and to lock the contact under this bar in relay A2 in closed position as in operations of transmission or total recording.

As the contact member AA moves away from the contact $j2$ it breaks the holding circuit for the relay RT causing this relay to deenergize.

As the contact member AA moves into contact with line $j3$ the circuit from plus extends across the line $j3$ to the line $j9$, Fig. 8, across the relay Fq to the line $j15''$ which extends across the relay Ep to the line $j65$ which now is connected in relay Sj to the line $k5''$ which is connected to the movable contacts under locking bar M4, Fig. 5, where it continues over closed contact in relay A6 to line $k13$ which continues on the line $k13''$, Fig. 7, across the relay Ep to line $j28$ which, when the relay RT is deenergized, is connected to the printing magnet MT associated with the type bar TB carrying the type 6. The current in $j28$ also continues across the connection box ZZ through Figures 9a and 9 and across closed contact in relay Bk0 to line $j38$ across the relay Dc, Fig. 5, to $j48$ which is the energizing lead for the relay A6. Relay A6 picks up and causes an operation of the operating magnet N and the locking of a contact under bar M2 in relay A6 as well understood.

As there is no significant amount locked under the bar M5 in Reg. II the contact under this bar in relay A0 is closed and immediately after the transmission of the numeral 6 an impulse will go out over line $k6$ across the closed contact in relay Fc to line $k38$ which in Fig. 7 is connected across the relay Ez to line $k39$ which is connected across the relay Ep to line $k40$. This causes the relay Uk to pick up and to connect plus to the lines w, v of which w is the energizing lead for the restoring magnet O associated with Reg. II.

Energization of the restoring magnet O causes the sleeve U to return and as it returns it disconnects the holding circuit $g2$ and causes the various relays, Fq, Xx , Sj and Bh, to deenergize and return the machine into normal condition.

The number 6192 by this operation has been changed to 62 and 62 has been printed. The digits 92 of the number 6192 have been discarded and one has been added to the lowest 120 denominational digit retained.

Subtraction of the smaller number from the larger number

Assume the example 64-29 is equal to 35. 125

I.—The number 64 is entered in the Reg. I, Figs. 7 and 5, by depressing the key Kb6 which will cause a contact to be locked in relay A6 under bar M1 and the ratchet mechanism to be moved in position to actuate the 130

bar M2. The key Kb4 is depressed which causes a contact to be locked in relay A4 under bar M2. With the ratchet mechanism in this position the reversing relay TR2 will be energized to connect line j8'' to the line j14''.

II—This number 64 is transferred from Reg. I to Reg. II after depression of the transmission key RR, as is well understood from the example under addition.

III—The number 29 is entered in Reg. I by depressing the keys Kb2 and Kb9. After this operation a contact will be locked in relay A2 under bar M1, a contact will be locked in

15 relay A9 under bar M2 and the reversing relay TR2 will pick up and connect line j8'' to line j14''.

IV—The number 29 will now be transmitted to Reg. II under control of the key

20 RO, Fig. 7, which in addition to the control effected by the key RP also applies plus to line n which, in Fig. 9a, extends over the coils of relays Cn and Dn to minus.

Dn disconnects the line j97 (connected in 25 Reg. II to j88—j96, the transfer lines from Fig. 9) from jj the energizing lead for the transfer relay Dt, and disconnects the line j87 (connected in Reg. II to j78—j86, the no-transfer lines from Fig. 9) from the energizing lead gj of the no-transfer relay CT.

Cn connects the line j97 to the energizing lead gj of the no-transfer relay CT and also connects the line j87 to the energizing lead jj of the transfer relay DT.

25 Energization of the relays Dn and Cn will cause the relays DT and CT to be substituted for each other with respect to the lines j88—j96 and j78—j86 so that no transfers are made in the cases corresponding in which 1 transfers are made in addition, and vice versa.

Relay Dn disconnects the lines j23, j24, j25 . . . j32 entering the relay Dn from the cable j23, j24, j25 . . . j32 entering Fig. 9, and the relay Cn connects lines j23, j24, j25 . . . j32 entering this relay to lines j31, j30, j29, etc. of complementary value.

The relay CT is energized over gj, Fig. 5, as before described at the time the relay Bk picks up.

10 The same circuits are made as in addition and the successive transmission circuits over contacts in Reg. I have the same value as in addition, their value being changed however in Fig. 9a before they enter Fig. 9.

As the number 64 is in Reg. II and 29 in Reg. I the plus on the line j1, Fig. 7, continues on line j8'', Fig. 8, across the relay TR2 which was energized under control of the ratchet contact in Reg. I, to line j14''

10 across the locked contact in relay A9 under bar M2, Reg. I, to line j31, Fig. 9a, across the relay Cn to line j23 across a contact in the adding relay Bk4 which was pulled up as in addition under control of the locked contact

65 in relay A4 under bar M1 of Reg. II, to line

j37 across the relay Dc, Fig. 5, to j47, to the coil of relay A5 which picks up and causes energization of the operating magnet N and the locking of the contact in relay A5 under bar M1 as in addition. After movement of the ratchet mechanism has effected locking of this contact in relay A5 the sleeve U will be in position to operate the locking bar M2.

In Fig. 9 the circuit on j23 in relay Bk4 branches off to line j82 which in the relay A5 75 of Reg. II is connected to line j87 which, as stated above, is connected in relay Cn to line jj the energizing lead of the transfer relay DT, which is the relay used for borrowing purposes in subtraction.

The relay DT picks up and, as explained before, causes the relay CT to be deenergized. This relay DT connects the lines j23, j24 . . . j32 to j24, j25 . . . j23 which are connected in relay Cn to lines j30, j29 . . . j31 so that line j23 "1" entering Fig. 9a is connected to j30 "8" entering Fig. 9, j24 "2" to j29 "7", j25 "3" to j28 "6", j26 "4" to j27 "5", j27 "5" to j28 "4", j28 "6" to j25 "3", j29 "7" to j24 "2", j30 "8" to j23 "1", j31 "9" to j32 "0" and j32 "0" to j31 "9".

In the next transmission the relay Bk6, Fig. 9, is energized under control of the locked contact in relay A6, Reg. II, and the transmission on line j1, over reversing relay TR2 to line j13'', over a locked contact in relay A2 under bar M1, Reg. I, over line j24 "2" to Fig. 9a where it is switched to line j29 "7" entering Fig. 9. The circuit continues over the relay Bk6 which is picked up under control of the locked contact in relay A6, Reg. II, under bar M2, to line j35 "3" across the relay Dc, Fig. 5, to line j45 to relay A3, Reg. II, causing a contact in relay A3 under bar M2, Reg. II, to be locked.

In relay Bk6 line j29 is branched off over line j90, over a contact in relay A3, Reg. II, to line j97 which continues over a contact in relay Cn to the energizing lead in relay CT. As the relay CT is energized and as the subtraction process is completed the relay Uk, Fig. 7, will be energized by the same circuit as in addition and the releasing magnet Q will be operated and the ratchet mechanism returned. As the sleeve U returns it de-energizes the whole system. The result, 35, is now locked in Reg. II the 3 being locked under bar M2 in relay A3 and the 5 being locked under bar M1 in relay A5.

The result of the computation may now be 120 printed under control of the key RE as described before in connection with the printing of the sum of numbers registered in Reg. II.

Subtraction of a larger number from a 125 smaller number

It may be necessary in certain computations to subtract a large number from a small number in which the small number may be 130

the result of calculations or may be the first entry of a series of debits and credits. If we assume the problem 29-64, and also assume that the register (Reg. II) is clear, the 5 operation is as follows:

I.—The number 29 is entered in Reg. I by depressing the keys Kb2 and Kb9.

II.—The number 29 is transferred to Reg. II by depressing the key RR.

10 III.—Number 64 is entered in Reg. I by depressing the keys Kb6 and Kb4.

IV.—The key RO is now depressed to energize the addition relay El Fig. 7, and to energize the subtraction relays Cn and Dn, 15 Fig. 9a.

The transmission circuit for subtracting four from nine will be as follows:

From plus across the relay Bh to line j' . . . j8'' . . . j14'' . . . across the contact

20 in relay A4 under bar M2 of Reg. I and . . . to line j26 "4" entering Fig. 9a across the relay CT across Cn to line j28 "6" across the relay Bk9 which is energized under the control of the contact in relay A9 under bar M1,

25 Reg. II. From here the circuit continues on the line j37 across the relay Dc, Fig. 5, to line j47 and over the coil of relay A5, Reg. II, causing the operating magnet N to operate and to lock the contact in relay A5 under bar M1, Reg. II.

30 From the line j28 in relay Bk9 the circuit branches to line j92 across a contact in relay A5 to line j97 across the relay Cn to the energizing lead for the relay CT which picks up and locks as under addition.

The next circuit to subtract 6 from 2 will be as follows:

Plus . . . j1 . . . j9'' to j13'' across a contact in relay A6, Reg. I, under bar M2 . . .

40 j28 "6" across the relay CT and relay Cn to line j26 "4" across the relay Bk2 under control of the locked contact under bar M2 of Reg. II. The circuit continues to the line j38 across the relay Dc to line j48 which is the energizing 45 lead for the relay A6, Reg. II. This causes a contact in relay A6 under bar M2, Reg. II, to be locked.

The current on j26 in relay Bk2 is branched to line j82 which is connected 50 across a contact in relay A6 to line j87 connected in relay Cn to the lead jj of the relay DT so that the transfer relay will be energized when the next transmission circuit is made.

55 The next transmission circuit over j1 goes to j10'' across the reversing relay TR2, Fig. 8, to the line j7 which causes the relay Uj, Fig. 7, to pick up. The relay Uj connects lines o5 and k39 to the line k40 which is the 60 energizing lead of the relay Uk which when energized applies plus to the line w which is the energizing lead for the releasing relay O of Reg. II.

The relay CT is deenergized whenever the 65 relay DT is energized so that the line o5 is

disconnected from the line o4 and a circuit for the line k40 is broken at this point.

The relay El is energized so that the circuit for k40 is broken at the connection between lines k38 and k39. The relay Uk will 70 therefore not be energized at this time.

In relay DT the line o4 is connected to the line j23. The current from plus across contact in the relay Uj to line o1 across relay El is continued on line o4 to line j23 "1" and 75 across the relay Cn to line j31 "9" across the relay Bk0 which is energized across the line k17, to line j41 across the relay Dc, Fig. 5, and line j51 to the coil of relay A9 causing a contact to be locked in relay A9, Reg. II under bar M3.

Plus on line j31 in relay Bk0 branches to the line j86 across a contact in relay A9 to line j87 and across the relay Cn to line jj 80 which is the energizing lead for the relay DT.

When the next transmission circuit is made the numeral 9 will be locked in relay A9 under bar M4 of Reg. II and the relay DT will be controlled to remain energized.

When the next transmission circuit takes place a digit will be locked in relay A9 under bar M5, Reg. II.

The number 99965 is now registered in 95 Reg. II and as the ratchet sleeve U is moved to lock the last 9 in Reg. II the contact member XA engages the fixed contact to which line k7 is connected. The circuit from plus across a normal closed contact in relay Ep to line k1 now continues over the contact XA, 100 line k7, Fig. 5, across a contact in relay DT across closed contact in relay Cn to the line Z1 which in Fig. 7 is connected across a normal closed contact in relay Ep to line Z2 105 connected across a normal closed contact of relay Yz to Z3 which is the energizing lead for relay Zz. As the relay Zz picks up it connects the line gj from Reg. II to the line n which is the energizing lead for the relays Cn and Dn and also connects gj to the line p which is the energizing lead for the relay Ep. The function of these circuits is to energize the relays Ep and the subtraction relays after the circuit from plus to gj has been made by 110 return of the ratchet mechanism in Reg. II.

As the relay Zz picks up it disconnects the line g3 from the holding line g2 which causes the relays Cn and Dn, Fig. 9a, to deenergize. As the relays deenergize the circuit on line k7 115 will be switched to line o5 which on Fig. 5 is connected across the relay Uj energized from j1 across contact AA and line j7, Fig. 5, to line k40 which is the energizing lead for relay Uk.

As this relay picks up it connects plus to line w which causes the release magnet O of Reg. II to cause the ratchet mechanism of this register to return to home position. As the sleeve U returns to its home position it connects the line g1 to gj which is 120 now connected across the relay Zz to the lines 125

130

n, p causing the subtraction relays *Cn* and *Dn* and the total recording relay *Ep* to pick up immediately.

As the relay *Ep* picks up it switches the line *z1* to the line *z4* to energize the relay *Ys* which opens the self-closing circuit for *Zs*.

The relay *Zs* deenergizes and connects the line *g3* to the holding line *g2*.

As relay *Ep* energizes it connects plus to the line *g* which, as shown in Fig. 8, causes the relay *Rq* to pick up.

The circuit from plus to line *j1* is now continued over *j8''* relay *Rq*, Fig. 8, line *j13''* across the relay *Ep* to line *j63* over line *k2''* 15 the locking contact of relay *A5*, Reg. II, under bar *M1* . . . *j27* "5", Fig. 9a, relay *CT*, relay *Cn* to *j27* "5" across *Bk0* to *j37* "5" across relay *Dc* line *j47* and over the coil of relay *A5* to minus. This causes a contact to be locked under bar *M1* in relay *A5* of Reg. II.

In the relay *Bk0* line *j27* is branched off to line *j82* across a contact in relay *A5* to line *j87* and across a contact in relay *Cn* to the 25 energizing lead for relay *DT*.

The next transmission circuit is from plus over line *j1*, *j9''*, *j14''* across the relay *Ep* to line *j64* to line *k3''* across a locking contact in relay *A6*, Reg. II, under bar *M2* . . . *j28* 30 "6" across the relays *DT* and *Cn* to *j25* "3" across the relay *Bk0* to *j35* across the relay *Dc* to *j45* to relay *A3*. This causes a contact to be closed in relay *A3* under bar *M2*.

In relay *Bk0* line *j25* is connected to the line *j81* which is connected across a contact in relay *A3* to line *j87* which is connected across contact in relay *Cn* to line *jj* which is the energizing lead for the relay *DT*.

The next transmission circuit continues 40 from *j1* to *j10''*, *j15''* across the relay *Ep* to *j65* to line *k4''* across the locked contact in relay *A9*, Reg. II, under bar *M3* to the line *k16* . . . line *j31* "9" across the relay *DT* to line *j32* "0" across the relay *Bk0* to line *j42* 45 and across the relay *Dc* to line *j52* which is the energizing lead for relay *A0*. The ratchet mechanism now operates and locks a contact under bar *M3* in relay *A0* in closed position.

50 This last circuit *j32* is not branched off to either of the cables *j78*—*j86* and *j88*—*j96*. Transfer relay *DT* will remain energized.

The next transmission circuit under control of the contact in relay *A9* under bar *M4* 55 will be the same as the one just described and will cause a contact to be locked under bar *M4* in relay *A0* of Reg. II.

The next transmission circuit will be exactly the same as the one just described and will cause a contact to be locked in relay *A0* under bar *M5*.

The amount now appearing in Reg. II is: 60 00035.

As the last 0 was locked in Reg. II the circuit on *k6''* continued across *Fc* to *k38* across

El to *k39* across *Ep* to *k40* which energizes *Uk* which applies + to *w* (and *v*) which causes magnet *O* to return sleeve *U* of Reg. II.

Printing the result

70

The result 35 which is now in Reg. II may be printed by depressing the key *RE* which controls the mechanism as described under total printing in addition.

Example in multiplication

75

The example $592 \times 74 = 43808$ is assumed. When switches are closed and keys depressed as indicated in the following, circuits will be made as set forth briefly.

I.—Close contact switch *O1* Reg. X (Fig. 6).

I. +—NN—O1—a-*Aa—(-)

II.—To enter 74 in Reg. X depress key *Kb7*, Reg. X (Fig. 6).

I. +—NN—K7—j49—*A7 (Reg. X)—(-)

2. +—Aa—c2—A7—c3—PP—c4—*N (Reg. X, Fig. 5)—(-)

This causes locking of the first contact (contact under bar *M1*), i. e. digit 7 has been entered in register X.

III.—Depression of the key *Kb4* causes the second contact (contact under bar *M2*) in *A4* in Reg. X to be locked in closed position.

Transmission of 74 from Reg. X to Reg. XI.

IV.—Depress key *RR* (Reg. XI, Fig. 10a).

1. +—TT—h—*Bh (Reg. XI)—(-)

2. +—Aa (Reg. X)—j1—AA (Reg. X)—BB—j4—Aa (Reg. X)—j9—j9'—*TR2 (Fig. 8)—(-)

3. +—Bh (Reg. XI)—j1—AA (Reg. XI)—BB—j2—Bh—j8—XX (Fig. 7)—

j8''—TR2—*j14''*—XX—*j14*—YY—*j19*—Aa (Reg. X)—*k3*—A4 (Reg. X)—*k11*—Bh—*j26*—RT—*j26*—Ci (*Bk0*)—*j36*—Dc (Reg. XI)—*j46*—*A4—(-)

4. +—Bh—c1—Fc—c2—A4—c3—c4—*N (Reg. XI)—(-)

This causes the first contact in *A4* Reg. XI to be locked in closed position.

The next circuit is as follows:

3¹. +—Bh (Reg. X)—j1—AA (Reg. XI)—BB—j3—Bh—j9—XX (Fig. 7)—

j9''—TR2—*j13''*—XX—*j13*—YY—*j18*—Aa (Reg. X)—*k2*—A7 (Reg. X)—*k14*—Bh—*j29*—RT—*j29*—Ci (*Bk0*)—*j39*—Dc (Reg. XI)—*j49*—*A7 (Reg. XI)—(-)

4¹. +—Bh—c1—Fc—c2—A7—c3—c4—*N (Reg. XI)—(-)

This causes the second contact in *A7* Reg. XI to be locked in closed position. The number 74 is now registered in Reg. XI.

Entry of the number 592 in Reg. X.

II¹.—Press key *Kb5*, Reg. X (Fig. 6).

I. +—NN—K5—j47—*A5 (Reg. X)—(-)

130

2. $+\text{--Aa--c2--A5--c3--PP--c4--*N}$
(Reg. X) $\text{--}(-)$

This causes locking of the first contact in A5 register X, i. e. the digit 5 has been entered in Reg. X.

III¹ and IV¹.—The digits 9 and 2 are entered by depressing keys Bk9 and Bk2 which causes locking of the second contact in A9 and the third contact in A2. The number 10 592 has now been entered in Reg. X.

IV¹.—1. $+\text{--Aa}$ (Reg. X) j1--AA--BB (Reg. X) $\text{j4--Aa--j10--j10'--*TR3}$ (Fig. 8) $\text{--}(-)$

The multiplication process is started by 15 depressing key KM.

V.—Depress key KM (Fig. 11).

1. $+\text{--KM--dm--*MD}$ (Fig. 11) $\text{--}(-)$

2. $+\text{--MD--h--*Bh}$ (Reg. XII) $\text{--}(-)$

3. $+\text{--Bh}$ (Reg. XII) $\text{--}g1--g7$ (Fig. 5) $\text{--}(-)$

20 MD (Fig. 11) j37--*Bk0 (Reg. XI) $\text{--}(-)$

4. $+\text{--k1--XA}$ (Reg. XI) --A4--k11--

MD (Fig. 11) j48--*MK4 (Fig. 12) $\text{--}(-)$

5. $+\text{--Bh}$ (Reg. XII) $\text{--i1--El--i2--Fc--}$

j3--k37 (Fig. 10a) --*Bk0 (Reg. XII) $\text{--}(-)$

25 VI.—Multiplying 592×4 .

1. $+\text{--Bh}$ (Reg. XIII) $\text{j1--AA--BB--j2--Bh--j8'--TR3}$ (Fig. 8) $\text{j15'--j15--Ep--j20--Aa}$ (Reg. X) $\text{--k4--locked contact of A2--k9--Fig. 11, MD--k2--*A2}$ (Reg. X).

30 Two impulses go out over the contacts in A2 (Reg. X), viz. a units and tens impulse. The units impulse goes over the locked contact in A2 (Reg. X) --k9--MD (Fig. 11) $\text{--}(-)$

35 j105--MK4--j30 (Fig. 12) --CT (Reg. XI) $\text{--j30--Bk0--j40--MD--j30--CT}$ (Reg. XII) $\text{--j30--Bk0--j40--Dc}$ (Reg. XII) --j50--*A8 (Reg. XII) $\text{--}(-)$

40 2. $+\text{--Bh--c1--Fc--c2--A8--c3--c4--*N}$ (Reg. XII) $\text{--}(-)$

This causes the first contact in A8 Reg. XII to be locked, i. e. the units digit of the product of 4×2 has been entered in register XII.

45 3. The tens impulse circuit is as follows: $+\text{--MD}$ (Fig. 11) --j87-- free but closed contact of A2 (Reg. X) --j79--Fcm (Fig. 11) --j115--MK4 (Fig. 12) --k37--*Bk0 (Reg. XI) $\text{--}(-)$ This represents the tens of 4×2 .

50 1¹. After the sleeve U in register XII has made one step, a circuit is made as follows: $+\text{--Bh--j1--AA--BB}$ (Reg. XII) $\text{--j3--Bh--j9'--TR3--j14'--j14--Ep--j19--Aa}$ (Reg. X) --k3--*A9 . Two impulses go out

55 from Reg. X. The first is over A9 (Reg. X) --k16--MD (Fig. 11) --j112--MK4 (Fig. 12) --j28--CT (Reg. XI) --j28--Bk0 (Reg. XII) $\text{--j28--j38--MD--j28--CT}$ (Reg. XII) $\text{--j28--Bk0--j38--Dc}$ (Reg. XII) --j48--*A6 (Reg. XII) $\text{--}(-)$

60 2¹. $+\text{--Bh--c1--Fc--c2--A6--c3--c4--*N}$ (Reg. XII) $\text{--}(-)$

This causes locking of the second contact 65 in A6 register XII. This is the sum of the tens of 4×2 and the units of 4×9 .

3¹. The second or tens impulse from Reg. X goes as follows: $+\text{--MD--j87}$ (Fig. 11) --A9 (Reg. X) --j86--Fcm--j122 (Fig. 11) --MK4 (Fig. 12) --k30--*Bk3 (Reg. XI) $\text{--}(-)$

This represents the tens of 4×9 .

1¹¹. After sleeve U has made its second step, the circuits are as follows: $+\text{--Bh}$ (Reg. XII) $\text{--j1--AA--BB--j4--Bh--j10'--TR3--j13'--j13--Ep--j18--Aa}$ (Reg. X) $\text{--k2--}75$

$*A5$ (Reg. X). Two impulses go out over A5 (Reg. X). The first is: A5 (Reg. X) --k12--MD (Fig. 11) --j108--MK4--j32 (Fig. 12) --CT (Reg. XI) --j32--Bk3 (Reg. XI) --j35--MD (Fig. 11) --j25--CT (Reg. XII) --j25--Bk0 (Reg. XII) $\text{--j35--Dc--j45--*A3}$ (Reg. XII) $\text{--}(-)$

2¹¹. $+\text{--Bh--c1--Fc--c2--A3--c3--c4--*N}$ (Reg. XII) $\text{--}(-)$

This causes the third contact in A3 register XII to be locked in closed position. This is the sum of the tens of 4×9 and the units of 4×5 .

3¹¹. The second impulse from Reg. X over A5 is as follows: $+\text{--MD--j87}$ (Fig. 11) --A5 (Reg. X) $\text{--j82--j118--MK4--k29--*Bk2}$ (Reg. XI) $\text{--}(-)$ This represents the tens of 4×5 .

1¹¹¹. After the sleeve U, Reg. XII, has made three steps of movement a circuit is made as follows: $+\text{--Bh--j1--AA--BB--j5}$ (Reg. XII) $\text{--Bh--j11'--TR3--j7}$ (Fig. 8) --MD (Fig. 11) $\text{--j32--CT--j32--Bk2}$ (Reg. XI) $\text{--j34--MD--j24--CT}$ (Reg. XII) $\text{--j24--Bk0--j34--DC--j44--*A2}$ (Reg. XII) $\text{--}(-)$

2¹¹¹. $+\text{--Bh--c1--Fc--c2--A2--c3--c4--*N}$ (Reg. XII) $\text{--}(-)$

This causes locking of the fourth contact in A2, register XII, i. e. the number $2368 = 105$ 592×4 is now locked in register XII.

4. Sleeve U, Reg. XII, has made four steps of movement. $+\text{--Bh--j1--AA--BB--j6--Bh--j12'--TR3--j124--MD}$ (Fig. 11) $\text{--j124--*Ua--}110$

5. $+\text{--Ep--k1--XA}$ (Reg. XII) --k6--Fc--k38--El (Fig. 7) $\text{--k39--Ua--k40--*Uc--}(-)$

6. $+\text{--Uc--c4--*N}$ (Reg. XI) $\text{--}(-)$

7. $+\text{--Uc--j52--*A0}$ (Reg. X) $\text{--}(-)$

7a. $+\text{--Uc--c4--*N}$ (Reg. X) $\text{--}(-)$

8. $+\text{--Uc--w--*O}$ (Reg. XII) $\text{--}(-)$

9. $+\text{--Uc--l--*El}$ (Reg. XII) $\text{--}(-)$

VII.—1. After sleeve U Reg. XII has been returned, $+\text{--Ep--k1--XA}$ (Reg. XII) $\text{--A8--k15--Fc--k25--El--k35--*Bk8}$ (Reg. XII) $\text{--}(-)$

2. $+\text{--Ep--k1--XA}$ (Reg. XI) $\text{--A7--j14--MD--k51--*MK7}$ (Fig. 12) $\text{--}(-)$

(See VI., 6)

3. $+\text{--Aa--j1--AA--BB}$ (Reg. X) $\text{--j5--Aa--j11--j11'--*TR4--}(-)$ (See VI., 7a)

4. $+\text{--Bh}$ (Reg. XII) --j1--g7--MD (Fig. 11) --j37--*Bk0 (Reg. XI) $\text{--}(-)$

VI¹.—The ratchet mechanism of Reg. XII is shifted to the second position before multiplication with 7 is initiated.

1. +—Bh (Reg. XII)—j1—AA—BB—
*j2—Bh—j8''—TR4 (Fig. 8)—j16''—j16—
Ep—j21—Aa (Reg. X)—k5—*A0 (Reg. X).
Two impulses go out from register X. The
first impulse goes over: A0 (Reg. X)—
k17d—Fc—k17—MD (Fig. 11)—j113—
10 MK7—j32—CT (Reg. XI)—j32—Bk0—
j42—MD—j32—CT (Reg. XII)—j32—
Bk8—j40—Dc—j50—*A8 (Reg. XII)—
(-)
2. +—Bh—c1—Fc—c2—A8—c3—c4—*N
(Reg. XII)—(-)

This causes locking of the first contact in A8 (Reg. XII) and shifting of the ratchet mechanism into position to operate the second bar.

- 20 3. The second impulse from Reg. X, is as follows: +—MD (Fig. 11)—j87—A0
(Reg. X)—j96—Fcm—j123—MK7—k37—
*Bk0 (Reg. XI)—(-)

- 25 4. Sleeve U, Reg. XII, has made one step
of movement: +—Ep—k1—XA (Reg.
XII)—A6—k13—Fc—k23—El—k33—*Bk6
(Reg. XII)—(-)

This represents the digit 6 of the product
2368 of 592×4 .

- 30 1¹. Multiplying 592×7 and adding the
product to that of 592×4 . The first op-
eration multiplies 7×2 and adds the units
of this product to 6 in Reg. XII. +—
Bh (Reg. XII)—j1—AA—BB—j3—Bh

- 35 j9''—TR4 (Fig. 8)—j15''—j15—Ep—j20—
Aa (Reg. X)—k4—*A2 (Reg. X). Two im-
pulses go out from Reg. X. The first im-
pulse goes out over: A2 (Reg. X)—k9—MD
(Fig. 11)—j105—MK7—j26—CT (Reg.

- 40 XI)—j26—Bk0—j36—MD—j26—CT (Reg.
XII)—j26—Bk6—j42—Dc (Reg. XII)—
j52—*A0 (Reg. XII)—(-)

- 2¹. +—Bh—c1—Fc—c2—A0—c3—c4—
*N (Reg. XII)—(-)

- 45 This causes locking of the second contact
in A0 Reg. XII, i. e. the second digit of the
product is now in register XII. This is the
sum of 6 and the units of the product 7×2 .

- 50 3¹. The second impulse from Reg. X goes
as follows: +—MD (Fig. 11)—j87—A2
(Reg. X)—j79—Fcm—j115—MK7—k28—
*Bk1 (Reg. XI)—(-)

This represents the tens of the product of
 7×2 .

- 55 5. From Bk6 register XII goes a sec-
ond impulse. (See VI¹, 1¹¹). j26—Bk6
(Reg. XII)—j96—A0—(Reg. XII)—j97—
Dn—j1—*DT (Reg. XII)—(-)

- 60 This will cause the units of transfer neces-
sitated by adding 4 to 6 to be added when
the next product digit is entered in Reg.
XII.

- 65 4¹. After sleeve U Reg. XII has made an-
other step: +—Ep—k1—XA (Reg. XII)—

A3—k10—Fc—k20—El—k30—*Bk3 (Reg.
XII)—(-)

- 1¹¹. +—Bh (Reg. XII)—j1—AA—BB—
j4—Bh—j10''—TR4—j14—Ep—j19—Aa
(Reg. X)—k3—*A9 (Reg. X). Two im-
pulses go over A9 Reg. X. The first is: A9
(Reg. X)—k16—MD (Fig. 1)—j112—
MK7—j25 (Fig. 12)—CT (Reg. XI)—
j25—Bk1—j36—MD (Fig. 11)—j26—DT
(Reg. XII)—j27—Bk3—j40—Dc—j50—*A8
(Reg. XII)—(-)
2¹¹. +—Bh—c1—Fc—c2—A8—c3—c4—
*N (Reg. XII)—(-)

This causes locking of the third contact
in A8 Reg. XII, i. e. the third digit of the
product is now in register XII. This is the
sum of the units of the product of 7×9 +
the tens of the product of 7×2 + the units of
transfer and the digit 3 in Reg. XII. The
number 808 is now registered in Reg. XII.

- 3¹¹. The second impulse from Register X
is: +—MD—j87—A9 (Reg. X)—j86—
Fcm—j122—MK7—k33—*Bk6 (Reg. XI)—
(-)

This represents the tens of the product
of 7×9 .

6. From Bk3 Reg. XII a second impulse
goes out. (See VI¹, 1¹¹). j27—Bk3—j85—
A8 (Reg. XII)—j87—Dn (Fig. 9a)—gj—
*CT (Reg. XII)—(-)

No transfer is necessitated by the last sum
entered in Reg. XII.

- 4¹¹. After sleeve U Reg. XII has made an-
other step, the circuit is as follows: +—Ep—
k1—XA (Reg. XII)—A2—k9—Fc—k19—
El—k29—*Bk2 (Reg. XII)—(-)

This represents the 2 in the fourth position
in Reg. XII.

- 1¹¹¹. +—Bh (Reg. XII)—j1—AA—BB—
j5—Bh—j11''—TR4—j13''—j13—Ep—j18—
Aa (Reg. X)—k2—*A5 (Reg. X). From
Reg. X two impulses go out. The first im-
pulse goes as follows: A5 (Reg. X)—k12—
MD—j109—MK7—j27—CT (Reg. XI)—
j27—Bk6—j33—MD—j23—CT (Reg. XII)—
j23—Bk2—j35—Dc—j45—*A3 (Reg.
XII)—(-)

- 2¹¹¹. +—Bh—c1—Fc—c2—A3—c3—c4—
*N (Reg. XII)—(-)

This causes locking of the fourth contact
in A3 Reg. XII, i. e. the fourth digit of the
product is now in register XII. This repre-
sents the sum of the units of the product
of $7 \times 5 + 6$ the tens of the product of 7×9 ,
+ 2 in Reg. XII. The number 3808 is now in
Reg. XII.

- 3¹¹¹. The second impulse from Reg. X goes
as follows: +—MD—j87—A5 (Reg. X)—
j82—Fcm—j118—MK7—k30—*Bk3 (Reg.
XI)—(-)

This represents the tens of the product of
 7×5 .

From Bk6 Reg. XI there is a second im-
pulse (See VI¹, 1¹¹¹).

6¹. +—Bk6 (Reg. XI)—j88—A1 (Reg. XI)—j97—Dn—jj—*DT (Reg. XI)—(—)

4¹¹¹. Sleeve U Reg. XII has made another or fourth step and the circuit is as follows: 5 +—Ep—k1—XA (Reg. XII)—A0—k17e—Fc—k27—El—k37—*Bk0 (Reg. XII)—(—)

This represents the O in the fifth position in Reg. XII.

1⁴. +—Bh—j1—AA—BB—j6 (Reg. XII) 10 +—Bh—j12''—TR4—j7 (Fig. 8)—MD (Fig. 11)—j32—DT (Reg. XI)—j23—Bk3—j36—MD—j26—CT (Reg. XII)—j26—Bk0—j36—Dc—j46—*A4 (Reg. XII)—(—)

This represents the sum of the tens of 15 the product of 7×5 plus a units of transfer.

2⁴. +—Bh—c1—Fc—c2—A4—c3—c4—*N (Reg. XII)—(—)

This causes locking of the fifth contact in 20 A4 Reg. XII, i. e. the result $43808 = 592 \times 74$ is now in register XII.

The sleeves of Reg. X and XI are advanced and the sleeve of Reg. XII is returned as described under VI, after which the following circuits are made.

7. +—Ep—k1—XA (Reg. XI)—k6—Fc—k38—El—k39 (Figs. 10a and 11)—MD—k39—*Ud—(—)

7^a. +—Ud—u10—*Ue—(—)

8. +—Ud—v—*O (Reg. X)—(—)

This returns the sleeve of Reg. X and de-

energizes relays Md and Ud.

9. +—Ud—w—*O (Reg. XI)—(—)

This returns the sleeve of Reg. XI.

10. +—Ue—P—Ud—P—*Ep (Reg. XII)—(—)

Automatic printing of the result in Reg. XII takes place as in total recording except that Ue is energized.

11. +—*Uf—u11—Ue—k40—*Uk (Reg. XII, Figs. 11 and 10a)—(—)

This is the releasing circuit after total recording.

12. +—Uk—w—*O (Reg. XII)—(—)

15. The product of the factors in Regs. X and XI which was entered in Reg. XII has been printed and all of the sleeves U in Regs. X, XI and XII are now in their home position.

Example in division

Assume the example $6192 \div 72 = 86$.

I. The dividend (6192) is first entered in Reg. X and then is transmitted to register XII by the usual transmission process. The divisor (72) together with two zeros will then be entered in register X.

II. Division key KD (Fig. 14a) is depressed.

60. 1. +—KD—*DM—(—)

2. +—DM—Uo—dm—*MD (Fig. 11a)—(—) i. e. the multiplication relay MD is energized to multiply the divisor in Reg. X with quotient digits selected by the ratchet mechanism in Fig. 14b.

3. +—Aa—j1—AA (Reg. X)—BB—j5—Aa—j11—j11'—DM (Fig. 14a)—j11—*RT4 (Fig. 8a)—(—)

4. +—DM—j1—AA (Reg. XI)—BB—j2—DM—j8—RT4—j11'—*TR4 (Figs. 8a and 8)—(—)

5. +—DM—aad—AAad—BB9 (Figs. 14a and 14b)—k53—*MK9 (Fig. 12)—(—)

6. +—DM—*El (Reg. XII)—(—)

This places the adding relays of Reg. XII under control of the locked contacts in Reg. XII.

7. +—DM—n—*Cn—(—) and *Dn (Reg. XII, Figs 10a and 9a)—(—)

This sets the calculating mechanism in Reg. XII for subtraction.

8. +—DM—dd—Su—dd—*SD1 (Fig. 14a)—(—)

III. 1. +—SD1 (Figs. 14 and 14a)—j9—j9''—TR4—j15''—SD1—k5 (Reg. XII)—A6—k13—Fc—k23—El—k33—*Bk6 (Reg. XII)—(—)

2. +—SD1—j19—Aa (Reg. X)—k3—A2 (Reg. X)—k9—SD1—j115—MK9 (Fig. 12)—k28—*Bk1 (Reg. XI)—(—)

This represents the tens of 9×2 .

3. +—Bh (Reg. XI)—c1—c10—Sj—c11—Bk1 (Reg. XI)—c12 (Fig. 10a)—MD (Fig. 11)—c10—Sj (Reg. XII)—c11—Bk6 (Reg. XII)—c12—MD—*Fcm—(—)

4. +—Fcm—de—Su (Fig. 14a)—de—*SD2—(—)

IV. 1. +—SL—df (Fig. 14a)—Sp—df—SD2—dg—*Su—(—)

This breaks the circuits dd and de and de-energizes SD1.

2. +—SD2—j18 (Fig. 14)—Aa (Reg. X)—k2—A7—k14—MD—j110—MK9—j25—CT (Reg. XI)—j25—Bk1—j36—MD (Fig. 11)—j26—CT (Reg. XII)—Cn—j28—Bk6—j34—Dc—j44—*A2 (Reg. XII)—(—)

This represents the result of 6 the first digit of the dividend minus the sum of the tens of 9×2 and the units of 9×7 .

The energizing lead c4 for the operating magnet N Reg. XII is broken in Su so that the ratchet mechanism of register XII will not move.

3. From Bk1 (register XI) an impulse goes to Dc Reg. XI (Fig. 13) as follows: Bk1—j36—Dc (Reg. XI)—j46—*A4 (Reg. XI)—(—)

4. From Bk1 (Reg. XI) a second impulse goes as follows: j25—Bk1—j81—A4 (Reg. XI)—j87—Dn (Fig. 9a)—gj—*CT (Fig. 9a, Reg. XI)—(—)

5. From Bk6 (Reg. XII) there is a second impulse: j28—Bk6—j89—A2 (Reg. XII)—j97—Cn—gj—*CT (Reg. XII)—(—)

Energization of A2 Reg. XII establishes the following circuit:

6. +—Bh—c1—Fc—c2—A2—c3—c4—Su—sc—*SD3 (Fig. 14a)—(—)

V. 1. c10 in the circuit (III, 3) will be disconnected in SD3 from the holding means

- for the addition relays in Regs. XI and XII.
2. +—SD3—*Sm—(—)
  - This breaks the line $c7$ Regs. XI and XII.
    3. +—SD3—j8—j8''—TR4—j16''—j16—

5. From $Bk6$ (Reg. XII) a second impulse goes as follows: $j25—Bk6—j86—A9$ (Reg. XII)— $j87—Cn—jj—*DT$ (Reg. XII)—(—)

6. Energization of $A9$ (Reg. XII) establishes the following circuit: +— $Bh—c1—Fc—c2—A9—c3—c4—Su—sc—*SD3$ (Fig. 14a)—(—)

V¹.—1. $c10$ in the circuit (III¹, 3) will be disconnected in $SD3$ from the holding circuits of the addition relays of Reg. XI and Reg. XII.

    2. +—SD3—*SM—(—) whereby $c7$ Regs. XI and XII will be broken.
    3. +—SD3—j8—j8''—TR4—j16''—j16—

SD1—SD3—k6 (Fig. 14)—A0 (Reg. XII)— $k17—Fc—k27—El—k37—*Bk0$ (Reg. XII)—(—)

4. +—SD2 (Fig. 14)—j18—Aa (Reg. X)— $k2—A7—k14—SD1—SD3—j120—$

10 MK9— $k33—*Bk6$ (Reg. XI)—(—)

This is the tens of 9×7 .

5. +—SD3 (Fig. 14)—j32—CT (Reg. XI)— $j32—Bk6—j38—MD$ (Fig. 11)— $j28—CT$ (Reg. XII)— $Cn—j26—Bk0—j36—Dc—$

15 $j46—*A4$ (Reg. XII)—(—)

This may be represented by (1) 0—6=4.

6. From $Bk6$ (Reg. XI) a second impulse goes to Dc Reg. XI (Fig. 13):

$Bk6—j38—Dc$ (Reg. XI)— $j48—*A6$ (Reg. XI)—(—)

7. From $Bk0$ (Reg. XII) a second impulse goes as follows:

$j26—Bk0—j81—A4$ (Reg. XII)— $j87—Cn—jj—*DT$ (—)

15 This shows that the first digit of the quotient is less than 9.

8. +—SD3—st—DT (Fig. 9a)—st—*N (XIV) (Fig. 14a)—(—)

Movement of the ratchet bar S (Fig. 14b) breaks the line df and deenergizes the second and third relays $SD2$ and $SD3$ and relay Su , by which the first relay $SD1$ will again be energized. The selection process will be repeated with the digit 8 as a trial quotient.

35 II¹.—5. +—DM—aad—AA d —BB8 (Figs. 14a and 14b)— $k52—*MK8$ (Fig. 12)—(—)

This may be represented by 6—(1+6)=09.

3. From $Bk1$ (register XI) an impulse goes to Dc Reg. XI: $Bk1—j39—Dc$ (Reg. XI)— $j49—*A7$ (Reg. XI)—(—)

4. From $Bk1$ (Reg. XI) a second impulse goes as follows: $j28—Bk1—j84—A7$ (Reg. XI)— $j87—Dn$ (Fig. 9a)— $gj—*CT$ (Reg. XI)—(—)

5. From $Bk6$ (Reg. XII) a second impulse goes as follows: $j25—Bk6—j86—A9$ (Reg. XII)— $j87—Cn—jj—*DT$ (Reg. XII)—(—)

6. Energization of $A9$ (Reg. XII) establishes the following circuit: +— $Bh—c1—Fc—c2—A9—c3—c4—Su—sc—*SD3$ (Fig. 14a)—(—)

V¹.—1. $c10$ in the circuit (III¹, 3) will be disconnected in $SD3$ from the holding circuits of the addition relays of Reg. XI and Reg. XII.

2. +—SD3—*SM—(—) whereby $c7$ Regs. XI and XII will be broken.

3. +—SD3—j8—j8''—TR4—j16''—j16—

SD1—SD3—k6 (Fig. 14)—A0 (Reg. XII)— $k17—Fc—k27—El—k37—*Bk0$ (Reg. XII)—(—)

4. +—SD2 (Fig. 14)—j18—Aa (Reg. X)— $k2—A7—k14—SD1—SD3—j120—$

MK8— $k32—*Bk5$ (Reg. XI)—(—)

5. +—SD3 (Fig. 14)—j32—CT (Reg. XI)— $j32—Bk5—j37—MD$ (Fig. 11)— $j27—XI—j32—Bk5—j37—MD$ (Fig. 11)— $j27—j46—*A4$ (Reg. XII)—(—)

6. From $Bk5$ (Reg. XI) a second impulse goes to Dc Reg. XI (Fig. 13): $Bk5—j37—Dc$ (Reg. XI)— $j47—A5$ (Reg. XI)—(—)

7. From $Bk0$ (Reg. XII) a second impulse goes out as follows: $j26—Bk0—j28—A4$ (Reg. XII)— $j87—Cn—jj—*DT$ (Reg. XII)—(—) whereby it is determined that the first digit of the quotient is less than 8.

The foregoing circuits include the circuits that are made when the trial quotients 9 and 8 are used. When the trial quotient 9 is used, 64 of the number 648, which is the product of 9×72 , is subtracted from the number 06 which includes 6 of the dividend 6912 and a zero placed in effect to the left of the 6. When the trial quotient 8 is used the number 57, which is the hundreds and tens of the product of 72×8 , is subtracted from 06. After it has been determined that the numeral 8 is too large the division ratchet will be stepped ahead by the circuit V 8 supra which was made as the relay DT (Reg. XII) was energized when 5 was subtracted from 0.

The selection process will go on with 7 as the trial quotient, when the circuit III 1 will again energize relay $Bk6$ (Reg. XII) and circuit III 2 will again energize relay $Bk1$ (Reg. XI). The circuit IV 2 will energize relay $A6$ (Reg. XII), circuit V 3 will energize relay $Bk0$ (Reg. XII), circuit V 4 will energize relay $Bk4$ (Reg. XI), and circuit V 5 will energize the relay $A5$ (Reg. XII).

A circuit will again be made over the DT relay (Reg. XII) to cause the division ratchet to step over the contact 6, after which the circuits will be as follows:

Circuit III 1 energizes $Bk6$ (Reg. XII), circuit III 2 energizes $Bk1$ (Reg. XI), circuit IV 2 energizes $A3$ (Reg. XII), circuit V 3 energizes $Bk0$ (Reg. XII), circuit V 4 ener-

gizes Bk4 (Reg. XI), circuit V 5 energizes A6 (Reg. XII). Circuits will again be made to show that the first numeral of the quotient is less than 6 and the division ratchet will be stepped over contact 5.

When 4 is the multiplier or trial quotient the relay Bk0 (Reg. XI) will be energized by the circuit III 2 as there is no tens in the product of 4×2 . The same circuit will also be closed when 3, 2, 1 and 0 are used as the trial quotients. When the 0 is tried as the first numeral of the quotient the circuit V' 7 will be closed as follows: j26—Bk0—j90—A0 (Reg. XII)—j97—Cn—gj—*CT (Reg. XII)—(—), whereby it is determined that the first number of the quotient is zero, that is, the product of 72 by the digits 9 to 1 includes a number in the hundreds position.

The circuits continue as follows:

8. +—SD3—st—CT (Reg. XI)—ts (Figs. 10a and 9a)—CT (Reg. XII)—ts—*Us (Fig. 14a)—(—)
9. +—Us—ps—*Sp (Fig. 14a)—(—)
10. +—Us—dg—*Su—(—)

Energization of Sp breaks the holding circuit for SD2 and SD3 and the lead to the operating magnet N, XIV. Energization of the relay Su holds the relay SD1 deenergized.

As the selection relays are deenergized multiplication of 72 by 0 under control of BB0 (Fig. 14b) is now carried out in the usual manner in accordance with the diagram in Fig. 11. As the calculating mechanism is set for subtraction the product of 72×0 will be subtracted from 6192 in Reg. XII with the result that 6192 will be re-registered in Reg. XII.

VI.—1. After the ratchet mechanism in Reg. XII has made the required number of steps to clear out the old dividend 6192 as the new dividend 6192 is entered the following circuit will be made: +—Bh (Reg. XII)—j1—AA—BB—j5—Bh—j11—TR2 (energized from Reg. X)—j124—MD—j124—DM (Fig. 14a)—j124—*Ub—(—)
2. +—U—AAd (Fig. 14a)—BB8—k52—Ub—j40—Dc (Reg. XI)—j50—*A0 (Reg. XI)—(—)
3. +—Ub (Fig. 14a)—c4—*N (Reg. XI)—(—).

This causes locking of the first contact in A0 Reg. XI, i. e. the first digit of the quotient is now in register XI.

4. +—Ub—w—*0 (Reg. XII)—(—)
This causes the sleeve U (Reg. XII) to be returned.

5. +—Bh (Reg. XII)—g1—UUg7 (Fig. 10a)—Ub—w—*O (XIV)—(—)
60 This causes the return of the division ratchet mechanism in Fig. 14b.

6. At the end of the return movement of sleeve U (Fig. 14b) the holding circuit g2 for Us will be broken causing deenergization 65 of relays Us, Ub, Sp and Su.

7. +—DM—dd—Su (deenergized)—dd—*SD1—(—)

This starts a new selection process with 6192 as the dividend.

II'—4. +—DM (Reg. XI)—j1—Aa—BB—j3—DM—j9—RT4—j10—*TR3 (Figs. 8a and 8)—(—)

The ratchet mechanism of Reg. XI made one step as 0 was registered.

The circuits are now as follows: 75

5. +—DM—aad—AAd—BB9—k53—*MK9 (Fig. 12)—(—)
6. +—DM—l—*El (Reg. XII)—(—)
7. +—DM—n—*Cn—(—) and *Dn (Reg. XII)—(—)
III'—1. +—SD1—j9—j9''—TR3—j14''—SD1—k4 (Reg. XII)—A1—k11—Fc—k21—El—k31—*Bk1 (Reg. XII)—(—)
2. +—SD1—j19—Aa (Reg. X)—k3—A2 (Reg. X)—k9—SD1—j115—MK9—k28—*Bk1 (Reg. XI)—(—)
3. +—Bh (Reg. XI)—c1—c10—Sj—c11—Bk1 (Reg. XI)—c12—MD—c10—Sj (Reg. XII)—c11—Bk1 (Reg. XII)—c12—MD—*Fcm—(—)
4. +—Fcm—de—Su—de—*SD2—(—)
IV'—1. +—SL—df—Sp—df—SD2—dg—*Su—(—)

This deenergizes SD1.

2. *A7 (Reg. XII), see circuit IV, 2. 95
That is, $1-(1+3)=7$.

3. *A4 (Reg. XI), see circuit IV, 3.

4. *CT (Reg. XI), see circuit IV, 4.

5. *DT (Reg. XII), see circuit IV, 5.

6. *SD3 (Fig. 14a), see circuit IV, 6.

V'—3. *Bk6 (Reg. XII), see circuit V, 3.

4. *Bk6 (Reg. XI), see circuit V, 4.

5. *A9 (Reg. XII), see circuit V, 5. That is, $(1)7-6=9$.

6. *A6 (Reg. XI), see circuit V, 6.

7. *DT (Reg. XII), see circuit V, 7.

Whereby it is determined that the second digit of the quotient is less than 9.

The selection process starts over again with 8 as the trial quotient and 61 as the two highest digits of the dividend, the division ratchet having been controlled by circuits as before.

When 8 is tried, the circuits will correspond to those made when 8 was tried with 06 as the first two digits. In this case, however, the first two digits of the product of 72×8 are subtracted from 61 of 6192.

As the first two digits of the product of 8×72 , i. e. 57, constitute a smaller number than 61 of 6192, no borrowing will be necessary and a circuit V' 8 will be made as in the case when 0 was taken as the first digit of the quotient. Ensuing circuits will be made as before to multiply 72×8 and to subtract the product from 6192, registering the remainder as a new dividend 432 in Reg. XII and the digit 8 under the second bar of Reg. XI and returning the division ratchet to 9 and energizing the reversing relay TR2. This will 120

cause the first circuit to Reg. XII to come in over k_3 and over the contact 3 representing the digit 3 of 432. Upon trial by 9, 8 and 7 it will be found that the DT relay of Reg.

- 5 XII will be energized. When 6 is tried and after 43 of the product of 6×72 , which is 432, is subtracted from the dividend 43 of 432, the circuit V' 7 will be made as before which controls subsequent multiplication of 72×6 and subtraction of product from 432, entry of 6 in Reg. XI and restoration of the division ratchet mechanism.

VI.—After multiplication of 72 by 6 and subtraction of the product 432 from 432, the remainder in Reg. XII will be zero.

1. +—Bh (Reg. XII)—j1—AA—BB—j4—TR1 (Fig. 8)—j124—MD—j124—DM (Fig. 14a)—j124—*Ub—(-)
2. +—U—AAD (Fig. 14a)—BB6—k50—Ub—j38—Dc (Reg. XI)—j48—*A6 (Reg. XI)—(-)
3. +—Ub (Fig. 14a)—c4—*N (Reg. XI)—(-)

The second digit "6" of the quotient 86 is now locked in register XI. The remainder "zero" is registered in Reg. XII. The divisor is still in Reg. X. The quotient in Reg. XI and the remainder in Reg. XII may be printed by total printing operations as described under total printing.

While the source of electrical energy for operating the machine of the present embodiment is diagrammatically illustrated and described herein as a battery; it is nevertheless within the contemplation of the invention that any suitable source of electrical energy may be utilized, in accordance with the design and construction of the particular machine desired and for which the various parts of the device are adapted. In connection with the present details of construction herein illustrated, as a present preferred embodiment of the invention, it might be pointed out that 50 volts D. C. has been found to be a suitable voltage for a calculating machine typical of this embodiment.

Having thus described my invention with particularity with reference to its preferred form, and having illustrated various modifications thereof, it will be obvious to those skilled in the art, after understanding my invention, that other changes and modifications may be made therein without departing from the spirit and scope of my invention, and I aim in the appended claims to cover such changes and modifications as are within the scope of the invention.

What I claim as new and desire to secure by Letters Patent is:

- 60 1. In an electric calculating machine two sets of digit lines corresponding to the units of a numerical system, key operated means for interconnecting said two sets of digit lines in various combinations, a number of 65 registering devices each comprising several

multiple contact relays adapted to be energized by current in one of the sets of digit lines and each of said relays having a plurality of contacts adapted to be locked with respect to respectively complementary contacts, means for locking a contact closed and then releasing the same when a current is caused to pass through a digit line of the same set corresponding to a number of the same denominational order, and a recording device actuated by current impulses passing through the contacts of a predetermined one of said registering devices for recording the result of the calculating operation.

2. In an electric calculating machine two sets of each ten digit lines corresponding to the units of the numerical system, key operated means for interconnecting said two sets of digit lines in ten combinations, a number of registering devices each comprising ten multiple contact relays and each of said relays having a plurality of contacts adapted to be locked with respect to respectively complementary contacts, each of said relays being adapted to be energized by current in one of the sets of digit lines, a series of locking bars for each registering device, each of the bars of each series being adapted to cooperate with one contact in each of said multiple contact relays in the corresponding register for locking the contacts closed and then releasing the same when current is caused to pass through a digit line of the same set corresponding to a number of the same denominational value, and means for selectively connecting each of said registering devices as a primary or a secondary register.

3. In an electric calculating machine two sets of each ten digit lines corresponding to the units of the numerical system, key operated means for interconnecting said two sets of digit lines in ten combinations, a number of registering devices each comprising ten multiple contact relays each of said relays being adapted to be energized by current in one of the sets of digit lines and each of said relays having a plurality of contacts adapted to be locked with respect to respectively complementary contacts, a series of locking bars for each registering device, each of the bars of each series being adapted to cooperate with one contact in each of said multiple contact relays in the corresponding register for locking the contacts closed and then releasing the same when a current is caused to pass through a digit line of the same set corresponding to a number of the same denominational value, and a recording device actuated selectively by current impulses passing through the contacts of one of said registering devices for recording the result of the calculating operation from one or the other of said registering devices.

4. In an electric calculating machine a keyboard, a set of digit keys thereon correspond-

- ing in number and value to the digits of a numerical system, sets of digit lines each comprising a number of lines corresponding to the numerical system, multiple contact relays for interconnecting said sets of digit lines in various combinations in accordance with the addition and multiplication tables, registering devices comprising relays each provided with a plurality of denominational 5 digit contacts, means for individually controlling the operation and locking of said contacts upon energization of the respective relays, and means for transmitting current impulses over the locked contacts of one of 10 said registering devices to the relays of another registering device over said lines interconnected by said multiple contact interconnecting relays energized by circuits over contacts of another registering device.
- 15 5. An electric calculating machine comprising ten digit keys, a number of standard register assemblies each comprising a set of calculating relays for interconnecting two sets of each ten digit lines in various combinations and a registering device cooperating with said calculating relays, key operated means for controlling and interconnecting the various register assemblies of the calculating machine for automatically performing 20 addition, subtraction, multiplication and combinations thereof, means for recording the result of such calculating operations, and means for simultaneously transmitting said result to and storing the same in a registering device.
- 25 6. An electric calculating machine comprising ten digit keys, a number of register assemblies each comprising a set of calculating relays for interconnecting two sets of each ten digit lines in various combinations and a registering device cooperating with said calculating relays, key operated means for controlling and interconnecting the various register assemblies for automatically performing addition, subtraction, multiplication, and combinations thereof in one or more of said register assemblies, means for recording the result of such calculating operations, and means for simultaneously transmitting said result to and storing the same in a registering device.
- 30 7. An electric calculating machine comprising ten digit keys, a register assembly associated therewith comprising a set of calculating relays for interconnecting two sets of digit lines according to the addition table and a registering device cooperating with said set of calculating relays, means for recording the result of a calculating process, and means for discarding a predetermined number of digits of lowest denominational value from the result before recording.
- 35 8. An electric calculating machine comprising ten digit keys, a register assembly associated therewith comprising a set of calculating relays for interconnecting two sets of digit lines according to the addition table and a registering device cooperating therewith, means for recording the result of a calculating process, means for discarding a predetermined number of digits of lowest denominational value from the result before recording, and means for automatically increasing the numerical value of the digit of smallest denominational value recorded by one in case the numerical value of the digit of highest denominational value discarded 40 be higher than a predetermined numerical value.
- 45 9. In an electric calculating machine a key board, a set of digit keys thereon corresponding to the digits of the numerical system, two sets of digit lines, multiple contact relays for interconnecting two sets of digit lines in various combinations, a primary register associated with the digit keys of said key board for setting up numbers therein, and means for ascertaining the number of digits entered into and set up in the said primary register.
- 50 10. An electric calculating machine comprising ten digit keys, a number of standard register assemblies each comprising a single set of calculating relays for interconnecting two sets of each ten digit lines in various combinations and a registering device cooperating with said calculating relays, said calculating relays, sets of digit lines and registering device being common to the denominational digits of a number, means for setting up a number in any one of said registers by successively depressing said digit keys, and means for transmitting said number simultaneously to a plurality of other registers.
- 55 11. An electric calculating machine comprising ten digit keys and a number of registers, means for setting up a number in one of said registers by successively depressing said digit keys, means for transmitting said number simultaneously to other registers, and means for individually adapting each register to cooperate with a set of calculating relays so as to automatically perform addition or subtraction of a number transmitted thereto to or from a number previously stored therein.
- 60 12. An electric calculating machine comprising ten digit keys, a number of registers, means for setting up a number in one of said registers by successively depressing said digit keys, means for transmitting said number simultaneously to other registers, and means for individually recording the number stored in any register.
- 65 13. An electric calculating machine comprising ten digit keys, a number of registers and sets of calculating relays for interconnecting two sets of digit lines in various combinations, means for setting up a number in

- one of said registers by successively depressing said digit keys, and means for simultaneously recording a number set up in a register and transmitting the same to another register.
14. In an electric calculating machine a key board, keys thereon for closing current circuits each corresponding to a digit of a numerical system, a primary registering device comprising a single set of multiple contact relays for registering the numbers corresponding to the current circuits closed, a plurality of secondary registers each adapted to cooperate with a set of calculating relays adapted to connect two sets of digit lines in various combinations, and means for sending electric impulses through the contacts of said primary registering device to said secondary registers for transmitting to the latter numbers set up in the former.
15. In an electric calculating machine a key board, keys thereon for closing current circuits each corresponding to a digit of a numerical system, registers each comprising a set of multiple contact relays each adapted to cooperate with a set of calculating relays adapted to connect two sets of digit lines in various combinations, each of said sets of multiple contact relays, calculating relays and sets of digit lines being common to the denominational digits of a number, electric circuits prepared by the contacts of said register relays, and means actuated by circuits controlled at will for successively closing said prepared circuits in order to transmit to other registers numbers set up in a register.
16. In an electric calculating machine a key board, keys thereon for closing current circuits each corresponding to a digit of a numerical system, a primary registering device comprising multiple contact relays for registering the numbers corresponding to the current circuits closed, a plurality of secondary registering devices each adapted to cooperate with a set of calculating relays adapted to connect two sets of digit lines in various combinations, said multiple contact relays and calculating relays being common to all denominational orders of a plural digit number, and means for successively closing electric circuits through the contacts of said primary registering device simultaneously to a plurality of said secondary registering devices for transmitting to the latter numbers set up in the former.
17. In an electric calculating machine a key board, keys thereon for closing current circuits each corresponding to a digit of a numerical system, a primary register comprising multiple contact relays for registering the numbers corresponding to the current circuits closed, a plurality of secondary registers each adapted to cooperate with a set of calculating relays adapted to connect two sets of digit lines in various combinations,
- electric circuits between the relay contacts of said primary register and each of said secondary registers and means actuated by circuits controlled at will for closing said first circuits in order to transmit to the secondary registers numbers set up in the primary register, reversing switches and means for connecting said reversing switches in the circuits between said primary register and said secondary registers in order to reverse the order of the digits in the number transmitted.
18. In an electric calculating machine a key board, a primary register electrically associated therewith, a register assembly comprising a registering device associated with a set of calculating relays, means for closing circuits between said primary register and said register assembly through said calculating relays to transmit current impulses from the former to the latter, and means associated with said register assembly for switching said impulses over from one circuit to a circuit corresponding to the complement of the numerical value of the first circuit.
19. In an electric calculating machine a key board, a primary register electrically associated therewith, a register assembly comprising a registering device associated with a set of calculating relays, means for closing circuits between said primary register and said register assembly through said calculating relays, to transmit current impulses from the former to the latter, key operated means for switching said impulses over to circuits respectively corresponding to the complement of their original numerical value in order to perform subtraction, and means for registering the result of a subtraction process in said secondary register.
20. In an electric calculating machine a key board, a primary register electrically associated therewith, a register assembly comprising a registering device associated with a set of calculating relays, means for closing circuits between said primary register and said register assembly through said calculating relays, to transmit current impulses from the former to the latter, a multiple contact switch for switching impulses corresponding to digits of the numerical system over to circuits respectively corresponding to digits of the complementary value, and means for closing circuits through the contacts of a register and said multiple contact switch in order to obtain the complement of a number registered when a number of higher numerical value is subtracted from a number of smaller numerical value.
21. In an electric calculating machine a key board, a primary register electrically associated therewith, a register assembly comprising a registering device associated with a set of calculating relays, means for closing circuits between said primary register and said register assembly through said calcu-

- lating relays to transmit current impulses from the former to the latter, a multiple contact switch for switching impulses corresponding respectively to digits of the numerical system over to circuits corresponding to digits of the respective complementary value, a transfer switch for effecting borrowing in subtraction, and means controlled by said transfer switch when operated for closing circuits through the contacts of said registering device and said multiple contact switch in order to obtain the complement of a number registered in said registering device when a number of higher numerical value is subtracted from a number of lower numerical value.
22. In an electric calculating machine a key board, a primary register electrically associated therewith, a register assembly comprising a registering device associated with a set of calculating relays, means for closing circuits between said primary register and said register assembly through said calculating relays to transmit current impulses from the former to the latter, and means for transmitting impulses from a register to the same register to register said digits in different denominational orders.
23. In an electric calculating machine two sets of each ten digit lines, multiple contact relays for interconnecting said two sets of digit lines in various combinations in accordance with the addition and multiplication table, registering devices comprising multiple contact relays for setting up numbers therein, the contacts of each relay corresponding to the digit value of the relay and to the various denominational positions of the digits of a number, and means for transmitting current impulses over the contacts of one registering device to the relays of another over contacts of the multiple contact interconnecting relays energized over contacts of a third registering device.
24. An electric calculating machine comprising a number of registers each adapted to cooperate with a set of calculating relays for interconnecting two sets of each ten digit lines in various combinations, means for setting the calculating machine for automatically performing addition, subtraction, multiplication and combinations thereof, means for recording the result of such calculating operations, and means for simultaneously transmitting said result to, and storing the same in a register.
25. In an electric calculating machine a register and a set of calculating relays for interconnecting two sets of digit lines according to the addition table, means for recording the result of a calculating process, and means for discarding a predetermined number of digits of lowest denomination from the result before recording.
26. An electric calculating machine comprising a number of registers each adapted to cooperate with a set of calculating relays for interconnecting two sets of each ten digit lines in various combinations, means for setting up a number of said registers, and means for simultaneously recording a number set up in a register and transmitting the same to another register.
27. In an electric calculating machine means for closing current circuits each corresponding to a digit of the numerical system, a primary registering device comprising multiple contact relays for registering the numbers corresponding to the current circuits closed, the contacts of each relay being of the same digit value and corresponding to the different possible denominational positions of such digit in a number, a plurality of secondary registers each adapted to cooperate with a set of calculating relays adapted to connect two sets of digit lines in various combinations, and means for sending electric impulses through the contacts of said primary registering device to said secondary registers for transmitting to the secondary registers numbers set up in the primary registering device.
28. In an electric multiplication machine a plurality of registers adapted to cooperate with sets of calculating relays for interconnecting sets of digit lines in accordance with the multiplication and addition tables respectively, means for setting up multiplicand and multiplier in different registers and automatic means for multiplying each digit of the multiplier with the multiplicand and adding the successive products thereof in a third register.
29. In an electric multiplication machine a plurality of registers and sets of calculating relays cooperating therewith for interconnecting sets of digit lines in accordance with the multiplication and addition tables respectively, means for setting up multiplicand and multiplier in different registering devices, automatic means for successively multiplying each digit of the multiplier with the multiplicand and adding the products thereof in a third register, and means for storing the multiplier in a register for performing a series of multiplications with constant multiplier.
30. In an electric multiplication machine a plurality of registers and sets of calculating relays cooperating therewith for interconnecting sets of digit lines in accordance with the multiplication and addition tables respectively, means for setting up multiplicand and multiplier in different registers, automatic means for multiplying each digit of the multiplier with the multiplicand and adding the successive products thereof in a third register, means for storing the product in a register and means for multiplying the prod-

uct registered by a third factor introduced into the machine.

31. In an electric multiplication machine a plurality of registers adapted to cooperate with sets of calculating relays for interconnecting sets of digit lines in accordance with the multiplication and addition tables respectively, means for setting up multiplicand and multiplier in different registers, automatic means for multiplying each digit of the multiplier with the multiplicand and adding the successive products thereof in a third register, and means for discarding a predetermined number of digits of lowest denominational value from the product.

32. In an electric multiplication machine a plurality of registers and sets of calculating relays cooperating therewith for interconnecting sets of digit lines in accordance with the multiplication and addition tables respectively, means for setting up multiplicand and multiplier in different registering devices, automatic means for multiplying each digit of the multiplier with the multiplicand and adding the successive products thereof in a third register, and means for automatically adding or subtracting the sum of said products in said third register to or from a number stored in a fourth register.

33. In an electric division machine a plurality of registers and sets of calculating relays cooperating therewith, means for transmitting current impulses to said registers in order to set up the dividend and a divisor in separate registers, selection means for automatically selecting the digits of the quotient by a series of multiplications of the divisor with the highest and successively the next lower digits of the numerical system until the proper digit is obtained and subtracting the consecutive products from the dividend.

34. In an electric division machine a plurality of registers and sets of calculating relays cooperating therewith, means for transmitting current impulses to said registers in order to set up the dividend and divisor in separate registers, selection means for automatically selecting the digits of the quotient by a series of multiplications of the divisor with the highest and successively the next lower digits of the numerical system until the proper digit is obtained and subtracting the consecutive products from the dividend, and automatic means for setting up the digits of the quotient in a separate register.

35. The combination with an electric calculating machine comprising a ten key keyboard, a plurality of registers, means for entering the digits of a number in denominational sequence in one register, means for transmitting said number to another register in reverse order, of a recording device adapted to type the digits of the number in the order from right to left during transmission

and in the order from left to right during entry of the number in the first register under control of the keyboard.

36. A register assembly for an electric calculating machine comprising a set of multiple contact locking relays corresponding to the digits of the numerical system, reciprocating locking bars for locking the contact armatures of said relays and releasing the same for short periods during their reciprocation, relay operated means for reciprocating the said locking bars, a set of calculating relays associated with said relays for controlling the energizing circuits for the same, said calculating relays being adapted to connect sets of digit lines in various combinations, and auxiliary multiple contact relays associated with said set of calculating relays and multiple contact relays for setting the same to automatically perform predetermined functions.

37. An electric calculating machine comprising a plurality of register assemblies in accordance with claim 36 (circuits interconnecting said register assemblies for transmitting registered impulses from one register assembly to another, and a set of reversing switches adapted to be connected in said circuits in order to transmit an impulse registered under a locking bar last actuated in one register to the locking bar first actuated in the second register).

38. An electric calculating machine comprising a plurality of register assemblies in accordance with claim 36, circuits interconnecting said register assemblies for transmitting registered impulses from one register assembly to another, and a set of reversing switches adapted to be connected in said circuits, and means controlled by the locking bar last actuated in one register for energizing a reversing switch adapted to reverse the denominational order of the impulses before transmitting the same to a second register.

39. In an electric calculating machine two sets of digit lines, multiple contact switches adapted to interconnect said two sets of digit lines in various combinations, multiple contact relays for successively registering impulses transmitted thereto by denominational locking contact armatures in closed position, relay operated switches for connecting the circuits of the machine in accordance with the operations to be performed, key-controlled circuits for energizing said switch operating relays and circuits controlled by said relays for maintaining their own energization.

40. In an electric calculating machine sets of calculating switches adapted to connect electric digit circuits in accordance with the addition and multiplication table, registering devices comprising relay operated multiple contact switches, relay operated means for locking the movable members of said switches in open or closed position, circuits controlled

by said switches for energizing said calculating relays, and circuits controlled by said calculating relays for energizing said switch operating relays and the relays controlling the said locking means.

5 41. In an electric calculating machine, two sets of digit lines each set of which comprises lines in number and value corresponding to a numerical system, interconnecting means for connecting certain predetermined lines of one set with lines of the other set according to the desired mathematical function to be performed, switching means comprising two alternate paths through which one of said sets of digit lines passes for altering in complementary order the normal sequential value of said set of lines, and means for automatically opening one path when the other respective path is closed.

20 42. In an electric calculating machine, two sets of digit lines each set of which comprises lines in number and value corresponding to a numerical system, interconnecting means for connecting certain predetermined lines of one set with lines of the other set according to the desired mathematical function to be performed, switching means comprising two alternate paths through which one of said sets of digit lines passes, one of said paths serving to close said lines in their normal sequential order and the other of said paths serving to close said lines in an order complementary to their normal order, and means controlled at will for closing one or the other of said paths.

35 43. In an electric calculating machine two sets of each ten digit lines corresponding to the units of the numerical system, ten key operated multiple contact relays for interconnecting said two sets of digit lines in ten combinations, a set of transfer lines, contacts on said multiple contact relays for connecting one of said transfer lines in parallel with any interconnected pair of digit lines representing digits the sum of which is a two-figured number, two switching relays having contacts connected in parallel through which one set of said digit lines is conducted, one of said relays being adapted to increase the numerical value of a digit line by one and being

50 operatively controlled by one of said transfer lines, and the other of said switching relays being adapted to connect the lines in their normal sequence, a registering device comprising ten multiple contact relays, each of which is adapted to be energized by current in one of the sets of digit lines, electrically operated means for locking the contacts closed and then releasing the same when a current is caused to pass through a digit line 55 of the same set corresponding to a number of the same denominational value and a recording device actuated by current impulses passing through the contacts of the registering device for recording the result of the calculating operation.

44. The combination of a plurality of denominational series of digit contacts adapted to be closed and locked as digits of a number are entered, a plurality of digit relays, denominational series of contacts adapted to be closed by said relays, a series of denominational reversing relays, contacts adapted to be closed by said reversing relays, lines connecting one member of each of said last mentioned contacts, means for successively establishing a connection between said lines and a source of energy, energizing leads for said denominational relays for selectively and successively energizing the relays corresponding to the number of denominational orders as they are entered in the first series of contacts, and energizing leads for the relays closing said second plurality of digit contacts extending over closed contacts in said first plurality of series of contacts and connected to second members of said denominational contacts, said contacts being arranged to interconnect said lines to direct the first impulse for the relays of the second plurality of contacts over the last contact closed in the first plurality of contacts.

45. The combination of two registering mechanisms, of means for adding corresponding denominational digits of the amounts on the two mechanisms together and computing the result, a transfer switch adapted to be closed when the result is greater than nine for adding one to the computation of the next higher digits, means for conditioning the machine to perform a computation, and means for opening said switch as an incident to the conditioning of the machine to perform such computation.

46. The combination of two registering mechanisms, of means for adding corresponding denominational digits of the amounts on the two mechanisms together and computing the result, a transfer switch adapted to be closed when the result is greater than nine for adding one to the computation of the next higher digits, a no-transfer switch adapted to be closed when the result is nine or less than nine, means for conditioning the machine to perform addition, and means controlled as an incident in conditioning the machine to perform addition, to open the transfer switch and close the no-transfer switch.

47. The combination of two registering mechanisms, of means for adding corresponding denominational digits of the amounts on the two mechanisms together and computing the result, a transfer switch adapted to be closed when the result is greater than nine for adding one to the computation of the result of the addition of the next higher digits, a no-transfer switch adapted to be closed when the result is nine or less than nine, means for conditioning the machine to perform addition, means controlled as an incident to an operation of

the machine in performing addition to open the transfer switch and close the no-transfer switch, and means for rendering said last mentioned means effective for permitting said transfer switch to be closed during addition of the first digits of the amounts to be added.

48. The combination of two registers, means for establishing transmitting circuits between the registers comprising a relay and contacts operated thereby, a key for controlling the energization of said relay, a self-closing circuit for said relay, and means for automatically establishing said self-closing circuit after the transmitting operation has begun and for maintaining it established until the transmitting operation has been concluded.

49. The combination of a receiving register comprising a plurality of denominational series of digit contacts, digit relays for closing said contacts, means movable step by step for locking said contacts in closed position as the digit relays are energized, a connecting relay in the circuits to and from said register, a key for energizing said relay, a self-closing circuit for said relay, and a switch operable by said step by step movable means for closing said self-closing circuit and maintaining it closed until said movable means has returned to its home position.

50. In a register comprising digit relays and a plurality of denominational series of contacts adapted to be closed by energization of said relays, energizing leads for said relays, normally closed contacts in said leads, a circuit-breaking relay for opening said contacts, locking means for each denominational series of contacts, means movable step by step for operating said locking means as a digit relay is energized, a ratchet for operating said movable means, a magnet for operating said ratchet, a contact in each digit relay adapted to be closed by energization of said relays to energize said ratchet operating magnet, another contact in each relay for closing a self-closing circuit for said relays at one point, means operated by said ratchet for closing said self-closing circuit at another point and maintaining it closed until the ratchet has returned to its home position and the contact has been locked, and a third contact in each digit relay adapted to establish a circuit to energize the relay controlling the leads for said digit relays for the purpose of breaking said leads, after the self-closing circuits have been established.

51. The combination of two registers each including a plurality of digit relays and a plurality of denominational series of contacts in said relays adapted to be closed upon energization of said relays, means for locking said contacts in closed position, a magnet for operating said locking means, digit

circuits from the closed contacts of both registers, a computing mechanism comprising digit relays connected to the circuits from the contacts of one register and digit contacts one member of each of which is connected to a digit circuit from the contacts of the other register and the other member to a digit line of a digit result line leading to the relays of the second register, normally closed contacts in said digit result lines, a relay controlling said contacts in the result lines, normally closed contacts in the circuits from the contacts of the result register, a relay adapted to be energized upon closing of the contacts of the computing mechanism to open the contacts in the lines from the contacts of the result register, a circuit for said relay in the result lines activated upon energization of said last mentioned relay and a relay in the result register and a circuit for said magnet operating said locking means activated by the operated relay in said result register.

52. The combination of two registers each including a plurality of digit relays, and a plurality of denominational series of contacts in said relays adapted to be closed and locked, means for locking said contacts in closed position, a magnet for operating said locking means, digit circuits from the closed contacts of both registers, a computing mechanism comprising digit delays connected to the circuits from the contacts of one register and digit contacts one member of each of which is connected to a digit circuit from the contacts of the other register and the other member to a digit line of a digit result line leading to the relays of the second register, normally closed contacts in said digit result lines, a relay controlling said contacts in the result lines, normally closed contacts in the circuits from the contacts of the result register, a relay adapted to be energized upon closing of the contacts in the computing mechanism to open the contacts in the circuits from the contacts of the result register and to close a holding circuit in conjunction with the relays of the result register for the relays of the result register, an energizing circuit for the relay controlling the contacts in the result lines to the result register and an energizing circuit for said magnet, and means operated by said magnet for deenergizing the relay controlling the contacts in the circuits from the contacts of the result register and the self-closing circuits of the digit relays of the result register and the relay controlling the contacts in the result circuits to the relays of the result register and for establishing another closed circuit for the digit relays in the result register and the relay controlling the contacts in the result lines and maintaining it during the entire movement of said locking means, and for interrupting the closed circuit of the digit relays of the result register and the relay controlling the con-

tacts in the result lines at the completion of the locking operation.

53. In a machine of the class described, the combination of two registers, means for transmitting the number in one register in denominational order to the second register, and means for subsequently automatically clearing the second register of digits of higher denominational order than the highest denomination of digits transmitted.

54. The combination of two registers, a computing mechanism, means for entering numbers in the computing mechanism corresponding to the numbers in the registers under control of the registers, means for transmitting the computed result to one register and clearing it of the number entering the computation incidentally to the entry of the computed result, means whereby the number in the other register is retained in said register, and means for transmitting to the result register a number equal to that in the other register, retaining the number in said other register and clearing the result register of any previous number involving any number of denominational orders.

55. The combination of a register adapted to receive numbers, means for entering new numbers and simultaneously as an incident to such entry erasing the previous number or the part thereof involving the same number of denominational orders, and means for erasing the portion of the previous number in higher denominational orders and registering zero in such orders.

56. The combination with a register comprising digit contacts for each denominational order within the capacity of the register, means for closing and locking a digit contact of a denominational order, means traveling from lowest to highest order for controlling the locking of the closed digit contact of the corresponding denominational order and for unlocking a closed contact in said denominational order, and means continuing the travel of said means after the last digit has been entered to unlock closed contacts of higher order representing portions of previously entered numbers.

57. The combination with a register comprising digit contacts for each denominational order within the capacity of the register, means for closing and locking a digit contact of a denominational order, means traveling from lowest to highest order for controlling the locking of the closed digit contact of the corresponding denominational order and for unlocking a closed contact in said denominational order, means continuing the travel of said means after the last digit has been entered to unlock closed contacts of higher order representing portions of previously entered numbers, and means for automatically returning said traveling means after its forward travel has been completed.

58. The combination with a register comprising digit contacts for each denominational order within the capacity of the register, means for closing and locking a digit contact of a denominational order, means traveling from lowest to highest order for controlling the locking of the closed digit contact of the corresponding denominational order and for unlocking a closed contact in said denominational order, means continuing the travel of said means after the last digit has been entered to unlock closed contacts of higher order representing portions of previously entered numbers, and means for automatically returning said traveling means after its forward travel has been completed, said means being set in operation after the entry of the highest order digit when the zero contacts of higher order are locked closed.

59. In a machine of the class described, the combination of a register, means for entering digits denominational in said register comprising means traveling step by step from lowest to highest denominational order, means for automatically returning said traveling means to its home position after a digit has been entered in the highest denominational order of the register, and means for controlling said returning means to return to home position immediately after the highest denominational digit of a number has been entered in case the register contained all zeros or a number of equal or fewer significant denominational digits.

60. In a machine of the class described, the combination of a register, means for entering digits denominational in said register comprising means traveling step by step from lowest to highest denominational order, a magnet for actuating said traveling means, a magnet for returning said traveling means, and control means carried by the traveling means to energize the returning magnet when a number equal to the capacity of the machine has been entered.

61. In a machine of the class described, the combination of a register, means for entering digits denominational in said register comprising means traveling step by step from lowest to highest denominational order, a magnet for actuating said traveling means, a magnet for returning said traveling means, control means carried by the traveling means to energize the returning magnet when a number equal to the capacity of the machine has been entered, and other control means carried by said traveling means for energizing said returning magnet after all of the digits have been entered and when zeros have been registered in denominational orders higher than the position of said traveling means after the entry of the highest order digit of said number.

62. The combination of a registering device, means for entering digits of a number

therein successively in denominational order and clearing said register of digits previously entered in corresponding denominational orders, means for registering zeros in denominations higher than the highest denominational digit entered in case digits were previously registered therein, means for interrupting the registration of zeros in case zeros were previously registered therein, and means for conditioning the register to receive another number after the registration of zeros has been effected or interrupted.

63. In a machine of the class described, the combination of a computing mechanism comprising a set of digit lines on which impulses denote one number entering the computation, another set of digit lines on which impulses denote another number entering the computation, result digit lines adapted to be activated under control of said computing digit lines, transfer and no-transfer multiple contact relays, energizing lines for said relays connected in circuit in said computing mechanism, one of said sets of computing digit lines being controlled by said transfer and no-transfer relays, and subtraction multiple contact relays for changing the value of said one set of digit computing lines to their complement and for connecting the no-transfer relay to the transfer lines and the transfer relay to the no-transfer lines.

64. The combination of a computing mechanism comprising two sets of digit lines over which impulses denoting the numbers to be computed are sent for addition, and in which impulses denoting one of the numbers are sent over one set and impulses denoting the complement of the other number are sent over the other set for subtraction, transfer lines from said computing mechanism for addition, transfer lines from said computing mechanism for subtraction, and transfer mechanism controlled by one or the other of said transfer lines according to whether the numbers are added or one number is added to the complement of the other to effect subtraction.

65. In a computing mechanism comprising a set of energizing digit lines denoting one of the numbers to be added in a computation of addition or the subtrahend in a computation of subtraction, a second set of digit lines denoting numbers to be added in a computation of addition or the minuend in a computation of subtraction, a third set of digit lines extending into said computing mechanism, and means for interconnecting the second and third set of lines to transmit the value of the second set of lines for addition or the complements thereof for adding the complement for subtraction, transfer switches in the second set of lines, and transfer lines from the computing mechanism for controlling said transfer switches to cause a transfer in addition when the sum of two

digits is more than nine and in subtraction when the sum is equal to or less than nine.

66. The combination of two registers, means traveling from denominational order to denominational order of the registers for entering numbers therein, means for entering a number in one of the registers, means for transmitting a similar number under control of the first register to the second register and restoring both traveling means to home position, said first register being adapted to receive a number and to have its traveling means remain in moved position, means for adding the numbers in the registers together denominationally and entering the sum in the second register under control of the traveling means of said registers, means for returning the traveling means of both registers to home after the highest digit of the amount corresponding to the first register has been added and the result set up on the second register when the sum of the last digits is not greater than nine, a transfer mechanism, and means under control of the transfer mechanism when set for preventing operation of said returning means until the transfers have been added.

67. The combination of a keyboard, an amount receiving mechanism under control of the keyboard, the digits of a number being indexed from left to right and entered in said mechanism successively in the same order, a computing mechanism, means for introducing successively into said computing mechanism digits corresponding to the digits of the said number from right to left, printing mechanism including type members and a platen relatively shiftable for letter spacing, means for printing from said type members as the digits are entered into said computing mechanism and for moving the platen from left to right, and means for printing from said type means as the digits are introduced into said receiving mechanism and for moving said platen from right to left.

68. In a machine of the class described, the combination of a keyboard for introducing numbers into the machine, means for reversing the order of the digits of the number introduced, a printing mechanism comprising type members and a platen automatically shiftable from right to left or vice versa, means for controlling the printing and the shifting of the carriage from right to left as numbers are introduced, and means for controlling the printing and the shifting of the carriage from left to right after the order of the digits of the numbers has been reversed.

69. In a machine of the class described, the combination of a ten-key keyboard for introducing digits of a number denominational into the machine, a series of denominational contacts, a denominational movable contact movable over said series of contacts.

tacts as digits are entered to close denominational circuits, and means in said circuits to indicate the number of digits entered when said circuits are energized.

5 70. The combination of a total register, a recording device, relays for operating the recording device under control of circuits from said register, means for establishing said circuits successively, means for conditioning the register to clear it of the number recorded, and means for transmitting the number recorded to the register under control of said circuits.

15 71. The combination of a total register, a recording device, relays for operating the recording device under control of circuits from said register, means for establishing said circuits successively, means for transmitting the number recorded to the register under control of said transmitting circuits, a keyboard, circuits adapted to energize said relays upon depression of said keys, and means automatically effected under a total recording process for preventing the keys 20 from making said circuits.

25 72. The combination of a total register, a recording device, relays for operating the recording device under control of circuits from said register, means for establishing said circuits successively, means for transmitting the number recorded to the register under control of said transmitting circuits, a keyboard, circuits adapted to be established by said keys for energizing said relays, a number 30 receiving register adapted to receive a set-up from said keys, means for reversing transmission circuits from said receiving register to said first mentioned register, circuits for said relays connected to said transmission 35 circuits to be energized after reversing has been accomplished, and means automatically effected under a total recording process for preventing the closing of the relay circuits from the keys and the establishing of the 40 reversing transmission circuits.

55 73. The combination of two registers, means for entering numbers in one and electrically transmitting such numbers to the other, circuits for controlling the printing of such numbers as they are transmitted, circuits for controlling the printing of the numbers after they have been transmitted, printing magnets common to said circuits, and means for connecting said printing circuits from 60 said second register to said transmitting circuits to said register for reregistering the number taken off said register and recorded.

55 74. The combination of a register, and means for directly electrically transmitting digits of a higher denominational order in the register back to the register as a lower denominational order and coincidentally erasing the digits not transmitted.

65 75. The combination of a register, means for directly electrically transmitting digits

of a higher denominational order in the register back to the register as a lower denominational order and coincidentally erasing the digits not transmitted, a transfer mechanism in the transmitting line, and means under control of the highest denominational order to be discarded to energize the transfer mechanism in case the digit in said order is larger than the value of the digit it is desired to discard.

75 76. The combination of a register, means for directly electrically transmitting digits of a higher denominational order in the register back to the register as a lower denominational order and coincidentally erasing the digits not transmitted, a transfer mechanism in the transmitting line, means under control of the highest denominational order to be discarded to energize the transfer mechanism in case the digit in said order is larger than the value of the digit it is desired to discard, and means for preventing an entry in said register until the lowest denominational digit to be retained is being transmitted through said transfer mechanism.

80 77. The combination of a register, means for directly electrically transmitting digits of a higher denominational order in the register back to the register as a lower denominational order and coincidentally erasing the digits not transmitted, and means for recording on a record sheet the digits transmitted and entered into to the register.

85 78. The combination of a register, means for directly transmitting digits from said register back to said register, means for preventing entry of digits of denominational orders to be discarded, and means for increasing the value of the lowest order digit to be retained by one when the highest order to be discarded has a certain value.

90 79. The combination of a register, means for directly electrically transmitting digits of a higher denominational order in the register back to the register as a lower denominational order and coincidentally erasing the digits not transmitted, and means for selectively transmitting from any one of a plurality of denominational orders to the lowest denominational order in the register.

110 80. In a computing mechanism comprising two sets of computation digit lines and a set of result digit lines, a transfer switch mechanism in one of said computing lines, a complemental switch mechanism in said one set of lines between the transfer switch mechanism and the computing mechanism, means for energizing said transfer mechanism whenever the sum of the complement digit value 115 of an energized line in said one set and the digit value of an energized line in said other set is not greater than nine, means for transmitting the result over the result lines, and means for changing the result to the comple-

ment whenever the minuend is larger than the subtrahend.

81. The combination of a register in which numbers are entered, a result register, means for transmitting the number from the receiving register to the result register, said receiving register being adapted to receive a second number and to be cleared of the first number, a subtracting computing mechanism for subtracting the number in the receiving register from that in the result register by adding the complement of the number in the receiving register to the number in the result register, means for transmitting the result computed to the result register and clearing it of the subtrahend, and means changing the result under control of the second register, to its complement and transmitting the complement to the second register when the minuend is larger than the subtrahend.
82. The combination of two registers each comprising a plurality of denominational series of digit contacts adapted to be locked to represent digits and when locked to control transmitting circuits, one of said registers receiving the minuend and the other the subtrahend, a subtracting mechanism, a transfer switch mechanism in the circuits from the minuend register, complemental switches, means for operating the complemental switches for all processes of subtraction, means for computing the result under control of the circuits from the minuend register as controlled by the complemental switches and the circuits from the subtrahend register, means for throwing the transfer switches when the sum of two digits computed is not greater than nine, result lines energized by said computing mechanism and adapted to enter the result on the subtrahend register, and means controlled by the transfer switch mechanism for controlling the energization of the complemental switches when the sum of the last digits is not greater than nine for transmitting the result from the subtrahend register through said complemental switches to the subtrahend register, and clearing it of the subtrahend.

83. The combination of a minuend register, a subtrahend register, each register comprising contacts in transmitting circuits adapted to be established denominational, an adding mechanism comprising switches and operating relays controlled by said transmitting circuits and including result transmitting circuits extending to said subtrahend register to enter the result in said register as the number therein is cleared out, transfer switches in the lines from the minuend register operating to cause the addition of one in the next higher order when the sum of two digits in any order in addition is greater than nine, complemental switches located between the transfer switches and the adding mechanism, means for throwing said comple-

mental switches for subtraction and for causing actuation of the transfer switches when the sum of two digits as computed in subtraction in the adding mechanism is not greater than nine, and means controlled by the transfer switches during subtraction when the sum of the last digits added is not greater than nine to cause the complement of the sum computed and registered in the subtrahend register to be transmitted back to the subtrahend register as a correct negative result.

84. The combination of a minuend register, a subtrahend register, each register comprising contacts in transmitting circuits adapted to be established denominational, an adding mechanism comprising switches and operating relays controlled by said transmitting circuits and including result transmitting circuits extending to said subtrahend register to enter the result in said register as the number therein is cleared out, transfer switches in the lines from the minuend register operating to cause the addition of one in the next higher order when the sum of two digits in any order in addition is greater than nine, complemental switches located between the transfer switches and the adding mechanism, means for throwing said complemental switches for subtraction and for causing actuation of the transfer switches when the sum of two digits as computed in subtraction in the adding mechanism is not greater than nine, means controlled by the transfer switches during subtraction when the sum of the last digits added is not greater than nine to cause the complement of the sum computed and registered in the subtrahend register to be transmitted back to the subtrahend register as a correct negative result, a printing mechanism, and circuits for controlling the printing mechanism to print the true subtrahend, minuend, and the true positive and negative balances.

85. In a machine of the class described, the combination of a register comprising a series of digit relays and a series of denominational contacts in each relay adapted to be locked in closed position, a recording mechanism, means for successively establishing circuits over said locked contacts and operating said recording mechanism and subsequently again locking said contacts, a transfer relay in said circuits between the contacts and recording mechanism, means for preventing operation of the recording mechanism as the first circuit over a contact is made to energize the digit relay corresponding to said contact, a circuit for said transfer relay adapted to be closed in said energized digit relay if the value is equal to or greater than a predetermined value, means for preventing locking of said contact in said digit relay, and means disabling said preventing means for permitting operation of said recording mechanism

and permitting locking of a contact when transmission is made through a higher order contact.

86. The combination of a register comprising a series of digit relays and denominational contacts in each relay and means for locking said contacts denominational, a recording mechanism, means for establishing transmitting circuits from said contacts to said recording mechanism and to relays corresponding to said contacts, means for causing said locking means to function and for disconnecting said relays from said transmission circuits upon energization of said relays, means for preventing operation of said locking means and said recording means for certain denominational order transmitting circuits, means operated by said transmitting circuits after operation of certain of said relays for causing the addition of one to the value of the next transmission circuit, and means for disabling said preventing means for permitting said next transmission circuit to control said recording mechanism and permitting operation of said locking means after energization of a digit relay by said next circuit.

87. The combination of a register and a computing mechanism, circuits for transmitting digits from said register to the computing mechanism, and means operated by the computing mechanism for interrupting said circuits.

88. The combination of a register comprising digit relays, a computing mechanism comprising calculating relays, means for energizing said calculating relays under control of said digit relays, digit transmission lines leading over the contacts of said calculating relays to said digit relays and to transfer lines when required, transfer switch mechanism in said transmission lines and comprising a relay energizable by said transfer lines, and means operated by a digit relay when energized for interrupting the current to said digit relay and for closing the transfer lines and directing the current to the transfer switch mechanism.

89. In a machine of the class described, the combination of a plurality of registers, means for setting up one of the factors in a multiplying process in one register, means for transferring it in reversed order to a second register and preparing the first register to receive the second factor, and means for causing a multiplying process of the factors in said registers.

90. In an electrical calculating machine of the class described, the combination with a ten-key keyboard, means for receiving the digits of the multiplier in direct denominational order as the digits of the multiplier are indexed from highest to lowest denominational order, means for receiving the digits

of the multiplicand in reverse denominational order after the digits of the multiplicand have been indexed from highest to lowest denominational order, of means for multiplying the digits of the multiplicand from lower to higher order successively first by the units multiplier, then the tens multiplier, etc., and adding the partial products.

91. In a machine of the class described, the combination of means for receiving the multiplicand, means for receiving the multiplier, and means for receiving the product, a partial product computing device, a plurality of adding mechanisms, transfer means associated with each adding mechanism, means for setting up the units of the first partial product in the product receiving means, means for setting up the tens of the product in one adding mechanism to cause its addition to the units of the next partial product, and means for causing the sum so obtained to be added in the other adding mechanism to amounts in the product receiving means.

92. The combination of multiplicand, multiplier and product receiving mechanisms each comprising a denominational ratchet mechanism, means for setting up the multiplier and returning its ratchet mechanism to zero, means for setting up the multiplicand and retaining its ratchet mechanism in denominational position, means for carrying out the process of multiplication of units multiplied by the units, tens, etc., digits of the multiplicand and stepping the product ratchets as partial products are entered, and means for advancing the ratchet mechanism of the multiplier and multiplicand mechanisms and returning the ratchet mechanism of the products mechanism in preparation for multiplication by the tens multiplier.

93. In an electrical multiplying machine comprising a multiplicand register, a multiplier register and a product register, a reversing mechanism comprising a plurality of denominational switches selectively closed under control of the multiplicand register in accordance with the number of denominations of the multiplicand, and means for successively selecting and closing a higher order reversing switch after the process of multiplication by a denominational digit of the multiplier has been completed.

94. In an electrical multiplying machine comprising a multiplicand register, a multiplier register, a product register, means for performing the process of multiplication and registering the product in the product register, and means for discarding the lowest denominational digits of the product.

95. In an electrical multiplying machine comprising a multiplicand register, a multiplier register, a product register, means for computing adding and registering the product of the multiplicand by the units, tens, etc., of the multiplier in the product register,

and automatic means for discarding the lowest denominational digit in the product as the multiplicand is multiplied by a higher order multiplier digit and the product of the latter added to the former in the product register.

96. The combination of a plurality of registers each comprising circuit closing contacts adapted to be held in circuit closing position, means for entering a multiplier in one of said registers and a multiplicand in another of said registers, adding mechanisms associated with said multiplier register and the third or product register, means for controlling the adding mechanism associated with the product register from the amounts in the product register, a multiplying computing device for computing the units and tens of a partial product, means for adding the units of the first partial product to zero in the adding mechanism associated with the multiplier register and the sum to zero in the adding mechanism associated with the product register and entering it in the product register, and means for subsequently controlling the adding mechanism associated with the multiplier register according to the tens of the product to add the tens of the first partial product to the units of the next partial product.

97. In a division machine comprising means for receiving a dividend means for receiving a divisor, and means for selecting the first digit of the quotient by successively multiplying the highest and successively the next lower value digits of the decimal system by the divisor until the product so obtained is less than a corresponding portion of the dividend.

98. In a division machine comprising means for receiving a dividend, means for receiving a divisor, a multiplying mechanism comprising a series of ten digit relays each including contacts activated by the dividend mechanism and adapted to close against contacts representing the product of the value of the first contacts by the value of the energized relay, and a ratchet mechanism for successively energizing said relays in a predetermined order.

99. In an electrical multiplying machine comprising mechanisms for receiving the multiplier, multiplicand and product, each of said mechanisms including a single series of digit relays each provided with a series of denominational digit contacts, means for locking said contacts closed denominational as respective relays are energized, computing mechanisms each comprising a single series of adding relays and a transfer relay, and an electrical multiplying mechanism adapted when set in operation to automatically establish circuits to successively multiply all the digits of the multiplicand first by the units and then by the tens, etc. digits of the multi-

plier and to add the partial products in said adding mechanisms and register the result in the product receiving mechanism, said transfer relay functioning to add the units of transfer of a sum greater than nine in the next higher denominational order.

100. In an electrical subtracting machine comprising mechanisms for receiving the subtrahend and the minuend, each of said mechanisms including a single series of digit relays each provided with a plurality of denominational digit contacts, and means for locking said contacts in closed position successively in denominational order as the numbers are received; a computing mechanism comprising a single series of relays for adding the complement of the minuend to the subtrahend, a transfer switch, a relay for transmitting the complement of the digits in the minuend receiving mechanism to said computing mechanism and through said transfer switch for borrowing when necessary, means adapted when set in operation to establish circuits over the contacts of the subtrahend and the minuend receiving mechanisms denominational in ascending order to the adding mechanism, the circuits from the minuend receiving mechanism being connected to circuits of complemental value in said complemental relay, and means for operating said borrowing mechanism when required to reduce the value of one of said circuits when established for the next higher order digit.

101. In a machine of the character described, an addition device comprising a plurality of addition units representing respective addition tables, three sets of electrical lines one of which serves to energize the said addition units with corresponding lines energizing respective units and the other two of which are adapted to be interconnected in varying combinations over respective units, means for interconnecting electrical lines to produce mathematical combinations, said means being connected to said device over one of said three sets of lines and serving to transmit current impulses to said device thereby, second means for transmitting electrical impulses to said device over a second set of said three sets of lines, said first and second means serving to furnish electrical impulses over two of said three sets of lines and said device operating to interconnect one of said last mentioned two sets of lines with the third set of said lines to produce impulses in said third set of lines corresponding to the sum of the numbers whose corresponding impulses are transmitted over said other two sets of lines.

102. In a machine of the character described, a device comprising a plurality of units for interconnecting two sets of electrical lines in respectively varying mathematical combinations, three sets of electrical lines one

- of which serves to energize the said units with corresponding lines energizing respective units and the other two of which are adapted to be interconnected in varying combinations 5 over respective units, means for interconnecting electrical lines to produce mathematical combinations, said means being connected to said device over one of said three sets of lines and serving to transmit current impulses to said device thereby, second means for transmitting electrical impulses to said device over a second set of said three sets of lines, said first and second means serving to furnish electrical impulses over two of said 10 three sets of lines and said device operating to interconnect one of said last mentioned two sets of lines with the third set of said lines to produce impulses in said third set of lines corresponding to the mathematical combination of the digits whose corresponding impulses are transmitted over said other two sets of lines. 15
103. In a machine of the character described, a device comprising a plurality of 20 addition units for interconnecting two sets of electrical lines representing digit values in respectively varying mathematical combinations, three sets of electrical lines one of which serves to energize the said addition 25 units with corresponding lines energizing respective units and the other two of which are adapted to be interconnected in varying combinations over respective units and are common to a plurality of denominational 30 orders, means for interconnecting electrical lines to produce mathematical combinations, said means being connected to said device over one of said three sets of lines and serving to transmit current impulses to said device 35 thereby, second means for transmitting electrical impulses to said device over a second set of said three sets of lines, said first and second means serving to furnish electrical impulses over two of said three sets of lines and said device operating to interconnect one of said last mentioned two sets of lines with the third set of said lines to produce impulses in said third set of lines corresponding to mathematical combinations of 40 the digits whose corresponding impulses are transmitted over said other two sets of lines. 45
104. In a device of the character described, a plurality of sets of digit lines common to all denominational orders within the capacity 50 of the machine, first means for interconnecting certain sets of said lines in accordance with the multiplication tables, second means for interconnecting certain sets of said lines in accordance with the addition tables, and 55 means under cyclical electrical control for operating said first means to produce respective partial products and for operating said second means to add said respective partial products to produce the total product. 60
105. In a device of the character described, 65
- a plurality of sets of digit lines common to all denominations, first means for interconnecting certain sets of said lines in accordance with the multiplication tables, second means for interconnecting certain sets of said lines in accordance with the addition tables, and means for operating said first means to produce respective partial products and for operating said second means to add successive 70 respective partial products to the total of previous partial products to produce the total product. 75
- In testimony whereof I have signed my name to this specification. 80
